UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 27, 1919. Serial No. 285,411.

To all whom it may concern:

Be it known that I, SAMUEL B. WILLIAMS, Jr., a citizen of the United States, residing at Brooklyn, in the county of Kings and 5 State of New York, have invented certain new and useful Improvements in Telephone-Exchange Systems, of which the following is a full, clear, concise, and exact description.

This invention relates to improvements in 10 telephone exchange systems, and has for its object the provision of means for insuring prompt and efficient service in telephone exchanges, in which connections of a varying nature may be established with devices including selectively operable switches.

With this object in view, according to one 20 of the features of the invention, connections between two telephone lines terminating in an exchange may be established under the control of operators divided into a plurality of separate and distinct groups, each group of operators handling calls initiated from stations of a certain character, such as stations entitled party line, message rate, flat 25 rate, etc., service.

Related to this feature are other features 30 which have to do with the automatic connection of a subscriber's line to an operator's position from which the establishment of a connection may be controlled by means including selectively operable switching devices, the manner in which an operator's position is selected being dependent on the character of the calling station.

35 A further feature of the invention has to do with the provision of emergency apparatus, such as relays, which may be taken into use at will and without disturbing the operation of the system.

40 Provision is made for a complete alarm system, whereby attendants may be informed of the character and location of troubles that may occur in the various parts of the telephone exchange.

45 Means are provided whereby a part of a group of selective apparatus may be tested for unstandard conditions, and repaired, without interfering with the service for which the group of apparatus is provided.

50 Still another feature of the invention has

to do with an improved arrangement for enabling an operator to identify the character and the number of the calling line.

Improved automatic means are provided 55 for controlling the connection of an operator's telephone set with a connecting link employed in extending a connection.

A feature of the invention has to do with the barring of an operator's position, if it is not desirable to have calls extended thereto. 60

Another feature of the invention contemplates the provision of improved means for controlling the charging for calls and the severing of connections.

Still a further feature of the invention relates to the provision of signaling lamps for 65 enabling an operator to properly supervise the establishment of a connection.

Means are also provided whereby a semi-automatic operator may at will maintain 70 connection between her position and the calling subscriber's line.

According to another feature of the invention, improved means are provided for testing lines for their busy or idle condition, 75 to determine their character and also their location relative to the calling line.

Another feature of the invention has to do with the provision of a special connecting 80 unit which may be used for connecting with subscribers' lines.

These and other features of the invention will more clearly appear from the following detailed description of a semi-mechanical telephone system in which they are embodied, and the appended claims. 85

The drawings, when placed together in the manner illustrated in Fig. 26, represent the circuits and apparatus employed in establishing a connection between two subscribers' lines terminating in a semi-mechanical exchange. Figs. 20, 21 and 22 illustrate a special connecting equipment which may be brought into association with the regular equipment illustrated in the figures indicated in Fig. 27. Figs. 28 to 34 inclusive are views of the commutators employed with the various switches used in the system. Fig. 35 is a schematic view of the switches employed in establishing connection between subscrib- 95 100

ers within the same exchange. Fig. 36 is a diagrammatic view of the fundamental circuits employed.

5   *Fundamental plan of operation.*

This system is arranged for giving telephone service in large exchange areas, divided into smaller office areas. In such exchange areas it is frequently advisable to 10 make sub-divisions so as to equitably charge for calls from one office area to another and also to provide for growth. In order to provide an economical and efficient telephone system, it may also be advisable to 15 connect all of the subscribers' lines in the exchange area to the same telephone switchboard. In systems of this sort it is necessary to advise the operator of the particular office area in which the calling subscriber 20 is situated. When such a large number of lines is connected to a single switchboard, the number of operators' positions required is larger than can be efficiently served through the single machine switch used as 25 the connecting unit selector because of the physical limitations in the construction of these switches. Furthermore, the throwing together of all of the operators into one electrically inter-related group, while desirable 30 from the standpoint of flexibility and efficiency of the machine switching apparatus itself, may be objectionable on account of the increased possibility of all service being temporarily shut off due to some accident occurring in the selecting apparatus or 35 circuits.

When the number of telephone lines is sufficiently large, they may be divided into 40 two general classes. One class may include lines, the extension of which requires relatively complicated, and the other class, lines requiring relatively simple operations on the part of the operator.

In the system described herein, the 45 operator group serving one of the two general classes of lines above mentioned is not large enough to be efficiently served by a single connection unit selector. However, because of the desirability of giving service 50 at all times, the apparatus by means of which the calling lines are extended to these operators is so arranged that the calls may be limited at times to part of the operators to provide for testing or for making 55 repairs on the apparatus serving the remaining part of the operators of the same group. A telephone system embodying such arrangement is described and claimed in patent of Samuel B. Williams, Jr., and 60 Ralph L. Quass, No. 1,330,417, dated February 10, 1920.

The other general class of lines in the 65 illustration of the system herein described, is so large as to require a number of operators greater than can be efficiently served

by a single connecting unit selector. This group of operators is therefore divided into sub-groups but means are provided whereby any line of this general class has access to any operator in either of the sub-groups. 70

The general arrangement of the apparatus and circuits for accomplishing this result is described and claimed in patent No. 1,324,365 dated December 9, 1919, to Samuel B. Williams, Jr., and Ralph L. 75 Quass.

Each of the two general classes of lines is divided into smaller groups of lines. In the illustration of this invention, the number of lines in each such group is limited 80 to 400, which lines are served by a group of line finders and any line finder is able to make connection with any of the 400 lines. In order to further effect an efficient and speedy connection with any of the 85 400 lines in the group, it is further divided into groups of 50 lines each. Each line finder switch is, therefore, provided with eight sets of wipers through which connections may be made to terminals of any of the 400 lines. Each group of 50 lines has associated with it certain common apparatus suitably connected together to form a so-called "group circuit." The eight group circuits serving the 400 lines terminating 90 at a single line finder are electrically inter-related and connected to apparatus suitably connected together to form a so-called "starting circuit." Each line finder switch is connected to a connecting unit selector 100 which, together with other apparatus suitably interconnected, form a so-called "finder circuit." The finder circuits serving a group of 400 lines are electrically inter-related so that but one of the finder circuits 105 is operatively connected to the starting circuit at any time. Associated with each group of electrically inter-related finder switches is apparatus connected together 110 to form a so-called "operator selecting circuit." This circuit is electrically inter-related with its associated group of finder circuits in such a manner that but one of the group of finder circuits can be in operative connection with the operator's selecting 115 circuit at a time. The operator's selecting circuit is electrically connected to the common part of those operators' desks which contain the connecting units to which the connecting unit selector of the finder circuits 120 has access. Each operator selecting circuit can be electrically connected to any finder circuit of the group, and to any operator to which the associated connecting unit selector has access. Furthermore, the 125 operator selecting circuit is adapted to serve all the groups of finder circuits having access to the group of operators, and means are provided so that but one idle operator's position can be selected by any 130

single finder circuit even though several finder circuits, each in a different finder group, may be selected by idle operators' positions. After the selection of the idle 5 operator's position, the selecting circuit is disconnected from the finder circuit and may be used by other finder circuits of the same group to select other idle operators' positions.

10 The position apparatus of all the operators' positions in one group, is electrically inter-related so that a uniform and equitable distribution of the load is effected in such a manner as to permit of but one call 15 being distributed to each idle operator in a group until all operators of the group have received a call. After this all the operators' positions which are idle are again rendered responsive to selection by the operator selecting circuit. An operator's position is 20 thus idle and responsive to selection by the operator's selecting circuit only when the operator's position apparatus is not connected to any of the connecting units in the 25 position, has not been selected, the position is occupied by an operator, and the group of positions has been rendered responsive because each of the previously idle operators has received her quota of one call. If the 30 position is busy when each of the other positions has received its quota of one call, that position will not receive a call until all the positions which were idle at that time have received their quota of one call.

35 In the smaller of the two general classes of lines, each of the 400 lines is served by two groups of finders, each of which has access to the same group of operators' positions. The operator selecting circuit is so 40 arranged that part of the selecting apparatus and corresponding operators' positions can be electrically disassociated from the other part. In the illustration, the odd positions form one part of the operator selecting 45 circuit and the even positions another. If it is desirable, one-half the finder circuits can be made non-responsive to calls and tested together with that part of the operator's selecting circuit serving either sub-division of 50 operators' positions.

In the larger of the two general classes, each group of 400 lines is served by two entirely separate groups of finder circuits, 55 each having access to one of the sub-groups of operators' positions serving these lines. The line finders on a single frame are therefore not connected to connecting unit selectors which are situated on the same frame, one group of line finders being connected to 60 connecting unit selectors on frames having access to one sub-group of operators, the remaining group of line finders being connected to connecting unit selectors having access to the other sub-group of operators' 65 positions. The line finders are suitably ar-

ranged to provide for depriving half of each of the line finder frames and half of each of the connecting unit selector frames of power, and yet permit the automatic distribution of calls to the two groups of operators. The starting circuits controlling the finders on this group of frames are so arranged as to give preference in the routing of the calls of the two groups of finder circuits, so that for a given 400 lines, all calls 70 will preferably be sent to operator group 1^A, for example. If, for any reason, this group of operators is not in a responsive condition or all the finders having access to this group of operators are busy, the call is 75 automatically routed to the other operator group, 1^B for example. If one-half the frames serving this large class of lines are wanted to give preference to operator group 1^A and the other to operator group 1^B, a 80 more uniform distribution of the load is effected. Furthermore, by means of this arrangement any of the operators in both sub-groups, 1^A and 1^B are available for calling lines. 85

Only one of the connecting units is shown complete and the multiple connections that exist between corresponding sets of switch terminals are omitted to avoid confusion in the drawings. The manner in which the various operative positions of one group are related is schematically illustrated in Fig. 7. Each of the groups of connecting unit selectors has associated with it certain selection 90 controlling apparatus like that associated with the connecting unit selector shown in Fig. 3. Two groups of relays shown in detail in Fig. 6, are provided for controlling the selection of an idle operator's position 95 by a connecting unit selector. There are as 100 many groups of these relays for each group of finder circuits (Fig. 3) as there are operators' positions in a certain group. The circuit in Fig. 5 serves to link the respective 105 groups of relays above mentioned to the group of finder circuits served by these relays. Each of the above-mentioned groups of relays comprises relays 601, 602 and 603. 110

As the line finder switches and the connecting unit selectors in themselves are not 115 novel, they are shown merely diagrammatically. These switches may be substantially like the switch illustrated and described in the patent to James L. McQuarrie No. 1,177,044, issued March 28, 1916. The line 120 finders and the connecting unit selectors are alike in all substantial respects. Each comprises a longitudinally movable shaft carrying as many sets of brushes as there are groups of stationary terminals to be engaged. In addition to the wipers, each line 125 finder and connecting circuit selector carries commutators comprising multiple brushes arranged to engage commutator segments shown in Figs. 28 and 29. Under the cap- 130

tion "line finder" and the caption "connecting circuit selector," the front and rear views of the commutator segments carried by these selectors are illustrated. The commutator brushes engaging the front of the commutator plates are connected to sub-battery.

It will be noted that several battery current sources are shown in the drawings. In practice, the current necessary for operating the system is derived from a common source. This common source of power for operating the system consists of battery which is connected to ground at an intermediate point and is thereby divided into positive and negative batteries. The positive battery is termed "sub-battery" and is indicated by two cells while the negative battery is termed "main battery" and is indicated by four cells. Thus a connection traced from main battery to sub-battery employs a combined potential of both positive and negative batteries impressed upon the circuit, whereas a circuit traced from the positive pole to ground has only the potential of sub-battery impressed upon it, and finally a circuit from the negative pole to ground has only the potential of main battery impressed upon it, but of opposite polarity to that impressed by a connection from sub-battery to ground.

The other selectively operable switching devices used in this system are of substantially the same construction as the one described in Patent No. 1,123,696 to E. B. Craft and J. N. Reynolds granted January 5, 1915. For the purpose of distinguishing the various selector switches from each other, they will be hereinafter referred to in the following manner:

District selector, Fig. 12; cord finder, Fig. 13; incoming selector, Fig. 18; and final selector, Fig. 19.

The commutators of these selectors are illustrated under corresponding captions in Figs. 30, 31, 32 and 34. These selector switches have individual tripping devices operable in the manner described in the mentioned patent to E. B. Craft and J. N. Reynolds, except the cord finder which being provided with only a single set of brushes has no tripping shaft.

For controlling the circuits of the organization, there are a number of sequence switches which may be of the type disclosed in Patent No. 1,127,808 to John N. Reynolds and Charles F. Baldwin granted February 9, 1915, which consists of an electromagnetically controlled motor or driving mechanism and a number of associated switch cams. For the sake of clearness in illustrating, the sequence switch cams are schematically illustrated, rather than in their mechanical relation to the power magnets.

The following sequence switches are

illustrated in the drawings: 100, 150, 300, 900, 1000, 1200, 1300, 1350, 1400, 1800, 1900, 2000, 2100, 2200 and 2400. The sequence switches appear on the figures designated by the first digit of the three figure numbers and first two digits of the four figure numbers, respectively. This scheme of numbering has been adopted also for other apparatus and the conductors, and it will be found that as far as possible the various apparatus and conductors appearing on a figure are designated by numerals beginning with numerals corresponding to the number of the figure. The cams of the sequence switches are designated by the numeral of the respective sequence switch power magnet to which are added letters of the alphabet (capitals). Register switches shown in Figs. 15 and 16 are of substantially the same type as the sequence switches. The cams controlled by these registers are also designated by a number corresponding to the designating number of the register power magnet and letters of the alphabet (capitals).

Sequence switch 100 or 150 performs one complete revolution upon the initiation of a call for the purpose of delaying subscribers, belonging to the groups to which the calling subscriber belongs, from initiating calls during a certain period of time.

Sequence switch 300 controls the operation of the line finder and the associated connecting units selector. The following are the resting positions of this sequence switch:

1. Normal.
2. Awaiting starting circuit.
3. Awaiting starting circuit release.
4. Hunting calling line.
5. Awaiting preceding finder circuit.
6. Awaiting operator selecting circuit.
7. Awaiting operator selecting circuit.
8. Releasing operator selecting circuit.
9. Hunting connecting unit.

14. Talking.
15. Line finder at tell-tale.
16. Connecting circuit selector at tell-tale and line finder returning.

17. Connecting circuit selector return.
- Sequence switch 900 is the listening key sequence switch and has the following resting positions:

1. Normal.
2. Awaiting other listening key sequence switches.
3. Listening in.
4. Listening out.
5. Awaiting district selector on disconnect.

- Sequence switch 1000 controls the operator's selecting circuit and has the following resting positions:

1. Awaiting selection.
2. Position idle.
3. Position busy.
- Sequence switch 1200 controls the opera-

- tion of the district selector and has the following resting positions:
1. Normal.
  2. Awaiting sender.
  3. Brush selection.
  4. Brush tripping; awaiting sender.
  5. Group selection.
  6. Awaiting relay.
  7. Trunk hunting.
  8. Awaiting sender on wipe-out return.
  9. Office selection.
  10. Wipe-out return.
  11. Selection beyond.
  12. Awaiting recording operator.
  13. Double disconnect.
  14. Ringing.
  15. Talking.
  16. Overflow.
  17. Return.
- 20 The sequence switch 1300 controls the operation of the cord finder by means of which an idle operator's sending and controlling equipment may be connected with a selected connecting circuit. The resting positions of this sequence switch are as follows:
1. Normal.
  2. Hunting.
  3. Awaiting class and district brush registers.
  4. Awaiting district group register.
  5. Awaiting office register.
  6. Awaiting number registers.
  7. Awaiting key release.
  8. Awaiting sender.
  15. Awaiting disconnect.
  17. Return.
  18. Awaiting allotment.
- Sequence switch 1350 is used for allotting an idle cord finder and its associated sending and controlling equipment through the agency of the sequence switch 1300. This allotting sequence switch has no normal position and preselects in its positions 1, 2, 4, 5, 7, 8, 10 and 11 different sending and controlling equipments for connection with the connecting circuit.
- Register sequence switch 1500 controls the district brush and district group selection, in some positions directly and in other positions in cooperation with register sequence switch 1525; register sequence switch 1550 cooperates with register 1500 under certain conditions to control the district group selection; register sequence switch 1600 controls the incoming brush, i. e., the thousands selection register; sequence switch 1625 the incoming group, i. e., the hundreds selection; sequence switch 1650, the tens selection; 1675 the units selection; register 1690 the stations selection.
- Sequence switch 1500 operates also as a class-register control, i. e., to determine the performance of certain operations depending on the character of the connection desired. The following is a list of the various kinds of operations that may be controlled in certain positions of this sequence switch in which its cams S, T and U are closed.
- I. Positions:—1—3/8—10—12/17: Want number pulses. 70
  - II. Positions:—3/4—6/8—12/13—15/17: Want stations pulses.
  - III. Positions:—2—6—11—15: No automatic listening out.
  - V. Positions:—1—5—10—14: No stations pulses. 75
  - VI. Positions:—1/3—5—7—9/12—14—16—18: Skip tandem.
  - VIII. Positions:—2—9—11—18: No number pulses. 80
  - IX. Positions:—2—6—11—15: Double disconnect.
  - X. Positions:—4—8—13—17: Toll pilot.
- The following kinds of connections may be established in certain positions of this sequence switch:
- Semi-automatic; positions 1—5—10—14.
- Manual with exclusive trunks; positions 3—7—12—16.
- Recording; positions 2—11; 6—15.
- Tandem; positions 4—13; 8—17.
- Traffic desks; positions 9—18.
- Sequence switch 1800 controls the operation of the incoming selector and has the following resting positions: 95
1. Normal.
  2. Brush selection.
  3. Trip; awaiting sender.
  4. Group selection.
  5. Awaiting relay.
  6. Trunk hunting.
  7. Awaiting sender.
  8. Final brush selection.
  9. Awaiting sender.
  10. Tens selection.
  11. Awaiting selector.
  12. Hunting.
  13. Awaiting trunk closure.
  15. Ringing "plus" party.
  16. Ringing "minus" party.
  17. Overflow.
  18. Return.
- The sequence switch 1900 controls the circuits of the final selector. The following are its resting positions: 115
1. Normal.
  2. Brush selection.
  3. Trip; awaiting sender.
  4. Tens selection.
  5. Awaiting sender.
  6. Units selection.
  7. Awaiting incoming selector.
  13. Testing line; P. B. X. hunting.
  15. Return on busy.
  16. Talking.
  17. Busy back.
  18. Return.
- The sequence switches 2000, 2100 and 2200 control the switches and circuits employed in the emergency connecting apparatus. 130

The sequence switch 2000 controls the district selector of this unit and has the following resting positions:

1. Normal.
5. Awaiting sender.
3. Brush selection.
4. Trip; awaiting sender.
5. Group selection.
6. Awaiting relay.
10. Trunk hunting.
8. Awaiting sender on wipe-out return.
9. Office selection.
10. Wipe-out return.
11. Selection beyond.
15. Awaiting recording operator.
13. Double disconnect.
14. Ringing.
16. Talking.
17. Overflow.
20. 18. Return.

The sequence switch 2100 is the listening key switch of the special connecting unit and has the same resting positions as the sequence switch 900 with the exception of 25 position 8.

The sequence switch 2200 controls the incoming selector used in this unit, and has the following resting positions:

1. Normal.
30. 2. Awaiting sender.
3. Brush selection.
4. Trip; awaiting sender.
5. Group selection.
6. Awaiting relay.
35. 7. Trunk hunting.
8. Awaiting sender.
9. Final brush selection.
10. Awaiting sender.
11. Tens selection.
40. 12. Awaiting sender.
13. Unit selection.
14. Awaiting sender.
16. Talking.
17. Overflow.
45. 18. Return.

In outline, the operation of the system in the embodiment disclosed is as follows: When a subscriber initiates a call, he causes the closing of a starting circuit that is common to a number of line finder switches, and also causes the energization of a trip magnet controlling the set of line-finder wipers arranged to engage the group of terminals in which his line terminates. The closing 50 of the starting circuit causes a preselected one of the finder switches to operate. The apparatus which brings about the energization of the trip magnet operates to prevent temporarily the trip magnets of other 55 groups of lines from being energized by calls that may at the time be initiated in the other groups.

As soon as the wipers of the finder switch are tripped, another finder switch is brought

65 into operative relation with the starting circuit, and then the starting circuit is released and made available for the use of calling lines in groups other than the group in which the first-mentioned calling line is located. That group is deprived of control 70 over the starting circuit until after the finder switch has connected with the terminals of the calling line. The object of this is to prevent the same calling line from starting a second finder switch in the interval before 75 the calling line is found.

When the finder switch wipers complete 80 connection with the terminals of the calling line, the operator's selecting circuit is operated to determine to which of a number of operators' positions the calling line shall be extended. The selection is effected through the medium of selection controlling apparatus that is common to the connecting circuit selector switches to which the finder 85 circuits lead, and through the operators' positions to which these selector switches have access. When a finder circuit is ready to extend a call, it first causes all of the operators' positions that are idle or awaiting a 90 call, to indicate their receptive condition by operating corresponding switch parts upon the common selection controlling apparatus. The selection controlling apparatus responds 95 by preparing a path for the energization of a connecting circuit selector tripping magnet corresponding with the first operator's position in the series that is ready to receive a call. The finder circuit that is extending the call then sends a tripping impulse over the path thus prepared. When the tripping magnet operates, it starts the movement of the selector switch. At the outset of the movement, the set of wipers is tripped that corresponds with the preselected operator's 100 position, and immediately thereafter the common selection controlling apparatus is released and made available for determining the selection of other operators' positions by other cord selector switches and finder 105 circuits.

110 After the set of cord selector wipers has been tripped, it continues its upward movement, successively engaging the terminals of the connecting circuits located at the operator's position that has been selected, and stops upon the terminals of the first connecting circuit encountered that is idle and available for use.

115 Prior to this, and at the instant that the operator's position is selected and the corresponding trip magnet energized, a tone is produced in the operator's telephone receiver which notifies her that her position has been selected and that a call is coming. At the same instant, the listening-in switches, associated with all of the connecting circuits of the position, are rendered in-

- operative so that the operator cannot interfere with the coming call by listening in on a cord circuit after the position has been selected and before the call arrives.
- 5 When the cord selector switch stops on the terminals of the selected connecting circuit, it lights a lamp associated with that circuit on the operator's position, and at the same time causes the tone in the operator's telephone receiver to cease. It also moves the listening key sequence switch of the selected connecting circuit to bring the operator's telephone set into connection with the selected circuit, and operates a relay
- 10 that closes the circuit to the operator's telephone instantly and in advance of its closure by the sequence switch, thus saving time in establishing communication between the calling subscriber and the operator.
- 15 At the operator's position there is provided a set of counting relays (Fig. 11) that are operated under the control of an interrupter (Fig. 11^A) connected with the subscriber's line in a manner to send out impulses designating the class of service to which the calling subscriber is entitled. These counting relays register the impulses by displaying certain visual signals at the operator's position. The selection of the operator's position results also in the starting of an allotted cord finder (Fig. 13) for attaching an idle operator's sending and controlling equipment (Figs. 14, 15 and 16) to the operator's connecting circuit selected for
- 20 use. This sending and controlling equipment comprises an operator's keyboard on which the operator registers the number of the called line by depressing keys of the various rows corresponding to the digits of the called number. Under the control of the register sequence switches, the counting relays (Fig. 17) receive a certain number of impulses from the various switches. The succession in which the various switches are controlled by the counting relays is determined by sequence switch 1300 and the sequence switches associated with the respective selectors. First the district selector is operated in accordance with the setting of
- 25 the register sequence switches 1500 and 1525. The setting of the district selector under the control of the sequence switches is determined by the setting of sequence switches 1550, which is the class register controller.
- 30 After the setting of the district selector, the incoming selector is operated in accordance with the adjustment of registers 1600 and 1625; and then the final selector in accordance with setting registers 1625, 1650 and
- 35 1675.

While the calling and called lines are interconnected, the operator can bring her telephone apparatus into or out of connection with the circuit by pressing the listen-

ing-in key individual to the circuit or the 65 listening-out key common to all of the circuits. In pressing a listening-in key to bring her telephone set into connection with one of the connecting circuits, the telephone set is automatically disconnected from any 70 other connecting circuit with which it may at the time be in connection. The operator may connect her telephone set also to one of the parties to the exclusion of the other party.

75 The operators' positions are arranged to receive incoming calls by way of several groups of finder circuits with their associated selector switches, and to prevent interference between simultaneous calls originating in different groups of finder circuits, the arrangement being such that when the selecting apparatus of one group acts to select a particular operator's position, that position is made inaccessible to the selecting apparatus and finder circuits of another group. The different operators' positions are also so inter-related that the positions are kept 80 equally busy, this being accomplished by rendering each position inaccessible to incoming calls after it has received a call or after the operator has supervised an existing connection, and restoring its accessibility 85 only when all of the positions have received a call or supervised a connection. The positions are then all restored to accessibility 90 excepting such as may at the time be attending to a call or to a connection, or have all of their connected circuits in use, or may be out of use by the operators being absent 95 from the position.

100 It should be noted also that the various selectively operable switching devices have access to 400 telephone lines each, and for this reason impulses are transmitted by the 105 switches to the sender in accordance with a numerical system differing from the numerical system in accordance with which the sender keyboard is arranged. Such systems are well known in the art as translation 110 systems, and their detailed description is not deemed necessary in the present application.

115 The sending and controlling equipment are automatically restored to normal upon the completion of the selecting operations or at any time under the control of the operator. The other apparatus may be restored, under the control of the operator, at any 120 change or after the establishment of the connection. In response to the serving of a successful connection or under the control of separate means, the calling line is charged for the call in accordance with the setting of the class-of-service apparatus. 125 Means are operable when the operator is connected to the particular connecting unit, whereby a suitable signal may be displayed,

which signal is arranged with other similar signals so as to give the operator an indication of the number of the calling line, thereby enabling her to check the calling line number given to her by the calling subscriber. This signal may also be used by the operator for obtaining the number of the calling line if she so desires, such operation requiring an extended time on the part of the operator because of the large number of similar signals which would be required for an exchange system of large size.

The operator's desk is also provided with connecting units of a different character than those above described, by means of which connection may be completed between two lines without any call having been originated by either of the parties desired. These units are termed double ended or special connecting units (Figs. 20 and 22). These special units are provided with means whereby connection may be made from the operator's desk to a subscriber's line even though that line is busy due to connection to it from some other portion of the operator controlled machine switching apparatus. These units are necessary for completing connections when the line called for, in the ordinary establishment of a connection, is busy, and the operator desires either voluntarily or upon request of the calling subscriber to make connection to such line at a later period of time. These double ended units are also useful in case of trouble of the operator controlled machine switching apparatus for extending the connection to the wanted line, so as to enable the operator to make connection through the terminals of the calling line and make connection with the terminals of the wanted line over an entirely different path without destroying the original connection to the operator from the calling subscriber.

Provision is made also for party-line ringing, private branch exchange hunting, reverting connections, trouble indicators and other operations necessary in operating large telephone exchange systems.

While the various features of the invention are disclosed as embodied in a call distributing semi-mechanical exchange system employing panel-type power-driven switching apparatus, they may be applied to systems of a widely varying character, without departing from the spirit of the invention. Only the semi-mechanical part of a telephone exchange system is disclosed in detail, but, obviously, the new and useful features herein disclosed may be employed when switching to manual or toll offices, special operators' positions, etc. The manner in which such switching operations may be accomplished is well known in the prior art as exemplified by Patents No. 1,232,944

to Alben E. Lundell, granted July 10, 1911, 65 and Alfred H. Dyson, No. 1,334,294 granted March 23, 1920.

DETAILED DESCRIPTION OF OPERATION.

Establishment of connection between two 70 lines terminating in one and the same semi-mechanical office.

The circuits and apparatus dealt with in this portion of the description are those illustrated in the figures designated in Fig. 26.

Initiation of call.

The subscriber at substation A entitled to flat rate service, desiring to initiate a call, 80 removes his receiver from the switchhook, whereupon line relay 101 becomes energized in the well-known manner by current flowing through the line circuit and the contacts of the cut-off relay 102.

85

Group circuit.

Upon energization, the line relay 101 connects sub-battery through its right-hand armature and front contact and a conductor 90 102¹, which is common to fifty line relays of the group to which the calling line belongs, the normal contacts of keys 190^b and 124^a, the contacts of the cam 100^c, the normal contact of key 124^b, and the winding of relay 104 to ground. The relay 104 closes a circuit from main battery, through the left-hand winding of relay 105, the front contact and armature of relay 104, conductor 111, the left-hand armatures and back contacts of the relays 104 associated with the preceding group circuits, the right-hand, back contacts and armatures of relays 200, 201 and 202 to sub-battery.

95

The relay 105 becomes energized and 105 closes a circuit from main battery, through its right-hand winding and the windings of trip magnets 106 and 106^a (individual to the group of lines to which the calling line belongs) in parallel, the right-hand front contact and armature of relay 105, conductor 112, the right-hand back contacts and armatures of the relays 105 associated with the preceding group circuits, the winding of relay 200 and the right-hand armatures and back contacts of relays 201 and 202 to sub-battery. The relay 105 is locked up through this circuit, and the trip magnets 106 and 106^a and the relay 200 become energized. Another circuit closed by relay 105 extends 115 from sub-battery, through the left-hand armature and front contact of relay 105, the contacts of cams 100-B and A and the power magnet of sequence switch 100 to main battery. The sequence switch 100 is moved out of position 1, and under the control of its normal contact A is caused to 120 perform a complete revolution in such time 125

as is required for the line finder to find any line in the group.

Operation of the line finder under control of the starting circuit.

- 5 The line finder associated with sequence switch 300 being the first in order on the preferred side of the frame, this sequence switch is in position 2 and closes a circuit 10 from sub-battery, through the right-hand armatures and back contacts of relays 202 and 201, the right-hand armature and front contact of relay 200, the left-hand armature and back contact of a relay 204, the 15 normal contact of key 240^e, conductor 252 (Fig. 3, see also Fig. 4), the lower contacts of cam 300^T, and the right-hand winding of a relay 330 to main battery, and a parallel path through the lower contacts of cam 20 300^T, the lower right-hand and upper left-hand contacts of cam 300^Y, the left-hand winding of relay 330, the left-hand contacts of cam 300° and a resistance 325 to main battery. The relay 330 becomes energized 25 and closes a locking circuit for itself from main battery, through resistance 325, the left-hand contacts of cam 300°, the low resistance left-hand winding of relay 330, the right-hand contacts of cam 300^N, the left- 30 hand front contact and armature of relay 330, and the back contact and armature of a relay 331 to sub-battery. The relay 330 closes also a circuit from main battery, through the power magnet of sequence 35 switch 300, the left-hand contact of cam 300^A, the upper right-hand contact of cam 300^C, the right-hand front contact and armature of relay 330, the upper left-hand and lower right-hand contacts of cam 300°, the 40 commutator segment M and commutator brush of the associated connecting unit selector to sub-battery.
- The sequence switch 300 is moved out of position 2, and under the control of its normal cam A and the right-hand contact thereof to sub-battery is moved into position 3. In each sequence switch to be herein described, the local circuit therefor through its A cam extends through a contact of said 50 cam to sub-battery. When the sequence switch moves out of position 2, the lower contacts of cam T are opened and this sequence switch cannot be selected upon a subsequent energization of the starting circuit.
- 55 As soon as it reaches position 3, a circuit is closed from main battery, through the winding of the up-drive magnet 328 of the line finder, the lower contacts of cam 300^P, the right-hand front contact and armature of relay 330, the upper left-hand and lower right-hand contacts of cam 300°, and the commutator segment M of the connecting circuit selector to sub-battery. In response to the energization of magnet 328, the line 60 finder is caused to travel in an upward di-

rection. During the initial period of the upward movement and before the brushes are opposite their corresponding terminal bank sections, due to the energized condition of the tripping magnets 106 and 106^a, 70 a set of line finder brushes, arranged to serve the group of lines to which the calling subscriber belongs, is tripped and thus permitted to engage the terminals of the respective section. The commutator brush thereupon connects sub-battery, through a commutator segment K, the left-hand contacts of cam 300^L, conductor 250, key contact 240^C and the windings of relays 201 and 203 in parallel to main battery. The relays 201 and 203 become energized and lock up through the left-hand front contact and armature of relay 201, the right-hand armature and back contact of relay 204, key contact 240^d, conductor 257, (Fig. 4, see also Fig. 3), and the contacts of cams I of all the sequence switches 300 on the preferred side of the line finder frame to sub-battery. This locking circuit is maintained closed until the sequence switch 300 of another line finder switch on the same side of the frame is moved into position 2 and opens the contacts of its cam I. The relay 201 opens the locking circuit including relays 200 and 105, 80 and the trip magnets 106 and 106^a.

The relay 203 closes a circuit from sub-battery, through its left-hand armature and front contact, key contact 240^a, conductor 248, the upper contact of cam 300^P and the power magnet of sequence switch 300 to main battery, for moving this sequence switch out of position 3 and into position 4; and another circuit from sub-battery through its right-hand armature and front contact, key contact 240^b, conductor 249 (Fig. 4, see also Fig. 3), the lower contacts of cam 300^G of the sequence switch 300; the upper contacts of cam G, the lower right-hand contact of cam D, and the power magnet of the sequence switch like 100 300 associated with the second line finder on the same side of the frame to the main battery. In response to the closure of this circuit, the idle sequence switch associated with the second line finder on the same side of the frame is moved out of position 1 and into position 2, and thus renders its associated line finder and connecting unit selector 105 ready for service upon the next energization of the starting circuit.

When the sequence switch associated with the second or other line finder on the same side of the frame moves into position 2, it opens the contacts of its cam I, whereupon the relays 201 and 203 become deenergized 115 120 and the starting circuit is ready to start other finders.

Seizing calling line.

As soon as the line finder engages with 130

its wiper 308 the terminal 304 of the calling line, a circuit is closed from main battery, through a resistance 332, the winding of relay 331, the lower contacts of cam 300^V, 5 commutator brush 312, wiper 308, terminal 304, conductor 115, the left-hand armature and front contact of line relay 101, and the windings of a relay 107 to sub-battery. The relay 331 becomes energized but the windings of relay 107 are so balanced that it will 10 not become energized upon the closure of this circuit. This relay becomes energized only when, due to some trouble, the conductor 115 is grounded, in which case the 15 relay is energized through its left hand winding and is held energized through both windings. By attracting its right-hand armature relay 107 lights a lamp 108 and actuates a relay 109, to give an alarm signal 20 to the supervisor, informing him of the trouble. In its back contact, the relay 331 opens the locking circuit of the relay 330, whereupon this relay opens the circuit of the magnet 328 and the line finder is arrested. 25 In order to insure the proper centering of the line finder wipers on the terminals of the calling line, as long as the commutator brush is in engagement with the conducting portion of segment C, sub-battery is connected 30 through segment C and the lower contacts of cam 300^R to the winding of relay 330. Relay 330 is thus maintained energized until the commutator brush engages an insulated portion of segment C, at which 35 time the line finder brushes are properly centered on the selected set of terminals. Upon deenergization, the relay 330 closes a circuit from main battery, through the power magnet of sequence switch 300, the 40 left-hand contact of cam 300^A, the lower right-hand contact of cam 300^C, the right-hand back contact and armature of relay 330, the upper left-hand and lower right-hand contacts of cam 300^Q, and commutator segment M of the connecting circuit selector to sub-battery. The sequence switch 300 is moved out of position 4 and into position 6. When the sequence switch 300 moves out of position 4, the relay 331 becomes deenergized. As soon as the sequence switch 300 reaches position 4₁, a circuit is closed from ground, through a resistance 338, the lower contacts of cam 300^K, commutator brush 311, the wiper 307, terminal 303, 50 conductor 116, and the winding of the cut-off relay 102, and the right-hand winding of message register magnet 103 in parallel to main battery. The cut-off relay becomes energized and opens the circuit of the line relay 101. The magnet 103 does not become energized. Due to the deenergization of line relay 101, the relay 331 of another hunting line finder will not find a circuit through the left-hand front contact of the line relay, 55

and thus the seizure of the calling line by another line finder is prevented. As will be hereinafter more fully set forth, due to the closure of the circuit including the cut-off relay, the potential on the terminal 192 and multiples thereof appearing as the test terminal of this line in the final selectors, will be reduced so as to prevent the seizure of this line by a final selector. 65 70 75

Selection of operator's position.

A circuit is closed in position 6 of the sequence switch 300 from sub-battery, through the left-hand armatures and back contacts of relays 511 and 510, conductor 505, the right-hand contacts of cams M controlled by the preceding sequence switches, the right-hand contacts of cam 300^M and the right-hand winding of relay 330 to main battery, and a parallel path through the lower right-hand and upper left-hand contacts of cam 300^V, the left-hand winding of relay 330, the left-hand contacts of cam 300°, and resistance 325 to main battery. The relay 330 becomes energized and closes a circuit from main battery through the power magnet of sequence switch 300, the left-hand contact of cam A, the upper right-hand contact of cam C, the right-hand front contact and armature of relay 330, the upper left-hand and lower right-hand contacts of cam 300^Q, segment M and the commutator brush of the connecting unit selector to sub-battery. The sequence switch 300 is moved out of position 6 into position 7, whereupon the relay 330 becomes deenergized. 90 95 100

When the sequence switch 300 reaches position 6₁, a circuit is closed from sub-battery, through the commutator brush and the segment M of the line finder, the lower left-hand contact of cam 300^W, the lower contacts of cam 300^X, conductor 500, and the winding of relay 577 to main battery. 105

The relay 577 closes a circuit from sub-battery, through its left-hand armature and front contact, conductor 527, the contacts of cam 1000^F and corresponding cams of all other sequence switches associated with idle operators' telephone circuits, the left-hand armature and back contact of relay 1035, and the winding of relay 1034 to main battery. Relay 1034 becomes energized. 110 115

When the sequence switch 300 reaches position 7, a circuit is closed from main battery, through the winding of relay 510, the right-hand armature and back contact of relay 511, and the winding of relay 512 in parallel, and then through conductor 507, the lower contacts of cam 300^W, and the segment M and the commutator brush of the line finder to sub-battery. The relays 510 and 512 become energized. 120 125

As soon as the relay 1034 becomes energized, it closes a circuit from main battery

- through resistance 1050, (Fig. 10) the armature and front contact of relay 1034, contacts of key 1045^a, conductor 606, key 690^b and the winding of relay 603 to sub-battery.
- 5 The relay 603 becomes energized and closes a circuit from main battery, through the armature and back contact of relay 1036, conductor 604, the left-hand back-contact and the winding of relay 602, the winding of relay 601, the right-hand back contact of relay 602, the right-hand front contact and armature of relay 603, conductor 529, the right-hand back contact and armature of relay 508, the right-hand front contact and armature of relay 510, the right-hand armatures and back contacts of relays 509 and 511, conductor 507, the lower contacts of cam 300^w, and the segment M and the commutator brush of the line finder to sub-battery. The relays 601 and 602 become energized and the latter relay opens the above traced circuit but said relays are held energized over a circuit presently to be described. Relay 601 closes a circuit through its left-hand armature for energizing trip magnet 600 of the connecting unit selector, and a circuit from sub-battery through its right-hand armature and front contact, key 690^c, conductor 530, and the winding of relay 509 to main battery. Relays 601 and 602 are maintained energized through a circuit extending from main battery, through resistance 1033, the winding of relay 1036, conductor 605, the left-hand armature and front contact of the relay 602, windings of relays 602 and 601, the right-hand front contact and armature of relay 602, conductor 529, the right-hand back contact and armature of relay 511, conductor 507, the lower contacts of cam 300^w, and the commutator segment M of the line finder to sub-battery.
- If the operator, at whose position the relay 1036 is provided, is ready to handle calls, her telephone set of the well-known type is connected by means of a double plug-ended cord to jack 1027. While her telephone set is thus connected, relay 1028 is maintained energized through a circuit including the lowermost contact of jack 1027. Upon the energization of relay 1036 a circuit is closed from sub-battery through the right-hand armature and front contact of relay 1028, the right-hand armature and front contact of relay 1036, and then in parallel through the windings of relays 1041 and 1044, and the right-hand windings of relays 1035 and 1032 to main battery. These relays become energized. The relay 1035 opens the circuit including relays 1034 and 603, whereupon these relays become deenergized. The left-hand back contact of relay 1035 being open, no other call may be routed to this operator's position. The relay 1041 closes a locking circuit through its winding, left-hand front contact and armature, the contacts of cam 1000^m and the right-hand front contact and armature of relay 1028 to sub-battery. The windings of relays 1035, 1032 and 1044 are connected in parallel to this circuit. The relay 1041 closes a circuit from sub-battery, through the right-hand armature and front contact of relay 1028, the left-hand contacts of cam 1000^c the lower armature and back contact of relay 1029, the right-hand armature and front contact of relay 1041, the lower left-hand contact of cam 1000^b, the left hand contact of cam 1000^a, and the power magnet of sequence switch 1000 to main battery. The sequence switch 1000 is moved out of position 1 into position 4, and is immediately driven out of that position into position 17 through a circuit including the left-hand armature and front contact of relay 1028, and the upper right-hand contact of cam 1000^b.
- Peg-count.
- When the relay 1036 becomes energized, a circuit is closed from main battery, through the left-hand-armature and front contact of relay 1036, the winding of relay 1038, the lower contacts of cam 1000^l in parallel with the winding of relay 1040, and the right-hand front contact and armature of relay 1028 to sub-battery. The relay 1040, being energized, opens the two circuits to the listening key contacts of the various connecting units, one of which is shown at 995^a. The relay 1038 becomes energized and closes a locking circuit from main battery, through the left-hand armature and front contact, and the windings of relays 1038 and 1040, and then through the above traced circuit. The automatic peg-count register magnet 1039 is energized from ground through the winding of the register magnet, and the left front contact and armature of relay 1038 to main battery. The relay 1019 is now operated by a circuit from main battery through its winding, the right-hand front contact and armature of relay 1038, the lower back contact and armature of relay 1029, the left-hand contacts of cam 1000^c, and the right-hand front contact and armature of relay 1028 to sub-battery. The relay 1019 connects the operator's telephone set inserted in jack 1027 to the warning tone circuit extending from ground, through the right-hand front contact and armature of relay 1019, the right-hand back contact and armature of relay 1004, the telephone set, the left-hand armature and back contact of relay 1004, the left-hand armature and front contact of relay 1019, a condenser, the left-hand armature and back contact of relay 1018, to the source of warning tone. The operator will now hear this warning tone and continue to hear it until the connecting

unit selector has seized the first idle connecting unit and connected the calling subscriber to the operator's telephone set.

5 *Selection of connecting unit.*

The relay 509 closes a circuit from sub-battery at the commutator segment M of the line finder, the lower contacts of cam 300^w connector 507, the right-hand armature 10 and back of contact relay 511, the armature and front contact of relay 509, and the winding of a slow-acting relay 526 to main battery. The relay 526 becomes energized and closes a circuit from sub-battery through its 15 armature and front contact, conductor 503, the left-hand contacts of cam 300^y, the left-hand winding of relay 330, the left-hand contacts of cam 300°, and resistance 325 to main battery, and a parallel path through 20 the lower contacts of cam 300^y, and the right-hand winding of relay 330 to main battery. The relay 330 becomes energized and closes the previously traced locking circuit for itself from main battery through 25 resistance 325, to sub-battery at the contact and armature of relay 331. Relay 330 also closed a circuit from main battery through the power magnet of sequence switch 300, the left-hand contact of cam A, the upper 30 right-hand contact of cam 300^c, the right-hand front contact and armature of relay 330, the upper left-hand and lower right-hand contacts of cam 300^q and segment M of the connecting circuit selector to sub-battery. The sequence switch 300 moves out 35 of position 7 and into position 8.

A circuit is closed from main battery, through the winding of magnet 327, the upper right-hand contact of cam 300^p, the 40 right-hand front contact and armature of relay 330, the upper right-hand contact of cam 300^x, and lower left-hand contact of cam 300^w to sub-battery at segment M of the line finder. Under the control of magnet 327, the connecting circuit selector is 45 caused to move in an upward direction. A set of brushes arranged to hunt for an idle circuit in the group to which the magnet 600 is individual, is tripped, and before the selector wipers engage the first set of terminals in the group, the commutator brush of the connecting circuit selector connects sub-battery through segment K of the connecting circuit selector, the lower contacts of cam 50 300^s, conductor 506, and the winding of relay 511 to main battery. The relay 511 becomes energized and locks up through conductor 507. In its right-hand back contact, the relay 511 opens the circuits through which 55 relays 526, 510, 601, 602 and 1036 were energized, and these relays release their armatures. Upon the deenergization of relay 601, the magnet 600 and the relay 509 become deenergized.

The sequence switch 300 is moved out of position 8 into position 9 by a circuit from sub-battery through the left-hand armature and front contact of relay 511, conductor 504, the lower left-hand contact of cam 300^b, the left-hand contact of cam 300^a, and the power magnet 300 to main battery. When the sequence switch 300 moves out of position 8, the locking circuit for relay 511 is broken at cam 300^w. Upon the deenergization of relay 511, the circuit is restored for 75 moving other finder sequence switches like 300 out of the waiting position 6, at which position said other sequence switches stop should they be started immediately following the seizure of another line finder, sub-battery being connected through the left-hand armature and back contact of this relay, and the conductor 505 to the series circuit of the M cams.

When the connecting circuit selector engages the terminals of an idle trunk in the selected group of trunks, a circuit is closed from main battery, through resistance 332, the winding of relay 331, the upper contacts of cam 300^r, commutator brush 324, wiper 320, terminal 316, conductor 904, the lower left-hand and upper right-hand contacts of cam 900^l, conductor 973, the upper left-hand and lower right-hand contacts of cam 1200^s, 90 resistance 1234, the left-hand contacts of 1200^v, conductor 971, the left-hand back contact and armature of relay 909, the lower right-hand and upper left-hand contacts of cam 900^c, the right-hand back contact and armature of relay 995, and the normal contact of disconnect key 908 to sub-battery. The relay 331 becomes energized and opens in its back contact the locking circuit of relay 330. However, in order to insure the proper centering of the selector wipers, as long as the commutator brush is in engagement with the conducting portion of segment C of the connecting circuit selector, sub-battery is connected to relay 330 through the upper right-hand and lower 110 left-hand contacts of cam 300^r for maintaining this relay energized. When the relay 330 becomes deenergized it opens the circuit of magnet 327, whereupon the connecting circuit selector is arrested. Upon deenergization, the relay closes a circuit from main battery through the power magnet of sequence switch 300, the left-hand contact of cam 300^a, the lower right-hand contact of cam 300^c, the right-hand back contact and 115 armature of relay 330, the cam 300^x, the lower left-hand contact of cam 300^w, the commutator segment M and the commutator brush of the line finder to sub-battery. The sequence switch 300 is moved out of position 9 and into position 14. When the sequence switch 300 opens the upper contacts of its cam T, the relay 331 becomes deenergized.

While the sequence switch 300 is passing through positions 11 and 12, sub-battery is connected through a resistance 326, the right-hand contacts of cam 300°, commutator brush 323, wiper 319, terminal 315, conductor 903, the lower left-hand and upper right-hand contacts of cam 900^l, the left-hand back contacts of relays 995 and 913, the right-hand contacts of cam 900^h and the winding of a relay 910 to main battery, and in parallel through the left-hand contacts of cam 900^k and the winding of relay 906 to main battery. The relays 906 and 910 become energized and remain energized until the sequence switch 900 moves out of position 3 and opens the left-hand contacts of its cam K, a locking circuit being closed for these relays from main battery through the winding of relay 906, the left-hand contacts of cam 900^k and in parallel through the winding of relay 910, and thence through the upper right-hand and lower left-hand contacts of cam 900^h, the right-hand front contact and armature of relay 910, the lower right-hand contacts of cams 900-W and V to sub-battery. The relay 906 connects through its contacts the talking conductors 901 and 902 (shown in heavy lines) through conductors 919 and 920, the armatures and back contacts of a relay 1001, the normal contacts of keys 1009—1013, the armatures and back contacts of relays 1019 and 1004 to a jack 1027, to which the telephone set of the operator (not shown) is connected by means of a plug.

The relay 910 closes a circuit from sub-battery through its left-hand armature and lower contact, and the winding of a relay 913 to main battery. Another circuit is closed from sub-battery through the left-hand armature and upper contact of the relay 910, the lower right-hand contact of cam B and the power magnet of sequence switch 900 to main battery. The sequence switch is moved out of position 1 and under the control of its normal contact A into position 2. As soon as the sequence switch 900 reaches position 1⁴, the relay 913 is locked up through a circuit from main battery, the winding, right-hand front contact and armature of relay 913, the upper contacts of cam 900°, and normal contact of key 908 to sub-battery. A circuit is now closed from main battery through the power magnet of sequence switch 900, the right-hand contacts of cam 900^j, conductor 921 and the back contact and armature of a relay 1070 to sub-battery. The sequence switch 900 is moved out of position 2 and into position 4.

Upon the energization of relay 913 a circuit is maintained closed while sequence switch 300 is in position 12⁴ to 14, and replaces the busy condition placed on the multiples of test terminal 303 of the line finder from ground through resistance 338 to

ground through the winding of relay 909, the left-hand armature and back contact of relay 907, the left-hand front contact and armature of relay 913, left-hand back contact of relay 995, the upper right and the lower left-hand contacts of cam 900^l, conductor 903, terminal 315, wiper 319 and commutator brush 323 of the connecting circuit selector, the upper right-hand and lower left-hand contacts of cam 300°, the left-hand winding of relay 330, upper right-hand and lower left-hand contact of cam 300^k, the commutator brush 311, wiper 307 and terminal 303 of the line finder. The relay 102 of the calling subscriber is maintained energized through this circuit instead of the circuit extending from ground through resistance 338 and the lower contacts of sequence switch cam 300^k. The relays 330 and 909 become energized in this circuit. Upon the energization of relay 909 a locking circuit is closed for relay 913, which is independent of contacts of sequence switch 900 and extends from main battery through the winding, right-hand front contact and armature of relay 913, right-hand front contact and armature of relay 909, and the normally closed contact of the disconnect key 908 to sub-battery. It should be noted that as soon as sequence switch 900 moves out of position 1, the upper contact of its cam L is opened, whereby the energization of relay 330 of another connecting circuit selector cannot be brought about through a test circuit including a multiple contact of 316. The test circuit is maintained open while the connecting circuit is in use in contacts of sequence switch 1200.

In positions 1⁴ to 9⁴ of sequence switch 900, a circuit is closed from sub-battery through the lower right-hand contact of cam 900^v, the upper right-hand cam 900^w, conductor 981, a lamp 1229, resistance 1230, the upper contacts of cam 1200^h and an interrupter 1236 to ground. Under the control of the interrupter 1236, the lamp 1229 is caused to flash, indicating to the operator that the calling line has been extended to a circuit to which this lamp is individual. Another circuit is closed from sub-battery through the lower right-hand contact of cam 900^v and the upper right-hand contact of cam 900^w, conductor 982, a lamp 1211 and a resistance 1209 to ground. The lamp 1211 serves as an answering supervisory lamp and does not light up at this time, due to the shunt placed around it by the relay 1201. When the sequence switch 900 reaches position 2, a circuit is closed from sub-battery through the lower right-hand contact of cam 900^v, the upper left-hand contact of cam 900^w, conductor 983, the lower right-hand contact of cam 1200^b, the contact of cam 1200^a, and the power magnet of sequence switch 1200 to main battery. Sequence

switch 1200 is moved out of position 1, and under the control of the upper contact of its cam A is moved into position 2.

Another circuit closed in position 1³ of sequence switch 900 extends from main battery through the winding of relay 1029, conductor 930, the lower right-hand and upper left-hand contacts of cam 900^R and the left-hand front contact and armature of relay 910 to 10 sub-battery.

The relay 1029 becomes energized, and at its lower back contact and armature breaks a circuit which has been maintaining the relay 1019 in an energized condition as above 15 described. The relay 1029 locks up in a circuit from main battery through its upper front contact and armature, the upper right-hand and lower left-hand contacts of cam 1000^C, the right-hand contact of relay 1028 20 to sub-battery, until the sequence switch 1000 has passed beyond position 16. At its lower front contact, the relay 1029 restores the circuit for making the listening keys 995^A effective, as will be hereinafter described. By 25 the release of relay 1019, the warning tone is now removed from the operators' telephone set, and this set is connected to the calling line.

The sequence switch 1000, having been 30 moved out of position 1 upon energization of relay 1036, continues its movement to position 17. When the sequence switch opens the contacts of cam L in position 15, the locking circuit for the relays 1038 and 1040 35 is opened. The release of relay 1029 cannot now result in the energization of relay 1019 because the relay 1038 is deenergized. When the sequence switch 1000 moves beyond position 16, the locking circuit for relay 1029 is 40 opened and that relay becomes deenergized. If the sequence switch 1000 has moved beyond position 16 before sequence switch 900 has moved beyond position 3, the relay 1029 is maintained energized by the circuit in 45 which it was originally operated as described above. In either event, the warning tone is removed from the operator's telephone set so that she is able to talk with the calling subscriber. The peg-count register 50 magnet 1039 becomes deenergized when relay 1038 becomes deenergized. The relay 1038, however, cannot become energized unless relay 1036, under the control of the operator's selecting circuit, is energized. Therefore, the peg-count register magnet 1039 is 55 energized only once on each incoming call.

In positions 2 to 5 of sequence switch 900, a circuit is closed for energizing relays 1035, 1032 and 1025, the circuit extending 60 from main battery through the left-hand winding of relays 1035 and 1032 and the winding of relay 1025 in parallel, conductor 939, and the upper left-hand and lower right-hand contacts of cam 900^V to sub-battery.

When the sequence switch 900 moves out of position 3, relays 910 and 906 become deenergized, the talking connection between the calling subscriber and the operator being now maintained closed through the contacts of cams 900^E and 900^F instead of the contacts of relay 906. 70

The operator, by conversing with the subscriber, may learn now the designation of the called line. 75

Class of service indication.

While the operator is conversing with the subscriber, the class of service of the calling line is indicated at her position by lighting the proper class-of-service pilot lamps 80 under the control of the counting relays shown in Fig. 11.

The class of service indication is given to the operator under control of interrupters 85 common to the exchange. Referring to Figure 11^A, it will be noted that the interrupter springs, shown on the left of this figure, are arranged to be suitably operated by cams such as cam 1173 shown in Fig. 11^B. 90 Each cam is cut in a different position as indicated by the roman numerals. These positions, as indicated by the roman numerals, indicate the relative position for operating the springs shown at the left of Figure 11^A. The normally closed circuit extends from ground to the interrupter springs as indicated, thence through the line signal 149, through the left-hand back contact and armature of the line relay 101, conductor 115, terminal 304, wiper 308, commutator segment 312, the left-hand contact of cam 300^P, the right-hand front contact and armature of relay 330, the left-hand contacts of cam 300^Q, commutator segment 100 324, wiper 320, terminal 316 of the connecting unit selector, conductor 904, the lower contacts of cam 900^P, conductor 917, the left-hand back contact and armature of relay 1008, conductor 1103, the left-hand armature and back contact of relay 1104, to the normally opened contact of key 1110 or the left-hand armatures and front contacts of 105 relays 1104 and 1111, winding of relay 1115 to main battery. Over this circuit are 110 transmitted the pulses from the interrupter (Fig. 11^A), by means of which the proper class of service indication is given to the operator. The general principles underlying the operation of this circuit are 115 completely explained in Patent 1,200,788 to Samuel B. Williams, jr., dated October 10, 1916, and that principle is further extended in this case to employ four "pick-ups" instead of two. In this case in the circuit as 120 above mentioned, a line signal 149 is included, which, as will be hereinafter described, may at the will of the operator be caused to light up by the closing of the contacts of the key 1110. 125 130

- In position 4 of sequence switch 900, sub-battery is connected through the right-hand contacts of cam 900^V, conductor 940, and then in parallel through the winding of relay 1107; the left-hand back contact of relay 1106 and the winding of relay 1104; and the winding of relay 1114, to main battery. Relays 1107, 1104 and 1114 become energized.
- 5 The various class-of-service impulses produced by the class-of-service interrupter, illustrated in Fig. 11^A, are divided into groups by means of pick-up impulses produced during the rotation of the interrupting device.
- 10 In Fig. 11^A adjacent to cam 1173, it is indicated in which positions of the interrupter these pick-up impulses are produced. When the first pick-up impulse is produced, a circuit is closed from main battery, through the winding of relay 1116, the left-hand back contact and armature of relay 1105, the right-hand armature and front contact of relay 1104, conductor 1100, the right-hand armature and back contact of relay 1018 to sub-battery, through cam I of the pick-up interrupter and a resistance 1197. The relay 1116 becomes energized and closes a circuit from main battery, through the winding of relay 1111, the left-hand front contact and armature of relay 1116, and conductor 940 to sub-battery at the V cam of sequence switch 900. Relay 1111 closes a locking circuit for itself extending from main battery, through its winding, right-hand front contact and armature, and the winding of relay 1105 to sub-battery at cam 900^V. Depending on the connection of the class-of-service interrupters (Fig. 11^A) to the left-hand back contact of line relay 101, a certain number of interruptions are produced in the circuit including the left-hand armature of line relay 101, conductor 115, terminal 304, wiper 308, commutator brush 312 of the line finder, the left-hand contacts of cam 300^P, the right-hand front contact and armature of relay 330, the left-hand contacts of cam 300^Q, commutator brush 324, wiper 320 and terminal 316 of the connecting circuit selector, conductor 904, the lower contacts of cam 900^L, conductor 917, the left-hand back contact and armature of relay 1008, conductor 1103, the left-hand armature and front contact of relay 1104, the left-hand armature and front contact of relay 1111, and the winding of relay 1115, to main battery. Supposing that one interruption is produced between the pick-up impulse 1 and pick-up impulse 2, the relay 1115 is first deenergized and then energized. Upon the first energization 15 of relay 1115, sub-battery was connected through the front contact of this relay, the right-hand armature and back contact of relay 1117, the right-hand armatures and back contacts of relays 1124, 1125 and 1126 in series, the left-hand armature and back contact of relay 1124, and the winding of relay 1130, to main battery. Relay 1130 becomes energized and closes a locking circuit for itself from main battery through its winding, left-hand armature and front contact, the winding of relay 1124, the left-hand back contact and armature of relay 1125, conductor 940, to sub-battery at sequence switch cam 900^V. Relay 1124 does not become energized upon the closure of this circuit because of a shunt path existing from the left-hand armature of relay 1130 to sub-battery at the armature of relay 1115. However, upon the deenergization of relay 1115, the relay 1124 becomes energized. Upon the next energization of relay 1115, sub-battery is connected through the right-hand armature and back contact of relay 1117, the right-hand armature and front contact of relay 1124, and the winding of relay 1131, to main battery. Relay 1131 becomes energized and closes a locking circuit for itself from main battery, through its winding, left-hand armature and front contact and the winding of relay 1125, the left-hand back contact and armature of relay 1126, and conductor 940 to ground at cam 900^V. The relay 1125 becomes energized as soon as the relay 1115 again deenergizes and removes the shunt path from the winding of relay 1131. Upon the energization of relay 1125, the above traced locking circuit, including relays 1124 and 1130, is opened and these relays becomes deenergized.
- 20 The second pick-up impulse is extended through the right-hand front contact and armature of relay 1105, the left-hand back contact and winding of relay 1117, and in parallel through the winding of relay 1112, to main battery. These relays become energized and relay 1117 closes a locking circuit extending from main battery, through the winding of relay 1112 and its own winding in parallel, the left-hand front contact and armature of relay 1117, conductor 940, to sub-battery at sequence switch cam 900^V. Assuming that no impulse is produced between pick-up 2 and pick-up 3, the relay 1115 connects sub-battery through its armature and contact, the right-hand armature and front contact of relay 1117, the left-hand armature and back contact of relay 1113, the right-hand armature and back contact of relay 1127, the right-hand armature and back contact of relay 1128, the left-hand armature and contact of relay 1127, and the winding of relay 1134, to main battery. The relay 1134 becomes energized and locks up through its left-hand armature and contact the winding of relay 1127, and the left-hand back contact and armature of relay 1128, to sub-battery at sequence switch cam 900^V.
- 25 Upon the production of the pick-up #3 impulse, a circuit is closed from main battery, through the windings of relays 1113 130

and 1118 in parallel, the left-hand back contact of relay 1118, and the right-hand armature and front contact of relay 1112 to sub-battery. Relays 1113 and 1118 become energized, the latter closing a locking circuit for both through its left-hand armature and front contact. The succeeding group of circuit interruptions effected by the class-of-service interrupter control through the armature and contact of relay 1115, the right-hand armature and front contact of relay 1117, the left-hand armature and front contact of relay 1113, the left-hand armature and back contact of relay 1136, the right-hand armatures and back contacts of relays 1146, 1147, 1148 and 1149 in series, the left-hand armature and back contact of relay 1146, and the winding of relay 1155 to main battery. Depending on the number of impulses produced by the class-of-service interrupter, relays 1146 to 1149 become successively energized and cause the deenergization of the previous set of counting relays within this group. Supposing that one interruption is produced in this group, relays 1147 and 1156 remain locked up.

The pick-up #4 impulse causes the closure of a circuit from sub-battery through the right-hand armature and front contact of relay 1113, the left-hand back contact of relay 1108, and the windings of relays 1108 and 1136 in parallel, to main battery, whereupon these two relays become energized and lock up through the left-hand front contact and armature of relay 1108. Upon the energization of relay 1115 after the pick-up #4 impulse, an impulse is extended through the armature and front contact of relay 1115, the right-hand armature and front contact of relay 1117, the left-hand armature and front contact of relay 1113, the left-hand armature and front contact of relay 1136, the right-hand armatures and back contacts of relays 1150 and 1151 in series, the left-hand armature and back contact of relay 1150, and the winding of relay 1160 to main battery. Supposing that no interruption was produced in this group, relay 1160 becomes energized and locks up.

When the pick-up #1 is again produced, then a circuit is closed from main battery, through the winding of relay 1106, the right-hand back contact of this relay, the armature and front contact of relay 1107, the left-hand front contact and armature of relay 1105, the right-hand armature and contact of relay 1104, conductor 1100, and the right-hand armature and back contact of relay 1108 to sub-battery. Relay 1106 becomes energized and opens in its left-hand contact the circuit of relay 1104. The relay 1106 locks up through its right-hand front contact and armature, conductor 940 and the V cam of sequence switch 900. Relay 1104 being deenergized, impulses produced by the

class-of-service interrupter can no more be transmitted to relay 1115, and thus the setting of the class-of-service counting relays will not be disturbed. In view of the particular setting of the class-of-service counting relays, the following lamps will be lighted. In group I, lamp 1139, ground being supplied through the left-hand armature and front contact of relay 1112; in group II no lamp, the armature of relay 1134 not being connected to any lamp; in group III, lamp 1163, ground being supplied through the right-hand front contact and armature of relay 1108; and in group IV, no lamp, the armature of relay 1160 not being connected to any lamp.

In order to enable the operator to ascertain the number of the calling line, a lamp, such as 149, is provided at the central station for each line. The operator may cause the lighting of the lamp, individual to the line calling, by closing a circuit from main battery, through the contact of key 1110, the left-hand back contact and armature of relay 1104, conductor 1103, the left-hand armature and back contact of relay 1008, conductor 917, the lower contacts of cam 900^L, conductor 904, terminal 316, wiper 320, brush 324, the left-hand contacts of cam 300^Q, the right-hand armature and front contact of relay 330, the left-hand contacts of cam 300^P, brush 312, wiper 308, terminal 304, conductor 115, the left-hand armature and back contact of relay 101, and lamp 149 to ground at the class-of-service interrupter.

Connection and adjustment of sender.

Sequence switch 900 being in position 4 and sequence switch 1200 in position 2, a circuit is closed from main battery, through the winding of relay 1314, the lower right-hand and upper left-hand contacts of cam 1300^F, conductor 980, the lower contacts of cam 900^U, conductor 977, the lower left-hand and upper right-hand contacts of cam 1200^S, the left-hand armature and back contact of relay 1232, the lower left-hand contacts of cams 1200-R and P, to sub-battery. The relay 1314 becomes energized and closes a circuit from sub-battery through its right-hand armature and front contact, the upper right-hand contact of the cam C, the left-hand contact of cam A, and the power magnet of sequence switch 1300 to main battery. Sequence switch 1300 is moved out of position 1, and under the control of its normal cam A is moved into position 2. When sequence switch 1300 moves out of position 1^{1/2} and opens the upper left-hand contact of its cam F, the above traced energizing circuit for relay 1314 is opened. This relay, however, remains energized by current flowing through a circuit extending from main battery through its winding, the lower contacts of cam F and the right-hand back con-

tact and armature of slow to release relay 1399, to sub-battery.

When the sequence switch 1300 reaches position 2, a circuit is closed from main battery through the winding of magnet 1315, the right-hand contacts of cam 1300^W, and the right-hand front contact and armature of relay 1314, to sub-battery. Under the control of the magnet 1315, the wipers 1307—1312 of the cord finder are caused to move in an upward direction. As soon as the wipers engage the terminals 1301—1306 representing the connecting unit 993, 994, to which the calling line has been extended by means of the line finder and the connecting unit selector, a circuit is closed from main battery, through the winding of relay 1399, the left-hand contacts of cam 1300^G, wiper 1308, terminal 1302, conductor 979, the upper right-hand and lower left-hand contacts of cam 900^U, conductor 977, the lower left-hand and upper right-hand contacts of cam 1200^S, the left-hand back contact and armature of relay 1232, and the lower left-hand contacts of cams 1200-R and P, to sub-battery. The relay 1399 becomes energized and interrupts at its right-hand back contact, the circuit of relay 1314. In order to insure the centering of the cord finder wipers on the selected set of terminals, as long as the commutator brush engages the conducting portion of segment C, a locking circuit is closed for relay 1314, from main battery through the winding, left-hand contact and armature of this relay, the right-hand contacts of cam 1300^U, the segment C and the commutator brush of the cord-finder to sub-battery. As soon as the commutator brush leaves the conducting portion of segment C, at which time the wipers are correctly centered, the relay 1314 becomes deenergized, and by opening the circuit of magnet 1315 arrests the upward travel of the cord finder. Relay 1314 closes a circuit from sub-battery, through its right-hand armature and back contact, the upper left-hand contact of the cam C, left-hand contact of cam 1300^A, and the power magnet of sequence switch 1300 to main battery. The sequence switch 1300 moves out of position 2 into position 3. When the sequence switch 1300 leaves position 2, the above traced circuit for relay 1399 is opened, but this relay is maintained energized by current flowing through a circuit extending from main battery, through the winding of relay 1399, the lower left-hand and upper right-hand contacts of cam 1300^G, and the right-hand front contact and armature of relay 1399 to sub-battery. This circuit is opened when the sequence switch moves out of position 2₁, but as soon as the sequence switch reaches position 2₂ and before the relay 1399 has time to release its armatures, a circuit is closed from main battery

through the winding of relay 1399, the lower contacts of cam 1300^G, the left-hand front contact and armature of relay 1399, the left-hand contacts of cam 1300^Y, wiper 1307, terminal 1301, conductor 1239, the winding of a relay 1235, the left-hand contacts of cam 1200°, and the right-hand back contact and armature of a relay 1228, to sub-battery. The relay 1235 becomes energized and closes a circuit from sub-battery, through its left-hand armature and front contact, a resistance 1242, a lamp 1231, the right-hand contact of cam 1200^H, and interrupter 1236 to ground. Under the control of interrupter 1236, the lamp 1231 is caused to flash, indicating to the operator that an idle sender has been attached to the selected connecting circuit.

For the purpose of controlling the setting of the selectors, the operator actuates her keyboard by depressing keys corresponding to digits of the called number. The operator's keyboard consists of nine rows of keys named: office, tandem hundreds, tandem tens, tandem units, thousands, hundreds, tens, units and station-keys. In the drawings (Fig. 15 and Fig. 16), only one key of each row is represented. In the present case it will be assumed that in order to cause the selection of the desired line, the keys 1522, 1603, 1627, 1652 and 1677 must be depressed. In addition to these keys, she depresses also a start key 1692, which carries a contact 1699.

The actuation of the key 1522 results in the closure of a circuit from sub-battery through the winding of a relay 1527, the right-hand contact of key 1522, the windings of relays 1503 and 1504, conductor 1355, the lower left-hand contact of cam H and the upper contact of cam G of the allotter sequence switch 1350 (which is now standing in position 1), the winding of relay 1351, the upper right-hand contact of cam 1350^R, the right-hand contacts of cams 1350^E and 1300^U to main battery. Relay 1351 becomes energized and closes a locking circuit for itself through its right-hand armature and front contact. Relays 1503, 1504 and 1527 also become energized. Relay 1504 closes a circuit from sub-battery through its front contact and armature, the right-hand armature and back contact of relay 1501, the power magnet of register sequence switch 1500, conductor 1383, the upper left-hand contact of cam 1300^L, and the lower left-hand contact of cam 1300^J to main battery. Two other circuits are closed in parallel with the above traced circuit from sub-battery, through the front contact and armature of relay 1504, the armatures and back contacts of relays 1526 and 1551, respectively, the windings of register power magnets 1525 and 1550 respectively, conductors 1386 and 1385, respectively, the left-hand

contacts of cam 1300^M, and the lower left-hand contact of cam 1300^J to main battery. In response to the closure of these circuits, the registers 1500, 1525 and 1550 are moved 5 out of whatever position in which they may be standing. When register 1500 reaches one of the positions in which the upper right-hand contact of its cam C is closed, e. g. position 14, a circuit is closed from sub-battery through the left-hand contact of key 1522, the upper right-hand and lower left-hand contacts of cam 1500^C, winding of relay 1501, conductor 1363, lower right-hand contact of cam 1350^J, upper right-hand contact of cam 1350^G, the winding of relay 1351, upper right-hand contact of cam 1350^R, the right-hand front contact and armature of relay 1351 to main battery. Relay 1501 becomes energized and by opening its right-hand back contact causes the arresting of register 1500 in position 14. In a similar manner, as soon as the register 1525 reaches position 4, a circuit is closed from sub-battery through the front contact and armature of relay 1527, the lower right-hand contact of cam 1525^b, winding of relay 1526, conductor 1362, the lower left-hand contact of cam 1350^J, and then through the above-traced path to main battery at cam 1300^U. The relay 1526 becomes energized and opens the driving circuit of register 1525, whereupon this register is arrested in position 4. As soon as the register 1550 reaches position 1, a circuit is closed from sub-battery 25 through the front contact and armature of relay 1503, the upper right-hand and lower left-hand contacts of cam 1550^C, winding of relay 1551, conductor 1361, the upper left-hand contact of cam 1350^I, and then to main 30 battery, at cam 1300^U. Relay 1551 becomes energized, whereupon the register 1550 is arrested in position 1.

Relay 1524 is connected in series with relays 1527, 1503 and 1504 that are controlled 45 by the office key for the office keys designating the local office. In the present case, the called line being associated with the local office, the relay 1524 is energized in response to the actuation of key 1522 and 50 closes a circuit from sub-battery through its armature and front contact, conductor 1387, the lower contacts of the allotter cam 1350^W and the winding of relay 1382 to main battery. The relay 1382 becomes energized and 55 closes a locking circuit for itself from main battery through its right-hand front contact and armature, the left-hand back contact and armature of relay 1319, the upper right-hand contact of cam 1300^S and the right-hand contact of cam 1300^R to sub-battery.

Relay 1694 being energized by current flowing from sub-battery through row contact 1699, the winding of relay 1694, conductor 1355 and contacts of cams 1350-H, I, 60

G and R to main battery, the register sequence switches shown in Fig. 16 are set in motion by circuits closed from sub-battery through the right-hand contact and armature of relay 1694, the right-hand armatures and 70 back contacts of relays 1601, 1626, 1651 and 1676 and left-hand armature and back contact of 1691 respectively; the windings of register magnets 1600, 1625, 1650, 1675 and 1690 respectively; conductor 1375 and the 75 upper right-hand contact of cam 1300^K; conductor 1374 and the lower right-hand contact of cam 1300^K; conductor 1373 and the lower left-hand contact of cam 1300^K; conductor 1372 and the upper left-hand contact of cam 1300^J, conductor 1371 and the upper right-hand contact of cam 1300^J respectively and then through the lower left-hand contact of cam 1300^J to main battery. When register 1600 reaches position 8, its driving circuit is interrupted in the right-hand back contact of relay 1601, this relay being energized through a circuit extending from sub-battery, through key 1603, the lower left-hand contact of cam 1600^E, the lower right-hand contact of cam 1600^C, relay 1601, conductor 1360, the lower left-hand contact of cam 1350^I, the upper right-hand contact of cam 1350^G, relay 1351, the upper right-hand contact of cam 1350^R, and the right-hand front contact and armature of relay 1351 to main battery. When the sequence switch register 1625 reaches position 7, a circuit is closed 85 from sub-battery through key 1627, the lower right-hand contacts of cams 1625-E and C, relay 1626, conductor 1359 and then through contacts of cam 1350-H, G and R to main battery. The relay 1626 becomes 90 energized and arrests register 1625. Similarly, the registers 1650 and 1675 are arrested when they reach positions 6 and 5, respectively, the relays 1651 and 1676 being 95 energized through circuits including contacts of keys 1652 and 1677, and conductors 1358 and 1357, respectively. Relay 1691 stops register 1690 in position 0, the circuit of this relay being closed from sub-battery through the back contact of key 1602, the front contact of key 1692, the lower contacts of cam 1690^C, relay 1691, conductor 1353, and the lower contacts of cam 1350^S to main battery. 100

Office keys, like key 1522, are provided only for the more important offices. The setting of registers 1500, 1525 and 1550 for controlling the establishment of connections with other offices is determined by depressing various combinations of the tandem keys, such as 1505, 1507 and 1509. If the tandem keys are used, sub-battery is supplied for operating the registers through row contacts 1506, 1508, and 1510' of the tandem keys instead of the armature and front contact of relay 1504. 105 110 115 120 125 130

It should be noted that any of the keys when depressed are mechanically locked in their actuated position. These keys may be of the nature shown in the patent to Lundell No. 1,210,505, granted January 2, 1917. Normally closed contacts 1623, 1633, 1653 and 1683 are opened whenever a key in the respective row is depressed. Sub-battery being connected to these contacts through the 5 left-hand armature and front contact of relay 1694, these contacts serve for stopping their associated registers in position 0, whereby it is unnecessary to depress a key if the digit is 0.

15 As soon as the relay 1526 became energized a circuit was closed from sub-battery through the front contact and armature of relay 1504, the armature and front contact of relay 1526, the left-hand armature and 20 front contact of relay 1501, conductor 1356, the lower right-hand contact of cam 1300^D, the cam A and the power magnet of sequence switch 1300 to main battery. The sequence switch 1300 is moved out of position 3 and 25 into position 4. As soon as the relay 1551 became energized, the sequence switch was driven out of position 4 and into position 5, the driving circuit being closed from sub-battery through the front contact and armature 30 of relay 1504, the armature and front contact of relay 1551, conductor 1354, the lower left-hand contact of cam 1300^D, the contact of cam A and the power magnet of sequence switch 1300 to main battery. The 35 lower left-hand contact of cam 1300^B being closed, the sequence switch is immediately driven into position 6. As soon as the relay 1691 becomes energized, a circuit is closed from sub-battery through the 40 right-hand front contact and armature of relay 1694, the left-hand armature and front contact of relay 1691, the left-hand armatures and front contacts of relays 1676, 1651, 1626 and 1601 in series, conductor 1416, the 45 upper left-hand contact of cam 1300^B, contact of cam A, and the power magnet of sequence switch 1300 to main battery for driving this sequence switch out of position 6 and into position 7. In this position of the 50 sequence switch, circuits are closed for the magnets 1510, 1511, 1512, 1513 and 1514 from sub-battery through the windings of these magnets, conductors 1364, 1365, 1366 and 1367 respectively, the right-hand contacts of cams 1300^M and 1300^L and the lower left-hand contact of cam 1300^J to main battery. These magnets are arranged to release the latch by means of which the 55 keys are locked in their actuated positions and thus cause their return to normal. When the sequence switch 1300 moves out of position 6, the originally traced circuits for the various register magnets are opened in the contacts of the cams 1300^J and 1300^K, whereby such registers cannot be set in mo-

tion upon the deenergization of their associated stop relays, which occurs upon the restoration of the various keys to normal. When the contacts of the keys are opened, all the relays that were energized, in response to the actuation of the various keys, become deenergized. Relay 1351 closes a circuit from sub-battery through its left-hand armature and back contact, the upper right-hand contact of cam 1300^D, the contact of the cam A and the power magnet of sequence switch 1300 to main battery, for moving this sequence switch out of position 7 and into position 8. In position 8 of the sequence switch 1300, the allotter 70 sequence switch 1350 is moved out of position 1 into position 2 for allotting another sender for use. The circuit for moving sequence switch 1350 out of position 1 into 75 position 2 extends from sub-battery through the lower contacts of cam 1350^C, the left-hand contacts of cam 1300^V and the power magnet of sequence switch 1350 to main battery. Under the control of its A cam, the allotter is moved into position 2. When 80 the sequence switch 1300 moved out of position 7, the key release magnets became deenergized. In position 2 of the allotter sequence switch 1350, a circuit is closed from main battery through the lower contacts 85 of cam 1350^R, the winding of relay 1351, a resistance 1390, the upper left-hand contact of cam 1350^D and the lower left-hand contact of cam 1350^C to sub-battery. The relay 1351 becomes energized and connects 90 main battery through its right-hand armature and front contact, the lower contact of cam 1350^E and the contacts of cam 1350^F to the winding of magnets 1510—1514. If, for any reason, the keys were not 95 properly released in response to the first energization of these magnets, their complete restoration will now be insured. As will be hereinafter explained more in detail, the cord finder sequence switch of an idle sender that is ready for allotment, is 100 in position 18. For that reason, when the allotter sequence switch reaches position 2, its power magnet will find a circuit from main battery through cams 1350-A and B, and the upper contacts of cam R of any 105 cord finder sequence switch that is in position 18 to sub-battery, whereupon the allotter 1350 is moved out of position 2 and into position 4. The relay 1351 becomes deenergized and causes in turn the deenergization of magnets 1510 to 1514. In position 110 4 of the allotter, another cord finder and sender are allotted for use, the connection of the registers being controlled through the cams of the allotter in the same manner as in the above assumed case. The sequence switch of the cord finder allotted for use in position 4 of the allotter has the upper 115 left-hand contact of its cam 1300^D con-

nected to the upper right-hand contact of cam 1350^c.

The operation of key contacts 1692 as previously described causes the energization 5 of relay 1695. A circuit may now be traced from sub-battery, through the right-hand contact of cam 1300^R, the upper left-hand contact of cam 1300^S, conductor 1380, the lower contacts of cam 1400^T, the lead X (Fig. 10), the right-hand armature and back contact of relay 1015, the lead "Y" (Fig. 16), the left-hand armature and front contact of relay 1695, conductor 1376, the right-hand armature and back contact of relay 1316, conductor 1026 and the winding of relay 1020 to main battery. The relay 1020 closes a locking circuit for itself, through its right-hand front contact and armature, the conductor 940, the right-hand contacts of cam 20 900^V to sub-battery. For the purpose of maintaining the relay 1020 in its energized condition until the sequence switch 900 has moved beyond position 4, another circuit is closed from sub-battery at the left-hand armature and first front contact of relay 1020, conductor 927, the lower left-hand contacts of cams 900-B and A, and the power magnet of sequence switch 900 to main battery. The sequence switch 900 is moved out of position 30 4 into position 7, in which position the operator's telephone set is disconnected from the connecting unit. In the lower right-hand contacts of cams 900-E and F, a circuit is also closed from sub-battery, through 35 left-hand armature and second front contact of the relay 1020, and the winding of relay 1015 to main battery. The relay 1015 is maintained in its energized condition through a circuit including its right-hand front contact and armature, the lead X (Fig. 40 14), the lower contacts of cam 1400^T, conductor 1380, the upper left-hand contact of cam 1300^S, and the right-hand contact of cam 1300^R to sub-battery. Another circuit is 45 closed from sub-battery through the left-hand armature and front contact of relay 1015, the left-hand windings of relays 1032 and 1035, and the winding of relay 1025 in parallel to main battery. For the purpose 50 of preventing a further selection of the operator's position by an incoming call until after the release of the keys under energization of the key magnets has been effected, these relays remain energized dependent 55 upon the continued energization of relay 1015, which in turn is dependent upon the movement of sequence switch 1300 beyond position 7.

The seizure of the operator's position may 60 also be prevented by a circuit from sub-battery through the right-hand contacts of the cams "S" controlled by the first, second, etc., sequence switches in series, the left-hand contacts of cam 900^S, conductor 942 65 and the winding of the slow release relay

1006 to ground. This relay becomes energized and closes a circuit from sub-battery through its front contacts to maintain the relays 1035, 1032 and 1025 in their energized condition. The relay 1006 being slow 70 to release, maintains the energization of the relays 1035, 1032 and 1025 during the interval that the sequence switch 900 is moved from position 9 into position 2, in the event that the operator desires to listen in on any 75 connecting unit in the position when all of the connecting units in that position are in use.

If, for any reason, the operator desires to listen-in on a connection, she depresses an 80 individual listening-in key 995^a. This key is effective with a listening key sequence switch 900 in position 7, and the operator's sequence switch 1000 either in position 16^a to 1 with relay 1036 deenergized, or in position 2 to 16 with relay 1029 energized. When key 995^a is depressed, a circuit is 85 closed from main battery through the windings of 1044, 1032, 1035 and 1041 in parallel, the left-hand armature and back contact of relay 1040, conductor 925, the upper contacts of cam 900^c, the left-hand contact of key 995^a, conductor 929, the right-hand armature and back contact of relay 1040, right-hand back contact and armature of relay 1036, and the right-hand front contact and armature of relay 1028 to sub-battery. The relay 1035 opens the circuit of relay 1034, whereby the 90 selection of this operator's position is prevented even if her sequence switch 1000 is in position 1. The relay 1035 opens, also, in its right-hand back contact the circuit of relay 1042 to prevent the operator's sequence switch from being moved out of position 17 into position 1, if the sequence switch 1000 is in position 17. The relays 1032 and 1044 100 close circuits for preventing this operator's position from being selected by an incoming call. The relay 1041 closes a circuit from main battery, through the winding of the power magnet of sequence switch 1000, the left-hand contact of cam 1000^A, the lower left-hand contact of cam 1000^B, the right-hand front contact and armature of relay 1041, the lower back contact and armature of relay 1029, the left-hand contacts of cam 1000^C, and the right-hand front contact and armature of relay 1028 to sub-battery, for 105 moving this sequence switch out of position 1 and into position 4, should the sequence switch be in position 1 at that time. 110

The sequence switch 900 is moved out of position 7 into position 8 by a circuit extending from main battery, through the winding of its power magnet, the right-hand contacts of cam 900°, the right-hand contact of key 995^a, conductor 929, the right-hand armature and back contact of relay 1040, the right-hand back contact and armature of relay 1036, and the right-hand front con- 115 120 125

tact and armature of relay 1028 to sub-battery. From position 8 the sequence switch 900 is immediately moved into position 1, and through that position into position 2, under the control of a circuit extending from main battery through the power magnet of sequence switch 900, the upper right-hand contact of cam 900^B, the left-hand front contact and armature of relay 909, lower right-hand and upper left-hand contacts of cam 900^C, the right-hand back contact and armature of relay 995, and the normal contact of disconnect key 908 to sub-battery. From position 2 the sequence switch 900 is moved into position 4, under the control of a circuit extending from main battery, through the power magnet of this sequence switch, the right-hand contacts of cam 900^J, conductor 921 and the back contact and armature of relay 1070 to sub-battery. If, when the listening sequence switch 900 reaches position 2, any other listening sequence switch happens to be in position 4, then the relay 1070 is energized and would prevent the movement of the sequence switch 900 out of position 2 and into position 4. However, as soon as the sequence switch 900 reaches position 2, a circuit is closed from sub-battery through the normal contact of disconnect key 908, the right-hand armature and back contact of relay 995, the upper contacts of cam 900^C, and then through the lower left-hand contacts of cams B and A of the respective listening key sequence switch for moving it out of position 4 and into position 7, whereupon the relay 1070 becomes deenergized and closes the above-traced circuit for moving the sequence switch 900 out of position 2 and into position 4.

In positions 2 to 5 of the listening key sequence switch 900, a circuit is closed from sub-battery, through the lower right-hand and upper left-hand contacts of cam 900^V, conductor 939, the left-hand windings of relays 1035 and 1032, and the winding of relay 1025 in parallel, to main battery. Relay 1032 closes a series circuit from the preceding to the succeeding operator's circuit. The relay 1025 connects a timing interrupter through its right-hand front contact and armature to the assistant chief operator's desk, whereby this operator will be informed how long the key is being depressed, and the relay 1035 prevents the extension of a call to this operator's position.

If, at this time, the district sequence switch 1200 is in position 1, it is moved into position 2, while the listening sequence switch 900 is moving from position 2 to 4, under the control of a circuit extending from sub-battery, through the lower right-hand contact of cam 900^V, the upper left-hand contact of cam 900^W, conductor 983 and the lower right-hand contacts of cams 1200-B

and A. When the listening sequence switch is in position 4, and the district sequence switch 1200 in position 2, an idle sender is associated with the selected connecting circuit in the above-described manner.

With the listening sequence switch 900 in position 4, the operator's telephone set is connected to the connecting circuit through the contacts of key 1009. The tip side of the circuit of the called line is connected through the contacts of the key 1003. The sleeve circuit to the calling subscriber's line through conductor 903 is connected through the lower contacts of cam 900^I, conductor 918, the left-hand back contact of relay 1014, conductor 916, the left-hand contacts of cam 900^J, left-hand normal contacts of relay 995, left-hand armature and front contact of relay 913, and left-hand back contact and armature of relay 907 to ground at relay 909. The relay 1114, at the class-of-service indicator, is again energized for the purpose of operating the device conventionally shown in Fig. 8 (Sheet 1) by connecting coin-return current through the winding of relay 1119, the armature and front contact of relay 1114, conductor 1102, to the contacts of the coin-return key 1009, should it be necessary for the operator to return the coin deposited in the coin box. The other class-of-service indicating relays (Fig. 11) are also operated in the above-described manner to indicate again to the operator the class of the calling subscriber.

When the master coin return key 1009 is actuated, the relay 1114 being maintained energized, a negative high voltage current is connected through the resistance lamp 1121, the winding of the relay 1119, the right hand armature and front contact of relay 1114, conductor 1102, and the right-hand contact of the coin-return-key 1009 to the tip side of the calling subscriber's line, to cause the return of the coin.

Operation of district selector.

As soon as the sequence switch 1300 reaches position 4, a circuit is closed from sub-battery, through the right-hand contact of cam 1300^R, the upper left-hand contact of cam 1300^Q, the right-hand armature and back contact of relay 1317, conductor 1340, the lower right-hand contact of cam 1400^C, the cam A and the power magnet of sequence switch 1400 to main battery, for moving this sequence switch out of position 1 and into position 2. As soon as the sequence switch 1300 reaches position 5, a fundamental circuit is closed from main battery through the winding of relay 1232, the right-hand contacts of cam 1200^I, the right-hand front contact and armature of relay 1235, conductor 1238, cord finder terminal 1304 and wiper 1310, the lower contacts of cam 1300^E, conductor 1330, the armature and

back contact of relay 1405, the windings of stepping relay 1401, the lower contacts of cam 1400^g, conductor 1328, resistance 1389, the upper right-hand contact of cam 1300^g, 5 and the right-hand contact of cam 1300^r to sub-battery. The relays 1401 and 1232 become energized. Relay 1232 closes a circuit from main battery through the power magnet of sequence switch 1200, the left-hand contacts of cam 1200^e, the left-hand front contact and armature of relay 1232, the lower left-hand contacts of cams 1200-R and P to sub-battery, for causing the movement of sequence switch 1200 out of position 10 2 and into position 3, whereby the lamp 1229 changes from a flickering to a steady signal, the upper right-hand contact of cam I is opened. The relay 1232 does not become deenergized, a locking circuit being 15 closed from main battery through the winding, right-hand front contact and armature of this relay, the upper left-hand contact of cam 1200^y, the lower right-hand contact of cam 1200ⁱ, and then through the previously traced path to sub-battery.

Upon the energization of relay 1401, a circuit is closed from sub-battery through the upper right-hand and lower left-hand contacts of cam 1400^s, the front contact and armature of relay 1401, the lower left-hand and upper right-hand contacts of cam 1400^r, conductor 1377, the lower left-hand and upper right-hand contacts of cam 1300^t, conductor 1379, the lower left-hand contact of cam 1400^k, the upper left-hand contact of cam 1400^l, conductor 1421, the lower contacts of cam 1500^g (the register 1500 being in position 14), the lower right-hand contact of cam 1525^g (the register 1525 being in position 40 4), the armature and back contact of counting relay 4' (Fig. 17), and the winding of counting relay 4 to main battery. The lower counting relay 4 becomes energized and closes a locking circuit for itself from main battery through its winding, the winding of the upper counting relay 4', the front contact and armature of the lower counting relay 4, and the upper left-hand and lower right-hand contacts of cam 1400^t to sub-battery. The upper counting relay cannot become energized in this circuit because through the above-traced path including the right-hand armature and back contact of counting relay 4' and the armature and front 45 contact of the stepping relay 1401, the winding of this upper counting relay is shunted as long as the stepping relay 1401 remains energized.

In the meantime, the district selector was started in motion, its magnet 1210 being energized by current flowing from main battery through the winding of this magnet, the lower contact of cam 1200^e, the left-hand front contact and armature of relay 1232, the lower contacts of cam 1200^t and the left-

hand back contact and armature of relay 1228 to sub-battery. As soon as the commutator brush of the selector engages the conducting portion of the Z segment of the commutator plate (see Fig. 31), sub-battery is connected through this commutator plate, the upper left-hand contacts of cams 1200ⁱ and 1200^j, and the armature and front contact of relay 1232 to the winding of this relay. Due to the closure of this path, the relay 1401 is shunted and becomes deenergized. The shunt is now removed from the winding of the upper counting relay 4', and thus this counting relay is permitted to become energized. As soon as the commutator brush engages the first insulated portion of the A section of the Z commutator segment, the shunt is removed from the fundamental circuit, whereupon the stepping relay is again permitted to become energized and connect sub-battery to the armature of the upper counting relay 4'. This counting relay is now energized, wherefore the sub-battery is extended through the front contact of the upper counting relay 4', the armature and back contact of the counting relay 3', and the winding of the lower counting relay 3 to main battery. The lower counting relay 3 becomes energized and provides a locking circuit for itself in the same manner as the lower counting relay 4. The upper counting relay 3' is shunted out through the front contact of the stepping relay 1401. When the commutator brush again engages the conducting portion of the segment Z, the fundamental circuit is again shunted, resulting in the deenergization of the stepping relay 1401 and the energization of the upper counting relay 3'. These operations are repeated when the commutator brush engages and disengages the third and fourth insulated segments in section A of commutator Z. When the commutator brush leaves the fourth insulated segment of section A of commutator Z and re-engages the conducting portion of this segment, causing thus the fifth shunting of the fundamental circuit, the upper counting relay 4', and in multiple therewith the relay 1405, becomes energized. The relay 1405 opens the fundamental circuit, whereupon the relays 1401 and 1232 becomes deenergized. The upper counting relay 4' closes a circuit from sub-battery through the right-hand contacts of cam 1400ⁱ, the armature and front contact of the upper counting relay 4', and power magnet of sequence switch 1400 to main battery, causing the movement of this sequence switch out of position 2 and into position 3. The contacts of cam 1400ⁱ being now open, all the counting relays that were locked up during the previously described operations become deenergized.

The relay 1232 by opening this left-hand

- front contact causes the deenergization of magnet 1210, whereupon the district selector will be arrested in its upward travel. Furthermore, this relay closes a circuit from 5 main battery through power magnet of sequence switch 1200, the contact of cam 1200^A, the lower left-hand contact of cam 1200^C, the left-hand back contact and armature of relay 1232, the lower contacts of cam 1200^T, and 10 the left-hand armature and back contact of relay 1228 to sub-battery. The sequence switch 1200 is moved out of position 3 and into position 4. A circuit is now closed from main battery through the winding of trip 15 magnet 1208 and the left-hand contacts of cam 1200^P to sub-battery, whereupon the trip magnet becomes energized and twists the tripping spindle. In view of the fact that district selector was moved up five steps, 20 that is to say, until five pairs of counting relays were energized, the fifth set of brushes is now in a position opposite a tripping finger that has been moved into the path of the catch supporting the springs of this brush 25 set. This set of brushes will be tripped when the district selector reassumes its upward movement.
- The sender sequence switch 1400 is driven out of position 3 and into position 4, the 30 driving circuit being closed from main battery through the power magnet of sequence switch 1400, the left-hand contacts of cam 1400^D, conductor 1348 and the lower contacts of cam 1300^R to sub-battery. In position 4 35 of the sender sequence switch, the above-traced fundamental circuit, including relays 1232 and 1401, is again established through the same contacts and these relays become energized. Upon the energization of 40 relay 1232, the circuit including the power magnet of sequence switch 1200 and the left-hand contacts of cam 1200^E, is again closed for moving this sequence switch out of position 4 and into position 5. The relay 1232 45 locks up in the same manner as above described. The up-drive magnet 1210 is again energized by current flowing in the above-traced circuit and causes the further travel in the upward direction of the district selector brush rod. The relay 1401 closes a 50 circuit from sub-battery through the lower contacts of cam 1400^R, the armature and front contact of relay 1401, the lower contacts of cam 1400^S, conductor 1377, the lower left-hand and upper right-hand contacts of cam 1300^I, conductor 1379, the lower left-hand contact of cam 1400^K, the upper right-hand contact of cam 1400^L, conductor 1420, the lower contacts of cam 1500^I, the upper 55 right-hand contact of cam 1550^F (register 1550 being in position 1), the armature and back contact of the upper counting relay 1', and the winding of the lower counting relay 1 to main battery. The lower counting relay 1 becomes energized and closes a locking 60 circuit for itself including the winding of the upper counting relay 1'. However, as long as the stepping relay 1401 is energized, the upper counting relay is shunted out in the above described manner. When the commutator brush engages the conducting portion of the segment B, sub-battery is connected through this commutator segment and the lower contacts of cam 1200^I to the fundamental circuit, causing the shunting out of 65 the stepping relay 1401, whereupon the upper counting relay 1' becomes energized. When the commutator brush engages the first insulated portion of the segment B, the stepping relay 1401 again becomes energized 70 and causes the energization of the lower counting relay 0. When the commutator brush again engages the conducting portion of segment B, the stepping relay becomes deenergized and permits the energization of 75 the upper counting relay 0' and of relay 1405, whereupon the fundamental circuit is opened and the relays 1401 and 1232 become deenergized. The relay 1232 opens the circuit of the up-drive magnet 1210 causing the 80 arresting of the district selector, and closes the circuit, including its left-hand back contact and armature and the lower left-hand contact of cam 1200^C, for driving the sequence switch 1200 out of position 5 and into 85 position 6. The upper counting relay 0' closes the above-traced circuit including the right-hand contacts of cam 1400^I for driving the sequence switch 1400 out of position 4 and into position 5, whereupon all the counting 90 relays become deenergized.
- In position 6 of sequence switch 1200, a circuit is closed from main battery through the right-hand winding of a relay 1233, the lower right-hand contact of cam 1200^R, and the lower left-hand contact of cam 1200^P to sub-battery. The relay 1233 becomes energized and closes a circuit from main battery through the power magnet of a sequence switch 1200, the left-hand contacts 95 of cam 1200^E, the right-hand front contact and armature of relay 1233, the lower contacts of cam 1200^T and the left-hand back contact and armature of relay 1228 to sub-battery, whereupon the sequence switch is 100 moved out of position 6 and into position 7. When the sequence switch moves out of position 6, the above-traced circuit through the right-hand winding of relay 1233 is opened. However, if the trunk which with the 105 brushes of the district selector are now in engagement, is busy, as will be hereinafter explained more in detail, the relay 1233 is supplied with sub-battery through multiples of the test terminal of such busy trunk, test wiper 1222, the left-hand armature and front contact, and the winding of relay 1233 to main battery for maintaining this relay 110 energized. The relay 1233 being energized, the magnet 1210 of the district selector is 115 120 125 130

supplied with sub-battery through the left-hand armature and back contact of relay 1228, the lower contacts of cam 1200^T, the right-hand armature and front contact of relay 1233 and the lower contacts of cam 1200^E for causing the further travel of the district selector. As soon as the test wiper 1222 encounters an idle test terminal, such as 1223, to which sub-battery is not connected, the relay 1233 becomes deenergized, and opens in its right-hand front contact the circuit of magnet 1210, causing the arresting of the selector. In order to insure the proper centering of the brushes, relay 1233 may be maintained energized independently of the idle or busy condition of the test terminals by current flowing from main battery to the right-hand winding of this relay, the lower contacts of cam 1200^M, the conducting portion of commutator segments C and G which are strapped together as shown in Fig. 31, the upper right and lower left-hand contacts of cam 1200^E, the right-hand front contact and armature of relay 1233, the lower contacts of cam 1200^T, the left-hand back contact and armature of relay 1228 to sub-battery. The commutator brush engages the conducting portion of the segment C while the wipers of the selector are not exactly centered on a set of terminals, and engages an insulated portion of this segment when the wipers are exactly centered on a set of terminals, causing the opening of the above traced circuit and the deenergization of relay 1233. Upon deenergization, the relay 1233 connects sub-battery from the left-hand armature of relay 1228, lower contacts of cam 1200^T, through the right-hand armature and back contact of relay 1233 and the upper left-hand contact of cam 1200^E to the power magnet of sequence switch 1200, causing the movement of this sequence switch out of position 7 and into position 8. When the sequence switch 1200 reaches position 8, a circuit is closed from main battery through the power magnet of sequence switch 1400, the left-hand contact of cam 1400^A, the lower left-hand contact of cam 1400^C, conductor 1339, the lower right-hand and upper left-hand contacts of cam 1300^V, conductor 1323, wiper 1311 and terminal 1305 of the cord finder, conductor 1240, the lower right-hand contact of cam 1200^Q, and the lower left-hand contact of cam 1200^P to sub-battery. The sequence switch 1400 is moved out of position 5 and into position 6. A circuit is now closed from main battery through the winding of relay 1232, the upper right-hand contact of sequence switch cam 1200^I, the lower left-hand contact of sequence switch cam 1200^J, conductor 1237, terminal 1306, and wiper 1312 of the cord finder, the lower left-hand and upper right-hand contacts of sequence switch cam 1300^H,

conductor 1329, and the right-hand contacts of cam 1400^E to sub-battery. The relay 1232 becomes energized and closes a locking circuit for itself from main battery through its winding, right-hand front contact and armature, the lower right-hand and upper left-hand contacts of cam 1200°, and the right-hand back contact and armature of relay 1228 to sub-battery. 70

The sequence switch 1400 is driven from position 6 into position 8, and through that position into position 9 in the following manner: In position 6 and 8 of this sequence switch, a circuit is closed from main battery, through the windings of counting relays O and O' in series and the winding of relay 1405 in parallel, conductor 1331, the left-hand contacts of cam 1300°, conductor 1332 and the lower contact of cam 1400^F to sub-battery. The two O counting relays and the relay 1405 become energized and lock up through the armature and front contact of the lower counting relay O, and the contacts of cam 1400^I. A circuit is then closed from sub-battery through the right-hand contacts of cam 1400^I, the armature and front contact of the upper counting relay O' and the power magnet of sequence switch 1400 to main battery. The sequence switch moves out of position 6 into position 8. When the sequence switch moved out of position 6 the two counting relays and the relay 1405 become deenergized. In position 8 of the sequence switch, the above described circuit for counting relays O and O' and relay 1405 is again closed, and the relay O' causes the movement of the sequence switch into position 9, whereupon the relays become deenergized. 95

The energization of relay 1232 results in 105 the movement of sequence switch 1200 out of position 8 and into position 9, the circuit being closed from main battery, through the power magnet of sequence switch 1200, the left-hand contact of cam 1200^E, the left-hand front contact and armature of relay 1232, the lower contacts of cam 1200^T and the left-hand back contact and armature of relay 1228 to sub-battery. As soon as the sequence switch 1200 moves out of position 8₁, the relay 1232 becomes deenergized. 110

The register sequence switch 1500 being in position 14, a circuit is closed from sub-battery through the lower contacts of cam 1500^S, the left-hand contacts of cam 1300^P, conductor 1343, the lower left-hand contacts of cam 1400^B and A, and the power magnet of sequence switch 1400 to main battery, whereupon this sequence switch is moved out of position 9 and into position 10. 120

During the establishment of a connection between two semi-automatic substations, no impulses are sent out for the purpose of setting a number-indicator, to indicate the number of an office at a tandem board. 130

Such impulses may be sent out in positions 10, 12 and 14 of sequence switch 1400. For this reason, in the present case the sequence switch 1400 is moved through positions 10, 12 and 14 and the fundamental circuit is maintained open so that the energization of the stepping relay 1401 is prevented while the sequence switch is moving through such positions. This is accomplished in the following manner: The sequence switch 1500 being in position 14, a circuit is closed from sub-battery through the lower right-hand contact of cam 1500^s, and the upper left-hand contact of cam 1500^t, the upper left-hand contact of cam 1400^f, conductor 1332, the left-hand contacts of cam 1300°, conductor 1331, the windings of relay 1405, and the lower counting relay O, and in parallel therewith the winding of the upper counting relay O' to main battery. The relay 1405 prevents the closure of the fundamental circuit by maintaining its armature attracted, and the upper counting relay O' closes a circuit from sub-battery through the right-hand contacts of cam 1400^f, its armature and front contact, and the power magnet of sequence switch 1400 to main battery for moving the sequence switch out of position 10 and into position 11. From position 11 the sequence switch 1400 is driven by the above-traced circuit including the lower left-hand contact of cam 1400^b, the left-hand contacts of cam 1300^p and lower contacts of cam 1500^s. From position 12, the sequence switch is driven into position 14, and from that position into position 15 by the above-traced circuit including the right-hand contacts of cam 1400^f, and the armature and front contact of the upper counting relay O'. Then the sequence switch is driven from position 15 and through positions 16, 17 and 18 into position 1 by the circuit including the lower left-hand contact of cam 1400^b, the left-hand contacts of cam 1300^p, and the lower contacts of cam 1500^s. When the sequence switch 1400 reaches position 18^t, a circuit is closed from main battery through the power magnet of sequence switch 1300, conductor 1335, the right-hand contacts of cam 1400^h, conductor 1341, the lower left-hand contact of cam 1300^q and the right-hand contact of cam 1300^r, to sub-battery. The sequence switch 1300 is driven out of position 8 and into position 15.

When sequence switch 1300 moves out of position 9 and opens in the left-hand contacts of its cam 1300^y, the connection between conductors 1321 and 1322, the locking circuit including relays 1399 and 1235 is opened. These relays, however, remain energized because in positions 14 to 11^t of sequence switch 1400 conductors 1321 and 1322 are linked through the lower right-hand and upper left-hand contacts of cam 1400^f.

When the sequence switch 1400 moves out of position 18, the circuit including relays 1405 and the counting relays O and O' is opened at the upper left-hand contact of cam 1400^f. A circuit is closed from main battery through the power magnet of sequence switch 1400, the left-hand contact of cam 1400^a, the lower right-hand contact of cam 1400^c, conductor 1340, the right-hand back contact and armature of relay 1317, the upper left-hand contact of cam 1300^q, and the right-hand contact of cam 1300^r to sub-battery, whereupon the sequence switch 1400 is moved out of position 1 and into position 2.

Operation of incoming selector.

The relay 1232 being deenergized when the sequence switch 1200 reaches position 9, a circuit is closed from main battery through the power magnet of sequence switch 1200, the lower contact of cam 1200^a, the lower left-hand contact of cam 1200^c, the left-hand back contact and armature of relay 1232, the lower contacts of cam 1200^r, and the left-hand back contact and armature of relay 1228 to sub-battery for moving the sequence switch 1200 out of position 9 and through position 10 into position 11. A circuit is now closed from main battery through the winding of relay 1802, the upper left-hand contact of cam 1800^f, the upper left-hand contact of cam 1800^g, resistance 1821, conductor 1224, terminal 1219, wiper 1218, the lower right-hand contact of cam 1200^j, the lower right-hand contact of cam 1200ⁱ, the right-hand front contact and armature of relay 1235, conductor 1238, terminal 1304 and wiper 1310 of the cord finder, the lower left-hand and upper right-hand contacts of sequence switch cam 1300^m, conductor 1324, the lower contact of cam 1400°, the armature and back contact of relay 1405, the windings of relay 1401, the lower contacts of cam 1400^g, conductor 1328, the lower contacts of cam 1300^h, wiper 1312 and terminal 1306 of the cord finder, conductor 1237, the lower contacts of cam 1200^k, wiper 1220 and terminal 1221 of the district selector, conductor 1225, the upper contacts of cam 1800^h and resistance 1822 to sub-battery. The relays 1401 and 1802 become energized. The relay 1401 closes a circuit from sub-battery through the upper right-hand and lower left-hand contacts of cam 1400^f, the front contact and armature of relay 1401, the lower left-hand and upper right-hand contacts of cam 1400^r, conductor 1377, the lower contacts of cam 1300ⁱ, conductor 1378, the lower left-hand contact of cam 1400ⁿ, the upper left-hand contact of cam 1400ⁿ, conductor 1422, the lower left-hand contact of cam 1600^r, the upper right-hand contact of cam 1600^g (register 1600 being in position 8), the right-hand armature and back contact of the counting relay 130.

4' and the winding of the counting relay 4 to main battery. Counting relay 4 becomes energized and locks up through the winding of the counting relay 4', but as above described the latter does not become energized until the stepping relay 1401 releases its armature.

The relay 1802 closes a circuit from sub-battery through the lower contacts of cam 1800^P, the right-hand armature and front contact of relay 1802, the left-hand contacts of cam 1800^E and the winding of relay 1801 to main battery. Relay 1801 becomes energized and locks up from main battery 10 through its winding, left-hand front contact and armature, resistance 1825, conductor 1226, terminal 1223, and wiper 1222 of the district selector, the left-hand armature and back contact of relay 1233, resistance 1234, 15 the upper contacts of cam 1200°, the right-hand upper contact of cam 1200°, and the lower left-hand contact of cam 1200^P to sub-battery. Relay 1801 closes a circuit from sub-battery through its right-hand armature and front contact, the left-hand contacts of cam 1800^C, and the power magnet of sequence switch 1800 to main battery. The sequence switch 1800 is moved out of position 1, and under the control of its normal 20 contact A, is moved into position 2. When the sequence switch 1800 moves out of position 1 and opens the upper left-hand contact of cam 1800^F, the relay 1802 does not become deenergized, a locking circuit being 25 closed for this relay from main battery through its winding, the lower contacts of cam 1800°, the left-hand front contact and armature of relay 1802, the lower left-hand contact of cam 1800^F, then through the 30 above-traced circuit including relay 1401. In position 2 of sequence switch 1800, a circuit is closed from main battery through the winding of up-drive magnet 1818, the lower contacts of cam 1800^E, the right-hand 35 front contact and armature of relay 1802, and the lower contacts of cam 1800^P to sub-battery. The magnet 1818 becomes energized and causes the brush rod of the incoming selector to move in an upward direction. When the commutator brush engages 40 the conducting portion of commutator segment Z, sub-battery is connected through this commutator segment and the upper right-hand contact of sequence switch cam 1800^F to the fundamental circuit, causing 45 the shunting out of the stepping relay 1401, whereupon the upper counting relay 4' becomes energized. As the commutator brush engages successively the conducting portion 50 of this commutator segment and the insulated strips A (Fig. 32), the stepping relay 1401 is energized and deenergized, causing the successive actuation of the counting relays in the above-described manner. After 55 the fifth shunting of the relay 1401, the

counting relays O and O' and the relay 1405 become energized, the latter opening the fundamental circuit and counting relay O', causing the movement of sequence switch 1400 out of position 2 and into position 3, 70 whereupon the counting relays become deenergized. The opening of the fundamental circuit results in the deenergization of stepping relay 1401 and relay 1802. Relay 1802 opens the circuit of the up-drive magnet 75 1818, causing the arresting of the incoming selector, and closes a circuit from sub-battery through the lower contacts of cam 1800^P, the right-hand armature and back contact of relay 1802, the left-hand armature 80 and back contact of relay 1835, the lower right-hand and upper left-hand contacts of cam 1800^C, and the power magnet of sequence switch 1800 to main battery. Sequence switch 1800 is moved out of position 2 and into position 3, 85 whereupon the trip magnet 1819 becomes energized by current flowing through its winding from main battery and through the right-hand contacts of cam 1800^P to sub-battery. In view of the fact that the incoming selector was permitted to move until the counting relays received five impulses from the incoming selector, the fifth set of 90 brushes of this selector will now be in position to be tripped when the selector is again set in motion.

The sequence switch 1400 is driven out of position 3 into position 4 by a circuit extending from main battery, through its power magnet, the left-hand contacts of cam 1400^D, conductor 1348 and the lower contacts of cam 1300^R to sub-battery. When the sequence switches 1400 and 1800 reach positions 4 and 3, respectively, the above-traced fundamental circuit, including relays 100 1401 and 1802, is again closed, whereupon these relays become energized. Relay 1401 closes a circuit from sub-battery through the lower contacts of cam 1400^R, the armature and front contact of relay 1401, the 105 lower contacts of cam 1400^S, conductor 1377, the lower contacts of cam 1300^I, conductor 1378, the lower left-hand contact of cam 1400^M, and the upper right-hand contact of cam 1400^N, conductor 1423 the lower contacts of cam 1600^H, the lower left-hand and 110 upper right-hand contacts of cam 1625^H (sequence switch register 1625 being in position 7), the armature and back contact of counting relay 1' and the winding of counting relay 1 to main battery. The counting relay 1 becomes energized and closes a locking circuit for itself through the winding of counting relay 1', but as above stated, the latter does not become energized. The 115 relay 1802 closes a circuit from sub-battery through the lower contacts of cam 1800^P, right-hand armature and front contact of relay 1802, the left-hand contacts of cam 1800^D and the power magnet of sequence 120 125

switch 1800 to main battery, moving the sequence switch out of position 3 and into position 4. The relay 1802 remains energized by current flowing through the above-traced locking circuit. The incoming selector is now again set in motion, the up-magnet being energized through a circuit extending from main battery through its winding, the lower contacts of cam 1800^E, the right-hand front contact and armature of relay 1802 and the lower contacts of the cam 1800^P to sub-battery. The fifth set of brushes is tripped, and as soon as the commutator brush engages the conducting portion of commutator segment B, sub-battery is connected to the fundamental circuit through the lower right-hand contact of cam 1800^F. The relay 1401 becomes deenergized and permits the energization of the counting relay 1'. When the first insulated portion of commutator segment B is engaged by the commutator brush, the stepping relay 1401 again becomes energized, whereupon the lower counting relay O becomes energized and locks up. The subsequent engagement by the commutator brush of the conducting portion of segment B results in the deenergization of the stepping relay 1401, whereupon the upper counting relay O' and the relay 1405 become energized, the former causing the movement of sequence switch 1400 out of position 4 and into position 5, and the latter opening the fundamental circuit. The relays 1401 and 1802 and the counting relays become deenergized. Relay 1802 opens the circuit of magnet 1818, whereupon the incoming selector is arrested. This relay closes also the above-traced circuit through its right-hand back contact and the lower right-hand contact of cam 1800^C for moving sequence switch 1800 out of position 4 and into position 5. The magnet 1819 becomes deenergized. The sequence switch 1400 is driven out of position 5 and into position 6 by a circuit extending from main battery through its winding, the lower contact of cam 1400^A, the lower left-hand contact of cam 1400^C, conductor 1339, the lower left-hand contact of cam 1300^S, and the right-hand contact of cam 1300^R to sub-battery.

As soon as sequence switch 1800 reaches position 5, a circuit is closed from sub-battery through the lower right-hand and upper left-hand contacts of cam 1800^L, and the left-hand winding of relay 1835 to main battery. The relay 1835 becomes energized and closes a circuit from sub-battery through the lower contacts of cam 1800^P, the right-hand armature and back contact of relay 1802, the left-hand armature and front contact of relay 1835, the left-hand contacts of cam 1800^D, and the power magnet of sequence switch 1800 to main battery for moving this sequence switch out of position 5 and into position 6. The above-traced energizing circuit for relay 1835 is now opened in the lower right-hand contact of cam 1800^L, but if the test wiper 1812 of the incoming selector engages the test terminal of a busy trunk, that is to say, one to which sub-battery is connected, the relay 1835 is maintained energized by current flowing from sub-battery through the busy test terminal, wiper 1812, resistance 1817, the right-hand armature and front contact of the relay 1835, the lower contacts of cam 1800^J and the right-hand winding of relay 1835 to main battery. For this reason, the up-magnet 1818 is again energized, the circuit extending from main battery through magnet 1818, the lower contacts of cam 1800^E, the left-hand armature and front contact of relay 1835, the right-hand back contact and armature of relay 1802, and the lower contacts of cam 1800^P to sub-battery. Under the control of this magnet the incoming selector is caused to continue its upward movement until the brush 1812 encounters the test terminal of an idle trunk such as terminal 1813, whereupon the relay 1835 becomes deenergized and causes the arresting of the incoming selector by opening the circuit of the magnet 1818. In order to insure the proper centering of the brushes, independently of the busy or idle condition of the trunks encountered by the test wiper, the test relay 1835 may be maintained energized by current flowing through a circuit extending from sub-battery through the lower contacts of cam 1800^P, the right-hand armature and back contact of relay 1802, the left-hand armature and front contact of relay 1835, the lower contacts of cam 1800^K, the commutator segment G, the conducting portion of segment C, the left-hand contacts of cam 1800^L, and the left-hand winding of relay 1835 to main battery. It is to be observed from Fig. 32 that segments G and C are strapped together. As soon as the commutator brush leaves the conducting portion of segment C and engages an insulated portion thereof, indicating that the brushes are properly centered on terminals 1809, 1811 and 1813, the last traced circuit for the relay 1835 is opened and this relay is permitted to become deenergized. A circuit is then closed from sub-battery through the lower contacts of cam 1800^P, the right-hand armature and back contact of relay 1802, the left-hand armature and back contact of relay 1835, the lower right-hand and upper left-hand contacts of cam 1800^C, and the power magnet of sequence switch 1800 to main battery for moving the sequence switch out of position 6 and into position 7. As soon as the relay 1835 becomes deenergized and until the connection is severed, sub-battery is connected to test terminal 1813 and multiples thereof for pre-

venting the seizure of trunk 1814, 1815 by another incoming selector. Immediately upon the deenergization of relay 1835, sub-battery is connected through the lower left-hand and upper right-hand contacts of cam 1800^M, the right-hand back contact and armature of relay 1835, resistance 1817 and wiper 1812. When sequence switch 1800 reaches position 7 and until it moves out of position 16, sub-battery is connected through the upper contacts of cam 1800^K, resistance 1817 and test wiper 1812.

Operation of final selector.

- 15 The circuit including the relay 1802 and the stepping relay 1401 is now again closed over the same path as described for the incoming selector and these relays become energized. The stepping relay closes a circuit 20 from sub-battery through the upper right-hand and lower left-hand contacts of cam 1400^S, the front contact and armature of relay 1401, the lower left-hand and upper right-hand contacts of cam 1400^R, conductor 25 1377, the lower contacts of cam 1300^I, conductor 1378, the lower left-hand contact of cam 1400^M, the lower right-hand contact of cam 1400^N, conductor 1424, the lower left-hand contacts of cam 1625-F and G, the 30 armature and back contact of the counting relay 2' and the winding of counting relay 2 to main battery. Counting relay 2 becomes energized and locks up. The relay 1802 closes a circuit from sub-battery through the 35 left-hand contacts of cam 1800^D for moving sequence switch 1800 out of position 7 and into position 8, and locks up through the lower contacts of cam 1800°, the left-hand front contact and armature of 1802, lower left contact of 1800^F and from thence over the previously traced fundamental circuit. When the sequence switch 1800 reaches position 40 8, a circuit is closed from sub-battery through the lower contacts of cam 1800^F, the right-hand armature and front contact of relay 1802, the lower left-hand and upper right-hand contacts of cam 1800^E, wiper 1808 and terminal 1809 of the incoming selector, conductor 1814, the upper left-hand 45 and lower right-hand contacts of cam 1900^I, and the windings of relay 1902 to main battery. Relay 1902 becomes energized and closes a circuit from sub-battery through its left-hand armature and front contact, the 50 upper contacts of cam 1900^C and the winding of relay 1901 to main battery. Relay 1901 becomes energized and locks up through its right hand front contact and armature, resistance 1911, conductor 1816, terminal 55 1813 and wiper 1812 of the incoming selector, resistance 1817, and the upper contacts of cam 1800^K to sub-battery. Relay 1901 closes a circuit from sub-battery through its left-hand armature and front contact, the upper right-hand contact of cam 60 65

1900^B, the lower contact of cam 1900^A and the power magnet of sequence switch 1900 to main battery for moving the sequence switch 1900 out of position 1 and into position 2. When the sequence switch 1900 moves out of position 1, the relay 1902 is maintained energized through a locking circuit extending from main battery through its winding, the left-hand contacts of cam 1900^E, the right-hand front contact and armature of relay 1902, the left-hand contacts of cam 1900^I and conductor 1814 to sub-battery at cam 1800^P. The final selector is now set in motion, its high speed up-drive magnet 1904 being energized by current 80 flowing through a circuit from main battery through the winding of this magnet, the lower contacts of cam 1900^E, the right-hand front contact and armature of relay 1902, the left-hand contacts of cam 1900^I, and conductor 1814 to sub-battery at cam 1800^P. When the commutator brush of the final selector engages the conducting portion of segment U, sub-battery is connected through 85 this segment, the upper right-hand contact of cam 1900^G, the upper right-hand contact of cam 1900^H, conductor 1815, terminal 1811, wiper 1810, the lower left-hand contact of cam 1800^G to the fundamental circuit for 90 causing the shunting out of the stepping relay 1401. The upper counting relay 1' becomes energized. When the commutator brush engages the first insulated segment in the A portion of commutator plate U, the lower counting relay O becomes energized, and when the commutator brush again contacts with the conducting portion of segment U, the upper counting relay O' and the relay 1405 become energized. The counting relay O' causes the movement of sequence switch 1400 out of position 6 and into position 8, whereupon the counting relays are unlocked. Relay 1405 opens the fundamental circuit whereupon the relays 1401 and 1802 become deenergized. Upon 100 the deenergization of relay 1802, relay 1902 and the up-drive magnet 1904 become deenergized. Relay 1902 closes a circuit from sub-battery through its left-hand armature and back contact, the lower contacts of cam 1900^C, and the power magnet of sequence switch 1900 to main battery for moving this sequence switch out of position 2 and into 105 position 3. The trip magnet 1910 of the final selector is now energized by current flowing through a circuit including the upper left-hand and lower right-hand contacts of cam 1900^J. In view of the fact that two 110 impulses were sent from the final selector to the counting relays, the second set of brushes will now be in position to be tripped when the final selector is further moved in the upward direction. The relay 1802 recloses the circuit through the lower right-hand and upper left-hand contacts of cam 115 120 125 130

1800^c, whereupon the sequence switch 1800 is moved from position 8 into position 9. The fundamental circuit including relays 1802 and 1401 is now again closed. The 5 relay 1401 closes a circuit from sub-battery through the lower contacts of cam 1400^R, the armature and front contact of relay 1401, the lower contacts of cam 1400^s, conductor 1377, the lower contacts of cam 1300^t, conductor 1378, the lower left-hand contacts of cam 1400-M and N, conductor 1425, the lower left-hand contact of cam 1650^F, the upper left-hand contact of cam 1650^G, the right-hand back contact and armature of 10 counting relay 6', and the winding of counting relay 6 to main battery. Counting relay 6 becomes energized and closes a locking circuit for itself. Relay 1802 recloses the circuit from sub-battery through the lower contacts of cam 1800^P and the left-hand contacts of cam 1800^D for moving the sequence switch 1800 out of position 9 and into position 10. Relay 1802 locks up through the above-traced circuit. Upon the energization 15 of the relay 1802, the relay 1902 is again energized through the above-traced circuit and closes the circuit from sub-battery through its left-hand armature and front contact and the upper right-hand and lower 20 left-hand contacts of cam 1900^C for moving sequence switch 1900 out of position 3 and into position 4. Relay 1902 is locked up through the above-traced circuit including the left-hand contacts of cam 1900^E and 25 the right-hand front contact and armature of relay 1902. The up-drive magnet 1904 is now again energized and causes the further travel of the final selector in an upward direction. The shunting of the stepping 30 relay 1401 is now controlled by the commutator brush of the final selector engaging the conducting portion of segment B and thus connecting sub-battery through the upper right-hand contact of cam 1900^F, the 35 lower left-hand contact of cam 1900^A, and conductor 1815 to the fundamental circuit. Upon the ninth shunting of the fundamental circuit, the counting relays O and O' and the relay 1405 become energized. The counting 40 relay O' closes a circuit for moving the sequence switch 1400 out of position 8 and into position 9, whereupon the counting relays are unlocked. The relay 1405 opens the fundamental circuit whereupon the relays 45 1401 and 1802 become deenergized. Relay 1802 opens the circuit of the up-drive magnet 1904 and of relay 1902. The relay 1902 closes a circuit through the lower contacts of cam 1900^C for moving the sequence switch 1900 out of position 4 and into position 5. The relay 1802 closes a circuit through the lower right-hand and upper left-hand contacts of cam 1800^C for moving the sequence switch 1800 out of position 10 and into posi- 50 tion 11. The sequence switch 1400 is driven out of position 9 into position 10 by a circuit extending from main battery through its power magnet, the left-hand contact of cam 1400^A, the upper right-hand contact of cam 1400^C, conductor 1342, the lower right-hand contact of cam 1300^Q, and the right-hand contact of cam 1300^R to sub-battery. The circuit including relays 1401 and 1802 55 is now again closed and these relays become energized. The relay 1401 closes a circuit from sub-battery through the upper right-hand and lower left-hand contacts of cam 1400^S, front contact and armature of relay 1401, the lower left-hand and upper right-hand contacts of cam 1400^R, conductor 1377, the lower contacts of cam 1300^t, conductor 1378, the lower left-hand and upper right-hand contacts of cam 1400^M, conductor 1426, the lower left-hand contact of cam 1675^F and the upper right-hand contact of cam 1675^G (sequence register switch 1675 being in position 5), the armature and back contact of counting relay 5', and the winding of counting relay 5 to main battery. Counting relay 5 becomes energized and locks up. The relay 1802 closes the circuit through the left-hand contacts of cam 1800^P, whereupon the sequence switch 1800 is moved out of position 11 and into position 12, and the circuit for energizing relay 1902 is again closed through cam 1800^E. The relay 1902 closes a circuit through the upper right-hand and lower left-hand contacts of cam 1900^C, whereupon the sequence switch 1900 is moved out of position 5 and into position 6. The trip magnet 1910 becomes deenergized. Instead of the high speed up-drive magnet 1904, the low speed up-drive magnet 1903 is now in the circuit including the upper right-hand and lower left-hand contacts of cam 1900^E, and causes the final selector to continue its upward movement. The shunting of the fundamental circuit is now again controlled through the commutator segment U and the upper right-hand contact of cam 1900^G until the counting relays O and O' and the relay 1405 become energized. The relay O' moves the sequence switch 1400 out of position 10 and into position 11, whereupon the counting relays are 60 unlocked. The relay 1405 opens the fundamental circuit, whereupon relays 1401 and 1802 become deenergized. The relay 1802 closes the circuit through the lower right-hand and upper left-hand contacts of cam 1800^C for moving the sequence switch 1800 out of position 12 and into position 13, and by opening its right-hand front contact causes the deenergization of relay 1902 and magnet 1903, whereupon the final selector is arrested. The relay 1902 closes the circuit through the lower contacts of cam 1900^C, whereupon the sequence switch 1900 is 65 70 75 80 85 90 95 100 105 110 115 120 125

moved out of position 6 and into position 7.

Reverting busy test.

5 The apparatus is now in condition to make the tests of the called line. The sleeve of the called line is assumed in this case to be connected to main battery through a cut-off relay similar to relay 102, terminal 1917, 10 and wiper 1916 of the final selector, the lower contacts of cam 1900^L, the upper winding of relay 1907, the lower contacts of cam 1900^M, the lower winding of relay 1907 to ground. As will be hereinafter set forth 15 more in detail, if the line is busy, relay 1907 will not be operated because both its windings in series are shunted by a path which would lead from the sleeve of the called line to a guarding resistance or relay and 20 ground, the value of this resistance being such that relay 1907 will not energize. If the line is idle, relay 1907 will become energized and through its upper front contact and armature close a circuit to ground at 25 the right-hand back contact of relay 1906, thus shunting its lower winding. The upper winding of relay 1907 is sufficiently low to prevent similar relays 1907 of other final selectors from energizing should the attempt 30 be made to make connection with the line.

It is thus seen that the line is in a busy condition either due to the low resistance path to ground from some other circuit which makes it busy, or from the particular 35 final selector itself. The time has now come to make the reverting busy test, that is to say, a functioning of the apparatus as a whole to determine whether the line called is the same as the calling line or not. Sequence switch 1400 is in position 11, 1200 is in position 40 11, 1800 in position 13, 1900 in position 7, 900 in position 7 and 300 in position 14. Relay 1382 is energized as previously described because relay 1524 was operated 45 at the time that the office key, denoting the local office, was operated. The object of the circuit as will immediately be described, is to determine by the operation or failure in operation of relay 1411 at the time that sequence switch 1400 is passing position 13 $\frac{1}{4}$, 50 whether or not relay 1412 will operate. If relay 1412 is operated in this position of sequence switch 1400, it will remain energized due to a locking path which will subsequently be traced. If relay 1412 is energized, it prevents sequence switch 1400 from 55 moving out of position 15 and gives the desired signal to the operator that the line connected to the final selector is the same as 60 that connected to the connecting unit through the finder circuit.

When the sequence switch 1400 reaches position 11, a circuit is closed from main battery through the winding of relay 1409, 65 the right-hand hand contacts of cam 1400^P,

conductor 1381, the left-hand front contact and armature of relay 1382, the lower right-hand contact of cam 1300^S, and the right-hand contact of cam 1300^R to sub-battery. The relay 1409 becomes energized and closes 70 a circuit from sub-battery through its armature and front contact, the winding of relay 1408, the left-hand back contact and armature of relay 1410, the left-hand contacts of cam 1400^H, conductor 1328, the lower contacts of cam 1300^H, wiper 1312 and terminal 1306 of the cord finder, conductor 1237, the lower contacts of cam 1200^K, wiper 1220 and terminal 1221 of the district selector, conductor 1225, the upper contacts of cam 1800°, the left-hand armature and back contact of relay 1802, the upper contacts of cam 1800^N, wiper 1808 and terminal 1809 of the incoming selector, conductor 1814, the upper left-hand and lower right-hand contacts of cam 1900^I, and the windings of relay 1902 to main battery. Relays 1902 and 1408 become energized when the sequence switches 1400 and 1900 arrive in positions 11 and 7, respectively, thus insuring that both these sequence switches are in their respective positions, in order that the proper time intervals required for the operation or non-operation of relay 1411 is assured. Relay 1408 closes a circuit from sub-battery through its armature and front contact, the upper left-hand contact of cam 1400^C, the left-hand contact of cam 1400^A, the power magnet of sequence switch 1400 to main battery for moving this sequence switch out of position 11 and into position 12, from which position it will be moved to position 14, and through this position into position 15, the driving circuit being closed from main battery through the power magnet of sequence switch 1400, the left-hand contact of cam 1400^A, the upper right-hand contact of cam 1400^C, conductor 1342, the lower right-hand contact of cam 1300°, the right-hand contact of cam 1300^R to sub-battery. The relay 1902 100 closes a circuit from sub-battery through its left-hand armature and front contact, the upper right-hand and lower left-hand contacts of cam 1900^C and the power magnet of sequence switch 1900 to main battery for moving sequence switch 1900 out of position 7 and into position 13. The relay 1902 becomes deenergized when sequence switch 1900 breaks its circuit in position 7 $\frac{1}{4}$ at cam I. The two sequence switches 1900 and 1400 105 are now actually moving from positions 7 and 11, respectively, to positions 13 and 15, respectively. While the sequence switch 1400 is moving from position 11 $\frac{1}{4}$ to position 14, the upper left-hand contact of cam 1400^P is maintained 110 open. As above described, relays 1235 and 1399 were maintained energized through this contact. The relay 1235 becomes deenergized. However, the relay 1399 is main- 115 120 125 130

tained energized by a circuit extending from main battery through its winding, the lower contacts of cam 1300^G, the left-hand front contact and armature of relay 1399, 5 conductor 1321, the lower contacts of cam 1400^P, conductor 1346, the lower contacts of cam 1300^N, the lower left-hand contact of cam 1500^T and the lower right-hand contact of cam 1500^S to sub-battery.

10 Upon the deenergization of relay 1235, a circuit is closed from sub-battery, through the left-hand armature and back contact of relay 1235, the right-hand contacts of cam 1200^V, and the winding of relay 1232 to main 15 battery for energizing this relay. The relay 1232 locks up through its right-hand front contact and armature, the upper right-hand contact of cam R and the lower left-hand contact of cam P of the sequence switch 1200.

20 When the sequence switch 1400 moves out of position 12, the circuit of relay 1409 is opened in the upper right-hand contact of cam 1400^G. This relay in turn opens the circuit of relay 1408. Relays 1408 and 1409 25 become deenergized. While the sequence switch 1400 is moving from position 12 to 13 $\frac{1}{2}$, a circuit is closed from main battery through the winding of relay 1410, the upper left-hand and lower right-hand contacts of cam 1400^G, conductor 1381, left-hand front contact of relay 1382 and the lower right-hand contacts of cams 1300-S and R to sub-battery. The relay 1410 becomes energized 30 and closes a circuit for the two windings 35 of the reverting busy test relay 1411 that extends to the sleeve conductor of the calling line and to the sleeve conductor of the called line, respectively. At this time sequence switch 1900 will have arrived at 40 position 8 and will not have passed position 10.

A circuit may now be traced, which connects the right-hand winding of the reverting busy test relay 1411 in multiple with 45 the sleeve circuit of the calling line and the left-hand winding of relay 1411 to the sleeve of the called line, so that a so-called Wheatstone bridge circuit is formed in which the sleeve circuit of the calling line, including 50 the left-hand winding of relay 330, is in series with the right-hand winding of relay 1411, which at that time is in multiple with relay 909. From the junction of these two 55 circuits as indicated at relay 1411, the galvanometer is replaced by the left-hand winding of relay 1411 which connects to a similar circuit to that above described, composed of the sleeve circuit of the called line and the upper winding of relay 1907, or its equivalent, 60 which is in parallel with resistance 1480. As will be shown, if the called line is different from the one that is called the current values through the two windings of relay 1411 will operate the same. The above outlined circuit may be traced in detail in the 65 following manner: from main battery through the winding of cutoff relay 102, sleeve conductor 116, terminal 303, wiper 307, and commutator 311 of the line finder, the lower left-hand and upper right-hand 70 contacts of cam 300^K, the left-hand winding of relay 330, the lower left-hand and upper right-hand contacts of cam 300°, commutator brush 323, wiper 319 and terminal 315 of the connecting unit selector, conductor 75 903, the lower left-hand and upper right-hand contacts of cam 900^I, the left-hand back contact of relay 995, the left-hand armature and front contact of relay 913; the back contact and left-hand armature of relay 907, conductor 992, the upper contacts 80 of cam 1200^L, the right-hand back contact and armature of relay 1235, conductor 1238, terminal 1304 and wiper 1310 of the cord finder, the lower left-hand and upper right-hand contacts of cam 1300^E, conductor 1324, 85 the upper right-hand contact of cam 1400°, the right-hand armature and front contact of relay 1410, and the right-hand winding of relay 1411 to ground. Starting from the junction of the two windings of relay 1411, the galvanometer part of this circuit may be traced through the left-hand winding of relay 1411, the left-hand front contact and armature of relay 1410, the left-hand contacts of cam 1400^H, conductor 1328, the lower contacts 90 of cam 1300^H, wiper 1312, and terminal 1306 of the cord finder, conductor 1237, the lower contacts of cam 1200^K and wiper 1220 of the district selector, terminal 1221 conductor 95 1225, the upper contacts of cam 1800°, the left-hand armature and back contact of relay 1802, the upper contacts of cam 1800^N, wiper 1808 and terminal 1809 of the incoming selector, conductor 1814, the left-hand contact of cam 1900^L, wiper 1916 and terminal 1917 of the final selector, and the winding of the cutoff relay associated with the called line to main battery. To complete 100 the Wheatstone bridge circuit above mentioned, the right-hand winding of relay 1411 is shunted by a circuit which may be traced from conductor 992 through the winding of relay 909 to ground, and from conductor 992, the upper contacts of cam 1200^L, the 105 right-hand back contact and armature of relay 1235, conductor 1238, terminal 1304 and wiper 1310 of the cord finder, lower left-hand and upper right-hand contacts of cam 1300^E, conductor 1324, the upper right-hand 110 contact of cam 1400°, the right-hand armature and the front contact of relay 1410 to the right-hand winding of relay 1411. In the called end, the resistance 1480 is connected in multiple with the upper winding 115 of relay 1907 through the above-traced path, from the left-hand winding and left-hand front contact of relay 1410 to the left-hand contact of cam 1900^L, from the lower right-hand contact of cam 1900^L to the upper 120 125 130 contact of cam 1900^L to the upper 130

winding of relay 1907, upper front contact and armature of relay 1907, right-hand back contact and armature of relay 1906 to ground.

- 5 The relay 1411 is connected into this circuit during positions 12 to 13½ of sequence switch 1400, by means of relay 1410 by cam 1400^Q and at the same time sequence switch 1900 of the final selector is moving through 10 positions 8 to 10, inclusive. Under this circuit condition, the relay 1411 is energized, the current passing through the two windings being sufficient to operate the relay if the line called is a different one from 15 that which was calling.

In order to attain this result, the following resistances have been found advantageous: for the windings of the cutoff relays 102 or their equivalent, 100 ohms; 20 for the left-hand winding of relay 330, 18½ ohms; for the winding of relay 909, 32½ ohms; for the upper winding of relay 1907 or its equivalent, 50 ohms; for the resistance 1480, 40 ohms; for each of the 25 two windings of the reverting busy test relay 1411, 265 ohms. With these resistance values, the relay 1411 will be operated whenever the line called is a different line, the cutoff relay of which is connected either 30 to the battery of the same polarity as that of the calling line, or to battery of the opposite polarity of the calling line; that is to say, if the cutoff relay of the calling line is connected to main battery, the cutoff relay 35 of the called line will be connected either to main or sub-battery, and the relay 1411 will be operated in the circuit above described provided the called line is a different line from the calling line. If the 40 called line is the same line as that of the calling line, the left-hand winding of the reverting busy test relay 1411 will be shunted by the left-hand winding of relay 330, and the direction of current through 45 the left-hand winding of relay 1411 will be in the opposite direction from that in which it will flow under any of the above mentioned conditions when the line tested is a different one from that which is calling. 50 Due to these effects and the differential balanced windings of relay 1411, the relay will be operated whenever the line called is a different line from that which is calling, and will not be operated when the line called 55 is the same as that which is calling.

It will be obvious to those skilled in the art that depending upon the sensitiveness of relay 1411 and its well-known factors, its operation or non-operation under the above 60 described condition may be produced by a different adjustment of the resistances or arrangement of the current paths or windings of the relay itself.

When the sequence switch 1400 reaches 65 position 15, it immediately moves into posi-

tion 16 under the control of a circuit extending from main battery through the power magnet of sequence switch 1400, the left-hand contact 1400^A, the lower right-hand contact of cam 1400^B, the right-hand armature and back contact of relay 1412, conductor 1381, the left-hand front contact and armature of relay 1382, the lower right-hand contact of cams 1300-S and R to sub-battery.

When the sequence switch 1400 reaches position 14, the locking circuit through the upper left-hand contact of 1400^P and including relays 1399 and 1235 is again closed, and the latter becomes energized.

Testing of called line

In positions 7 to 13 of the sequence switch 1900, the called line is tested for its busy or idle condition. Assuming that the line is idle, main battery potential is supplied to test terminal 1917 and then through test wiper 1916, the lower contact of cam 1900^L, the upper winding of marginal test relay 1907, the lower contacts of cam 1900^M and the lower winding of test relay 1907 to ground. The relay 1902 which became deenergized when the sequence switch 1900 moved out of position 7, becomes energized again as soon as the sequence switch reaches position 7½. The circuit may be traced from main battery through the windings of relay 1902, the upper left-hand contact of cam 1900^F, the lower right-hand contact of cam 1900^G, the back contact and armature of relay 1908, the lower back contact and armature of relay 1907 and the left-hand back contact and armature of relay 1906 to sub-battery. When relay 1907 becomes energized it opens this circuit, whereupon relay 1902 becomes deenergized. As soon as the sequence switch reaches position 13, it is immediately driven into position 15 by a circuit extending from sub-battery through the left-hand armature and back contact of relay 1902, 105 the lower contacts of cam 1900^C and the power magnet of sequence switch 1900 to main battery. From this position it is driven into position 16 by a circuit extending from main battery through the power magnet of sequence switch 1900, the lower right-hand contacts of cams 1900^A and 1900^B, the left-hand contacts of cam 1900°, the lower front contact and armature of relay 1907, and the left-hand back contact 115 and armature of relay 1906 to sub-battery.

Upon energization, the relay 1907 shunts out its high resistance (lower) winding, whereby the potential on the multiples of terminal 1917 will be reduced so as to prevent the seizure of this line by another connector. In position 16 of the sequence switch 1900, instead of the upper low resistance winding of relay 1907, the winding of relay 1906 is included in the test circuit 125 130

through the lower contact of cam 1900^L, the winding of relay 1906 and the lower right-hand and upper left-hand contacts of cam 1900^K to ground. Upon the energization of relay 1906, the relay 1907 becomes deenergized.

When the sequence switch 1200 reaches position 12, a circuit is closed from ground through the secondary winding of repeating coil 1205, normal contacts of key 1206, conductor 974, the upper left-hand and lower right-hand contacts of cam 900^N, conductor 975, the right-hand contacts of cam 1200^J, wiper 1218, terminal 1219, conductor 1224, the upper right-hand contact of cam 1800^G, the upper left-hand contact of cam 1800^F and the winding of relay 1802 to main battery. The relay 1802 becomes energized and closes the circuit including its right-hand armature and front contact and the left-hand contacts of cam 1800^D for driving the sequence switch 1800 out of position 13 and into position 15, whereupon the relay 1802 becomes deenergized.

25 *Restoration of sender.*

In position 16 of sequence switch 1400, a circuit is closed from main battery through the power magnet of sequence switch 1200, the lower left-hand and upper right-hand contacts of cam 1200^D, conductor 1240, terminal 1305, wiper 1311, conductor 1323, the right-hand contacts of cam 1400^E, conductor 1346, the lower contacts of cam 1300^N, the lower left hand-contact of cam 1500^T and the lower right-hand contact of cam 1500^S to sub-battery. Under the control of this circuit the sequence switch 1200 is moved out of position 11 into position 12, whereupon the relays 1232, 1235 and 1399 become deenergized. This sequence switch is driven from position 12 into position 14 under the control of a circuit extending from main battery through its power magnet, the right-hand contact of cam A, the upper-right hand contact of cam B, the right-hand back contact and armature of relay 1215 and the lower left-hand contacts of cams Q and P to sub-battery.

The relay 1399 closes a circuit from sub-battery through its right-hand armature and back contact, the lower left-hand contacts of cams 1300-C and A, and the power magnet of sequence switch 1300 to main battery. The sequence switch 1300 is moved out of position 15 into position 17. A circuit is now closed from sub-battery through the right-hand armature and back contact of relay 1399, the lower left-hand and upper right-hand contacts of cam 1800^F, conductor 1347, the lower contacts of cam 1400^D and the power magnet of sequence switch 1400 to main battery. The sequence switch 1400 is moved out of position 16 and through

positions 17 and 18 into position 1. A circuit is now closed from main battery through the winding of downdrive magnet 1326, conductor 1349, the right-hand contacts of cam 1400^D, conductor 1347, the upper right-hand and lower left-hand contacts of cam 1300^F, and the right-hand armature and back contact of relay 1399 to sub-battery. The magnet 1326 becomes energized and causes the cord finder to move in a downward direction. When the cord finder is restored to normal, a circuit is closed from sub-battery through the commutator brush, segment Y, the upper right-hand contact of cam 1300^B, the left-hand contact of cam A and the power magnet of sequence switch 1300 to main battery for moving it out of position 17 into position 18. Magnet 1326 and relay 1382 become deenergized, the latter due to the opening of its locking circuit at the upper right-hand contact of cam 1300^S. The operator's sending and controlling equipment is now restored to normal and may be used for controlling the establishment of another connection as soon as the sequence switch 1300 is moved into position 1. This will be accomplished when the allötter sequence switch 1350 is moved into position 1 and closes a circuit from sub-battery through the lower contacts of cam 1350^C, the upper left-hand contact of cam 1300^D, the left-hand contact of cam A and the power magnet of sequence switch 1300 to main battery.

100 *Ringing.*

The connection being now established, the signaling of the called party is accomplished in the following manner: A circuit is closed from main battery through the left-hand contacts of cam 1800^F, the right-hand armature and back contact of relay 1802, the left-hand armature and back contact of relay 1835, right-hand contacts of cam 1800^C, the right-hand armature and back contact of relay 1805, the back contact and armature of relay 1806, the winding of relay 1807, the left-hand back contact of relay 1804, the lower contacts of cam 1800^N, conductor 1224, terminal 1219 and wiper 1218 of the district selector, the right-hand contacts of cam 1200^J, conductor 975, the lower right-hand and upper left-hand contacts of cam 900^N, conductor 974, the upper normal contact of key 1206 and the secondary winding of the repeating coil 1205 to ground. The relay 1807 becomes energized. Although the winding of the relay 1806 is connected in parallel with the winding of the relay 1807, the former does not become energized because of the shunt path existing through the armatures and back contacts of relays 1805 and 1806. The relay 1807 connects ground through its upper armature and front contact, wiper 1808, terminal 1809 of 120

115

120

125

130

the incoming selector, conductor 1814, the upper contacts of cam 1900^c, wiper 1912, and terminal 1913 of the final selector, the bell at the substation, terminal 1915 and 5 wiper 1914 of the final selector, contacts of cam 1900^h, conductor 1815, terminal 1811 and wiper 1810 of the incoming selector the lower armature and front contact of relay 1807, the lower contacts of sequence 10 switch cam 1800^c and the left-hand winding of relay 1805 to a superimposed ringing current source. The substation bell is rung but the relay 1805, which is marginal in operation, does not become energized until 15 the subscriber removes his receiver from the switchhook. When the relay 1805 becomes energized, it opens in its back contact the shunt closed around the winding of relay 1806, permitting the energization of this 20 relay. The relay 1806 closes in its front contact a shunt around the winding of relay 1807, whereupon the latter becomes deenergized. The relay 1806 locks up through its front contact and the above traced circuit. 25 Upon the removal of the receiver at the called station and the consequent deenergization of relay 1807, the calling supervisory relays 1803 and 1207 become energized in a well-known manner. The relay 30 1803 closes a circuit from ground through its armature and front contact, the winding of relay 1804, the right-hand contacts of cam 1800^c, the left-hand back contact and armature of relay 1835, the right-hand 35 back contact and armature of relay 1802 and the left-hand contacts of cam 1800^p to grounded battery. Relay 1804 becomes energized, but the relay 1806 is maintained in its energized condition by the substitution 40 of the ground at the repeating coil 1205 with ground connected to the armature of relay 1804. The relay 1207 closes a circuit from 45 sub-battery through its armature and front contact, the lower right-hand and upper left-hand contacts of cam 1200^c, conductor 990, the upper contacts of cam 900^p, conductor 991, and the power magnet of sequence switch 1200 to main battery for 50 moving this sequence switch out of position 14 and into position 16. The talking circuit is now established through the conductors indicated in heavy lines.

In position 16 of sequence switch 1200, a 55 circuit is closed from ground through the right-hand contacts of cam 1200^u, resistance 1216, and lamp 1217 to sub-battery. However, the lighting of this lamp is prevented due to the existence of a shunt path through resistance 1213, the lower contacts of cam 60 1200^c and the armature and front contact of relay 1207 to a sub-battery. Another circuit is closed from ground through resistance 1209, lamp 1211, conductor 982, the upper right-hand contact of cam 900^w and 65 the lower right-hand contact of cam 900^v

to sub-battery. This lamp is also shunted, the path extending through resistance 1213⁷, the front contact and armature of relay 1201, the upper left-hand contact of cam 1200^q and the lower left-hand contact of 70 cam 1200^p to sub-battery.

While the calling and called subscribers' lines are interconnected, the operator may 75 connect her telephone set to either subscriber's line to the exclusion of the other. First, she moves the sequence switch 900 into position 4 by actuating key 995^a, and then she actuates a splitting key 1204' arranged to operate contacts 1204 or contacts 80 1206. When the key 1204' is thrown so as to actuate contact 1206, it replaces the repeating coil circuit toward the called line with battery and ground, through resistances 1202 and 1202^a, whereby the operator is enabled to talk exclusively with the calling subscriber. When thrown so as to close the contacts 1204, it replaces the repeating coil circuit toward the calling subscriber with battery and ground connections, through the resistance coils 1202 and 1202^a, 85 and closes a circuit from main battery, through the winding of relay 1004, conductor 933, the right-hand contacts of cam 900^p, conductor 984, and the upper make contact of 1204 to sub-battery. The relay 1004 90 becomes energized and connects the operator's telephone set through its armatures and front contacts, the armatures and front contacts of relay 1004, the left-hand contacts of cams 900-O and M, conductors 976 95 and 974, with the called side of the connecting circuit, whereby the operator is enabled to talk exclusively with the called subscriber. 100

Disconnecting and call charging operations.

While the calling and called subscribers are talking, the sequence switches associated with the various selectors remain in the following positions: Sequence switch 300 in 110 position 14; 900 in position 4; 1200 in position 16; 1800 in position 15; and 1900 in position 16. The following relays are maintained energized: 102, 330, 909, 913, 915, 1201, 1207, 1801, 1803, 1804, 1806, 1901, 1906 and 115 the cutoff relay of the called line. Furthermore, the lamp 1229 is lighted.

When the subscribers are through talking, they restore their receivers to the switchhooks. As a result of the opening of the 120 line circuits, the relays 1803, 1207 and 1201 become deenergized. The relays 1201 and 1207, by releasing their armatures, remove the shunts from around the lamps 1211 and 1217, whereupon these lamps light up. The relay 1803 causes the deenergization of relay 1804, which in turn opens the locking circuit of relay 1806, whereupon the originally traced locking circuit for this relay is re-established. 125 130

When the lamps 1211 and 1217 light up, the operator depresses the charge disconnect key 999.

The actuation of this key causes the operation of the message register 103, associated with the calling line, and breaks down the connection between the calling and called lines. It may also cause the operation of a coin box at the subscriber's station, if the calling line is a coin box line, and break down the connection between such line and the called line. It may be also provided merely for the breaking down of the connection between the calling line and the called line, in case the calling line is neither equipped with a message register nor a coin box.

The following operations are performed upon the actuation of this key: Relay 910 is energized by current flowing from main battery through its winding, the left-hand contact of key 999, the left-hand back contact and armature of relay 914, the lower left-hand contact of cam 900^W and the lower right-hand contact of cam 900^V to sub-battery. Relay 910 closes a circuit from main battery through the winding of relay 995, the left-hand contacts of cam 900^H, the right-hand front contact and armature of relay 910, and the lower right-hand contacts of cams 900-W and V to sub-battery. The relay 995 becomes energized and opens the circuit including relays 102, 330 and 909. The relay 909 becomes deenergized, but the other two relays remain energized through the substitute path including the left-hand front contact and armature of relay 995, conductor 946, the left-hand back contacts of relays 1129 and 1142, and resistance 1143 to ground. The relay 909 closes a circuit from main battery through the lower winding of relay 905, the upper right-hand and lower left-hand contacts of cam 900^X, the right-hand back contact and armature of relay 909, and the normal contact of key 908 to sub-battery. Upon the deenergization of relay 909, a circuit is established for moving sequence switch 900 out of position 4 into position 7, if this sequence switch is in position 4 when the key 999 is operated. The power magnet of the sequence switch 900 will be energized from main battery through the magnet, the upper left-hand contact of cam 900^B, the left-hand back contact and armature of relay 909, the lower contact of cam 900^C, conductor 923, and the right-hand back contact and armature of relay 1014 to sub-battery. When the sequence switch 900 is in position 7, the locking circuit for relay 913 is broken at the left-hand front contact and armature of relay 909, but since the relay 910 has been operated as above described, the relay 913 will remain energized by a circuit from the main battery through its

winding, the left-hand lower contact and armature of relay 910 to sub-battery.

Message rate call.

If the call is initiated from a message rate station, then neither the relay 911 nor the relay 915 is energized. After the actuation of key 999, a circuit is closed from main battery, through the winding of relay 1142, conductor 935, the left-hand back contact and armature of relay 915, conductor 987, the lower contacts of cam 1200^L, conductor 989, the left-hand contacts of cam 900^P and the left-hand upper front contact and armature of relay 910, to sub-battery, for energizing relay 1142. This relay disconnects the ground applied through resistance 1143, the right-hand normal contacts of relay 1142, the normal contacts of relay 1129, conductor 946, the left-hand armature and alternate contact of relay 995, and the upper right-hand and lower left-hand contacts of cam 900^I to the sleeve conductor of the calling line and connects this conductor through its front contacts and armatures, the back contacts, armature and back contacts of relays 1144 and 1145, and the windings of relay 1154 to sub and main battery.

By current supplied from this main battery through the magnet of 103 to the calling line, the relay 1144 is energized by current flowing through a circuit from main battery through the register magnet 103 on the above described path, including the right-hand armature and front contact of relay 1142, the armature and back contact of relay 1145, the windings of relay 1144, the left-hand winding of relay 1154 to sub-battery. A parallel path to main battery around the register magnet 103 may be traced from the left-hand armature and front contact of relay 1142, and armature and back contact of relay 1144, the windings of relay 1145, the right-hand winding of relay 1154 to main battery. The relay 1145, being shunted by the register magnet 103, will not operate, but the relay 1144 will. The relay 1144 breaks the circuit of relay 1145 and short circuits the high resistance right-hand winding of relay 1144. The short-circuiting path may be traced from the left-hand front contact of relay 1142, the armature and front contact of relay 1144, thence through the low resistance left-hand winding of relay 1144, left-hand winding of relay 1154 to sub-battery. Sufficient current flows through this path for operating the register magnet 103. The operation of the register magnet 103 causes the left-hand winding of this magnet to be connected in multiple with the right-hand winding of the magnet through its front contact. This reduces the resistance of the circuit sufficiently to provide for the ener-

gization of relay 1154. The relay 1154 closes a circuit from sub-battery, its armature and front contact, the winding of the position register magnet 1171 to ground. This magnet registers the number of calls received by the operator. The magnet 1171 closes a circuit from ground, its armature and front contact, and the lamp 1172 to main battery. The lamp 1172 lights and indicates to the operator that the line register has operated. If the cutoff relay 102 and register magnet 103 of the calling line had been connected to sub-battery, then through the above described path, the relay 1145 would have operated since the relay 1144 would be included in the shunt path of the cutoff relay 102 and register magnet 103. The operation of relay 1145 provides for the shunting of its own high resistance left-hand winding, and includes the low resistance right-hand winding of this relay in the circuit for the right-hand winding of relay 1154 and the energization of the line register 103; then the relay 1154 would cause the lamp 1172 to be lighted as above described.

The operator will then release the charge disconnect key 999 which breaks the circuit for relays 910 and 995. The relay 910 causes the deenergization of relay 913. The relay 995 breaks the sleeve circuit, whereupon the cut-off relay 102 and line register magnet 103, if there be one, and the above mentioned relays shown in Fig. 11, are deenergized. The relay 995 also closes a circuit for moving the sequence switch 900 out of position 7 into position 8. This circuit extends from main battery through the power magnet of sequence switch 900, the upper left-hand contact of cam 900^B, the left-hand back contact and armature of relay 909, the lower right-hand and upper left-hand contacts of cam 900^C, the right-hand back contact and armature of relay 995 to sub-battery through the normally closed contacts of the disconnect key 908. The sequence switch 900 in position 8 now awaits the restoring of the sequence switch 1200 to position 1. The sequence switch 1200 is restored to position 1 through the agency of relay 1228. This is brought about by a circuit from main battery through the winding of relay 1228, left-hand contacts of 1200^F, conductor 978, the right-hand back contact and armature of relay 913, the upper contacts of cam 900^A and the normal contacts of key 908 to sub-battery.

Upon energization, relay 1228 closes a circuit from sub-battery, through its right-hand armature and front contact, the left-hand contacts of cam 1200^D and the power magnet of sequence switch 1200 to main battery. Under the control of this circuit, the sequence switch 1200 is moved out of position 16 and through position 17 into position 18. A circuit is now closed from

main battery, through the winding of release magnet 1227, the lower right-hand and upper left-hand contacts of cam 1200^D, and the right-hand front contact and armature of relay 1228 to sub-battery. The magnet 1227 becomes energized and causes the restoration of the wipers of this district selector. When the district selector reaches its normal position, a circuit is closed from sub-battery, through the commutator segment Y, the lower left-hand contact of cam 1200^B, the lower contact of cam 1200^A and the power magnet of sequence switch 1200 to main battery, for moving this sequence switch out of position 18 into position 1, whereupon the magnet 1227 and the relay 1228 become deenergized. When the sequence switch 1200 moves out of position 16, the relay 1806 becomes deenergized. When the sequence switch 1200 moves out of position 16₁, the relay 1801 becomes deenergized and brings about the restoration of the incoming selector (Fig. 18), as will be described below. When the sequence switch 1200 reaches position 1, a circuit is closed from main battery, through the winding of relay 334, the upper contacts of cam 300^V, the right-hand back contact and armature of relay 330, the left-hand contacts of cam 300^Q, commutator brush 324, wiper 320, terminal 316, conductor 904, the lower left-hand and upper right-hand contacts of cam 900^L, conductor 973, upper left-hand and lower right-hand contacts of cam 1200^S, resistance 1234, the left-hand contacts of cam 1200^V, conductor 971, the left-hand back contact and armature of relay 909, the lower right-hand and upper left-hand contacts of cam 900^C, the right-hand back contact and armature of relay 995 and the contact of key 908 to sub-battery. Relay 334 becomes energized and closes a circuit from sub-battery, through its armature and front contact and the power magnet of sequence switch 300 to main battery for moving this sequence switch out of position 14 and into position 15, whereupon the relay 334 becomes deenergized and opens the driving circuit of the sequence switch. From position 15, the sequence switch is driven into position 16 by a circuit extending from main battery, through its power magnet, the left-hand contact of cam 300^A, the lower contact of cam 300^C, the right-hand back contact and armature of relay 330, the right-hand contact of cam 300^X, the lower left-hand contact of cam 300^W, conducting segment M of the line finder, and the commutator brush of the line finder to sub-battery. A circuit is now closed from main battery, through the winding of downdrive magnet 329, the right-hand contacts of cam 300^Q, the commutator segment M of the connecting circuit selector, and the commutator brush of the connecting circuit selector to sub-battery.

Under the control of magnet 329, the line finder is caused to return to normal. When it reaches its normal position, it closes a circuit from sub-battery, through its commutator brush, commutator segment Y, the upper right-hand contact of cam 300^P, the lower left-hand contact of cam 300^A and the power magnet of sequence switch 300 to main battery for moving this sequence switch out of position 16 and into position 17. In position 17 of the sequence switch, a circuit is closed from main battery, through the winding of downdrive magnet 333, the left-hand contacts of cam 300^W, and the segment M of the line finder to sub-battery. Under the control of the magnet 333, the connecting circuit selector is caused to return to normal, and when it reaches its normal position, it closes a circuit from sub-battery through its commutator brush, and segment Y, the lower right-hand contact of cam 300^P, the upper left-hand contact of cam 300^A, and the winding of power magnet 300 to main battery for moving this sequence switch out of position 17 and into position 1, whereupon the magnet 333 becomes deenergized.

When the sequence switch 1200 reached position 1, a circuit was also established for moving the sequence switch 900 out of position 8 into position 1. This circuit may be traced from main battery through the winding of power magnet 900, the right-hand contacts of cam 900^M, conductor 972, the right-hand contacts of cam 1200^F to sub-battery. As the sequence switch 900 moves beyond position 9, the relay 905 is deenergized, a circuit for this relay having been maintained closed from main battery, through its lower winding, the upper right-hand and lower left-hand contacts of cam 900^X, the right-hand contact and armature of relay 909 to sub-battery at the normally closed contact of key 908, the circuit being broken at cam 900^X. By this time, the sequence switch 300 will have passed beyond position 14, so that when relay 905 deenergizes and restores the circuit from the terminals 313 and 314 of the connecting unit selector to the ground and main battery respectively from the repeating coil 1205, no false call will be originated (in the case of the coin box line) due to the operation of the relay 101 from ground at the repeating coil 1205.

The opening of the sleeve conductor 1226 at the upper right-hand contact of cam 1200° when the sequence switch 1200 leaves position 16₁, results in the deenergization of relay 1801. This relay closes a circuit from sub-battery through its right-hand armature and back contact, the upper left-hand contact of cam 1800^B, the lower contact of cam 1800^A and the power magnet of sequence switch 1800 to main battery, for moving this

sequence switch out of position 15 and through positions 16 and 17, into position 18. A circuit is now closed from main battery through the winding of downdrive magnet 1820, and the lower contacts of cam 1800^M to sub-battery. The magnet 1820 becomes energized and causes the restoration of the incoming selector. When the incoming selector reaches its normal position, a circuit is closed from sub-battery, through the commutator brush, the segment Y, the lower left-hand contact of cam 1800^P, the lower contact of cam 1800^A and the power magnet of sequence switch 1800 to main battery for moving this sequence switch out of position 18 and into position 1, whereupon the magnet 1820 becomes deenergized.

Upon the opening of the sleeve conductor 1816 when the sequence switch 1900 leaves position 16, the relay 1901 becomes deenergized and closes a circuit from sub-battery, through its left-hand armature and back contact, the upper left-hand contact of cam 1900^B, lower contact of cam 1900^A, and the power magnet of sequence switch 1900 to main battery, for moving this sequence switch out of position 16, through position 17 and into position 18, whereupon a circuit is closed from main battery, through the winding of downdrive magnet 1905, upper contacts of cam 1900^F to sub-battery. Under the control of the magnet 1905, the final selector is released to normal, and when it reaches its normal position, a circuit is closed from sub-battery, through the commutator brush, the commutator segment Y, the lower left-hand contact of cam 1900^B, the lower contact of cam 1900^A, and the power magnet of sequence switch 1900 to main battery, for moving this sequence switch out of position 18 and into position 1, whereupon the magnet 1905 becomes deenergized. When the sequence switch 1900 moves out of position 16, the relay 1906 becomes deenergized and the called line is rendered again selectable.

The apparatus used in establishing the connection is now restored to normal and may be utilized in setting up a new call.

Flat rate call.

If the call is initiated from a flat rate line, then the relay 915 is energized over a circuit traceable from main battery through the winding and normal right-hand contacts of this relay, the upper right-hand and lower left-hand contacts of cam 900^R, conductor 938, right-hand back contact and armature of relay 1167, and the right-hand front contact and armature of relay 1136 to sub-battery. In response to the actuation of key 999, a circuit is closed from main battery, through the winding of relay 1129, conductor 936, the left-hand front contact and armature of relay 915, conductor 987, the

lower contacts of cam 1200^L, conductor 989, the left-hand contacts of cam 900^P and the left-hand upper front contact and armature of relay 910 to sub-battery. The relay 1129 5 becomes energized, disconnects the path including relays 102 and 330 from ground at resistance 1143, and connects it through its front contact and armature and the winding of relay 1137 to ground. The relays 102 10 and 330 are maintained energized, and the relay 1137 becomes energized and closes a circuit for magnet 1171, and lights the lamp 1172 as above described. The disconnect operations are the same as above described.

15 *Coin box station call.*

If the calling party initiates a call from a coin box station, which fact is indicated by the energization of relay 911 through the 20 right-hand contacts of cam 900^K, conductor 945, left-hand front contact and armature of relay 1168, right-hand front contact and armature of relay 1136 to sub-battery, under the control of the class-of-service indicator 25 in the above-described manner, then the relay 1109 is energized by current flowing through a circuit which may be traced from main battery through the winding of this relay, conductor 947, the right-hand front contact and armature of relay 911, the right-hand contact of key 999, the right-hand front contact and armature of relay 995, and the normal contact of key 908 to sub-battery. Relay 1109 becomes energized and connects 30 a positive high voltage current source through a resistance lamp 1123, the winding of a relay 1120, the right-hand armature and front contact of relay 1109, conductor 1101, conductor 934, the right-hand contacts of cam 900^T, right-hand armature and back contact of relay 907, the upper 35 front contact and armature of relay 905, and then through the connecting circuit selector and the line finder to the coin collect magnet conventionally shown in Fig. 8 at the prepayment box to ground. The relay 1120 causes the lighting of the lamp 1122, indicating to the operator that the coin has 40 been collected. The disconnect operations 45 are the same as above described.

In view of the fact that in accordance with general practice in coin boxes, sluggish releasing relays are used in order not to allow a false call to be started when using a 50 charge-disconnect key on a coin box line, the opening of the sleeve circuit of the calling line is slightly delayed after the key 999 is released. This is accomplished by holding the relay 995 energized through a circuit extending from main battery, through the winding of this relay, the left-hand contacts of cam 900^H, the right-hand front contact and armature of relay 910, the left-hand contacts of cam 900^Y, conductor 937, and the 55 right-hand front contact and armature of

relay 1170 to sub-battery. The relay 1170 is energized upon the energization of relay 1109, and a locking circuit is established in series with the winding of relay 1153 through its left-hand front contact and armature, and the back contact and armature of the sluggish releasing relay 1169. The relay 1153 will not energize until the relay 1109 is deenergized due to the opening of the key contacts 999. When this happens, relay 1153 closes a circuit for energizing a sluggish relay 1152, which in turn causes the energization of a sluggish relay 1169. In view of the fact that relays 1152 and 1169 are sluggish to operate, a short period of time 70 will elapse before the relay 1170 becomes deenergized, and permits in turn the deenergization of relay 995.

The charging of the calling line may be controlled also in position 4 of sequence switch 900 without severing the connection. By actuating key 1005, a circuit is closed from main battery through the windings of relays 1001 and 1014 in parallel, the left-hand contact of key 1005, the right-hand back contact and armature of relay 1008, conductor 940 and the right-hand contacts of cam 900^V to sub-battery. The relays 1001 and 1014 become energized. The relay 1001 connects, through its right-hand armature and front contact, conductor 1101, and the right-hand front contact and armature of relay 1109, the winding of relay 1120 and resistance lamp 1123, the high-voltage positive current source to the tip side of the line, to cause the collection of a coin, if a call has 85 been initiated from a pay-station. The relay 1014 connects through its left-hand armature and front contact and conductor 946 the register circuit to the sleeve of the line, so as to actuate the register, if the call has 90 been initiated from a message rate line.

If the calling line has a coin box, the relay 911 being energized, the relay 1109 is energized in a circuit from sub-battery, right-hand armature and front contact of relay 1014, conductor 928, right-hand contacts of cam 900^Y, and thence to the circuit including the right-hand contacts of relay 911 as above 95 described. The energization of relay 911 causes the completion of the above-traced coin-collect circuit. Also, if the district sequence switch 1200 is in position 16, the relay 1129 becomes energized from sub-battery, right-hand armature and back contact of relay 1017', key contacts 1005, conductor 941, left-hand contacts of cam 900^T, conductor 989, lower contacts of cam 1200^L, conductor 987, left-hand armature and front contact of relay 915, conductor 936, and winding of relay 1129 to main battery. Relay 1129 closes a circuit to operate, under the control of the magnet 1171, the position register.

If the calling line is a message rate line, 100 the relay 915 being deenergized, and the dis-

trict sequence switch 1200 is in position 16, then, in the above-described manner, the relay 1142 is energized and causes the completion of the metering circuit.

- 5 A connection may be severed also under the control of the individual disconnect key 908 with the listening sequence switch 900 in either position 4 or in position 7, and with the district sequence switch 1200 in 70 any position other than 11. On local calls, such as has been described, the key 908 is effective to break down a connection in position 11 of the sequence switch 1200, after the sender has fully performed its function.
- 15 Upon the actuation of this key, a circuit is closed from sub-battery through its make contact and the upper winding of relay 905 to main battery, for energizing this relay. Upon the opening of the normal contact of 75 key 908, the relay 913 becomes deenergized and causes in turn the deenergization of relays 909, 330 and 102. If the listening sequence switch is in position 4, then, upon the deenergization of relay 909, it is moved into 80 position 7 under the control of a circuit extending from main battery, through the power magnet of sequence switch 900, the upper left-hand contact of cam 900^B, the left-hand contact and armature of relay 909, the lower contacts of cam 900^C, conductor 85 923, and the right-hand back contact and armature of relay 1014 to sub-battery.
- 20 90
- 25 95
- 30 100
- 35 105
- 40 110
- 45 115

When the key 908 is released, a circuit is closed from sub-battery, through the normal contact of this key, the right-hand armature and back contact of relay 995, the upper left-hand and lower right-hand contacts of cam 900^C, the left-hand armature and back contact of relay 909, the upper left-hand contact of cam 900^B, and the power magnet of sequence switch 900 to main battery, for moving it out of position 7 into position 8. From this point on the disconnection of both the calling and called subscribers takes place in 120 the above-described manner.

50 After the restoration of either the disconnect key 908 or the disconnect charge key 999, the relay 905 is maintained energized by the previously traced circuit, including the upper right-hand and lower left-hand contacts of cam 900^X, the right-hand back contact and armature of relay 909, and the normal contact of disconnect key 908, until the listening switch 900 moves beyond position 55 9 and opens the upper right-hand contact of cam 900^X. To prevent the relay 905 from becoming deenergized when its energizing circuit is switched from its upper to its lower winding, the key 908 is provided with continuity contacts. This is done to prevent, in the case of a coin box line, the starting of a false call from the tip side of the district circuit.

60 65 Key 1007 common to an operator's position is a further means for controlling dis-

connection. This key is effective in position 4 of the sequence switch 900. Upon the actuation of this key, a circuit is closed from sub-battery, through the right-hand armature and back contact of relay 1017', the contact of key 1007, conductor 948, the upper left-hand and lower right-hand contacts of cam 900^X, conductor 978, the left-hand contacts of cam 1200^F, and the winding of relay 1228 to main battery. The relay 1228 70 75 becomes energized and locks up, causing the disconnection of the called end of the connection at any stage of the selection. This is accomplished by moving the sequence switch 1200 into position 8 out of any position it may be in, between 2 and 7, under the control of a circuit extending from sub-battery, through the right-hand armature and front contact of relay 1228, the left-hand contacts of cam 1200^D, and the power 80 85 magnet of the sequence switch 1200 to main battery, the relay 1228 locking up through a circuit including its left-hand armature and front contact and the left-hand contacts of cam 1200^F. Connected in parallel with this locking circuit is the winding of relay 1214 which becomes energized through its winding and left-hand contacts of cam 1200^F and opens the circuit including the calling supervisory relays, should these relays be energized. In position 8 of sequence switch 1200, the magnet 1227 is energized and causes the restoration of the district selector, whereupon the circuit through the Y segment is closed and the sequence switch is moved into position 1. 90 95

If the key 1007 is depressed while sequence switch 1200 is in positions 8 or 10, then the circuit of magnet 1227 is immediately closed and restoration follows. If the key is depressed in positions 9 or 11 to 17, then the relay 1228 closes the above-traced circuit including the left-hand contacts of cam D for moving the sequence switch 1200 into position 10 or 18, whereupon the district selector is restored to normal.

Reverting call.

If the calling station is associated with the same line with which the called station is associated, that is to say, if the call is a reverting party line call, then upon the energization of the relay 1410, the windings of the relay 1411 are connected through the district, incoming and final selector to a terminal, like 1917, which in this case is connected in multiple with terminal 192 of the calling line, whereby the relay will be unbalanced and does not operate. For this reason, when the sender sequence switch 1400 reaches position 13₁, the relay 1412 becomes energized and locks up through its right-hand front contact and armature. For this reason, when the sender sequence switch 1400 reaches position 15, it will find no circuit for driving it out of 120 125 130

that position, the right-hand back contact of relay 1412 being open. This relay closes also a circuit from ground, through interrupter 1413, the left-hand armature and 5 front contact of relay 1412, conductor 1384, the lower contacts of cam 1300^X, wiper 1309, and terminal 1303 of the cord finder, conductor 1241, the right-hand contacts of cam 1200^N, resistance 1216, and lamp 1217 to sub- 10 battery. Under the control of the interrupter 1413, the lamp 1217 is caused to flash. As above described, as soon as the sender sequence switch 1400 reaches position 14, the relay 1235 becomes again energized. This 15 relay closes a circuit from grounded battery, through its left-hand armature and front contact, resistance 1242, lamp 1231, the right-hand contact of cam 1200^H, and interrupter 1236 to ground, for causing the 20 flashing of lamp 1231. The operator, upon observing the flashing signals of lamps 1231 and 1217, will know that the call is for a party on the same line with the calling party.

The operator may then actuate key contacts 995^a and cause sequence switch 900 to be moved into position 4, in a manner to be subsequently described. The operator actuates key contacts 1007 whereupon a circuit is closed from sub-battery, through the right- 25 armature and back contact of relay 1017, contacts of key 1007, conductor 948, the upper left-hand and lower right-hand contacts of cam 900^X, conductor 978, the left contacts of cam 1200^F, and the winding of relay 1228 30 to main battery. Relay 1228 becomes energized and closes a locking circuit for itself from sub-battery through its left-hand armature and front contact, the left-hand contacts of cam 1200^F, and the winding of relay 40 1228 to main battery. A circuit is now closed from sub-battery through the right-hand armature and front contact of relay 1228, conductor 986, the right-hand back contact and armature of relay 914, conductor 45 985, the upper right-hand and lower left-hand contacts of cam 1200^T, the left-hand armature and front contact of relay 1232, energized as previously described, the left- 50 hand contacts of cam 1200^E and the power magnet of sequence switch 1200 to main battery. The sequence switch 1200 moves out of position 11 into position 17 under the control of a circuit which is closed in 55 position 12 of the sequence switch 1200 from sub-battery through the right-hand armature and front contact of relay 1228, the left contacts of cam 1200^D and the power magnet of sequence switch 1200 to main battery. In position 18 of the sequence switch 1200, the down drive magnet 1227 is energized from main battery through its winding, the lower right-hand and upper 60 left-hand contacts of cam 1200^D, and the

right front contact and armature of relay 1228 to sub-battery. The district selector is restored to its normal position when the sequence switch 1200 is moved to position 1, the circuit extending from main battery through the power magnet 1200, the lower contact of the cam A and the lower left-hand contact of cam B to sub-battery, through the commutator segment Y. Having moved to position 1, sequence switch 1200 will be immediately moved into position 2 and a new sender attached thereto under the control of the circuits closed as previously described.

When the sequence switch 1200 moved out of position 11, the circuit including the relays 1235 and 1399 was broken at the left-hand contacts of cam 1200^P. The relay 1399 closes a circuit for moving sequence switch 1300 to position 17 from main battery through the power magnet of sequence switch 1300, the left-hand contacts of cams 1300-A and C, the right-hand back contact and armature of relay 1399 to sub-battery. Sequence switch 1300 moves to position 17 and closes a circuit for moving sequence switch 1400 out of position 15 from main battery through the power magnet of sequence switch 1400, the lower contacts of cam 1400^P, conductor 1347, the upper right-hand and lower left-hand contacts of cam 1300^F, and the right-hand back contact of armature and relay 1399 to sub-battery. The cord finder is then restored to its normal position, sequence switch 1300 moved to position 18, and sequence switch 1400 moved to position 1, through the agency of circuits previously described.

The operator will then request the calling subscriber to hang up his receiver in order that the bell of the desired party may be rung. To ring this bell the operator closes key contacts 1010, 1011, 1012 or 1013 depending upon the character of the ringing current required. The circuits closed by any of these keys may be traced from the bell to the keys as above described, through the left-hand back contacts of relays 1016 or 1017, if key contacts 1012 or 1013 are closed, or if key contacts 1010 or 1011 are closed, through the resistance lamps 1023 or 1024, to positive or negative current supply and to ground.

The operator will then actuate the recording keys which are at this time connected to the new sender, such number being designated for use in completing reverting calls. The line terminals 1913 and 1915 of the line selected by the final selector are connected together through the resistance of the called 120 substation so as to effect the energization of the ringing current relay 1805 and the energization of the relays 1207 and 1803 in the

manner above described. The lamp 1217 is extinguished by the energization of relay 1207 which establishes a shunt path through resistance 1213, the lower contacts of cam 5 1200^c, and the armature and front contact of relay 1207 to sub-battery. Sequence switch 900 will be moved to position 7 and the operator's position apparatus disconnected from the connecting unit.

10 *Holdinga.*

If the operator desired to hold the connection between a connecting circuit and a calling line, and at the same time free the calling line for incoming and outgoing traffic, she depresses an individual holding key 912, which locks mechanically in its actuated position. This key is effective with the listening switch 900 in position 4, the listening-in-position. When this key is operated, the following circuits are closed: from sub-battery, through the left-hand contact of key 912, and the lower winding of relay 905 to main battery; from sub-battery, through the right-hand contact of key 912 and the windings of the relays 914 and 907, in parallel, to main battery; and from sub-battery through the left-hand contacts of key 912, the right-hand contacts of cam 900^s, conductor 944, and the windings of the relays 1008, 1017' and 1018, in parallel to main battery. The relays included in the above circuits become energized. The locking circuit of relay 913, including the right-hand front contact and armature of relay 909, remains closed, and relay 913 remains energized, because when the circuit of relay 909 is opened in the left-hand back contact of relay 907, a new circuit is established for the former as soon as the left-hand armature of relay 907 contacts with the front contact. The disconnect key 908 is now ineffective because relays 913 and 909 are energized independent of the sub-battery connection controlled by the disconnect key 908. If the disconnect key is actuated and removes the sub-battery from the locking circuit of relay 913, then this relay would be maintained energized by a circuit extending from main battery through its winding, the left-hand front contact and armature of relay 914, the lower left-hand contact of cam 900^w and the lower right-hand contact of cam 900^v to sub-battery. The charge disconnect key 999 is also ineffective because of the energized condition of relay 914, which in its left-hand back contact breaks the sub-battery connection between this key and the lower right-hand contact of sequence switch cam 900^w.

The relay 905 opens the talking circuit to the calling subscriber's line. The relay 907 opens the sleeve circuit towards the calling subscriber's line and allows thus the

deenergization of the relays 330 and 102, 65
whereupon the calling line will test idle.
However, the line finder is not restored to
normal upon the deenergization of relay
330, because the circuit of relay 334 is main-
tained open in the upper right-hand con-
tact of cam 900^L and the left-hand back
contact of relay 1008. If the sequence
switch 900 is in position 7 and the sequence
switch 1200 in position 1, the above circuit
for operating relay 334 is maintained open
at the back contact of relay 909. The oper-
ator will now listen-out and cause the se-
quence switch 900 to move to position 7. 70
75

When the operator wishes to obtain connection with the subscriber's line held in the above-described manner, she will listen-in and cause the sequence switch 900 to move to position 4. The relays 1008, 1017' and 1018 will again energize as above described. The relay 1017' closes a circuit from ground, through the high resistance right-hand winding of relay 1022, the left-hand front contact and armature of relay 1017', the left-hand back contact of relay 1014, conductor 918, the lower contacts of sequence switch cam 900', conductor 903 and then through the sleeve circuit to main battery at the calling substation. If the subscriber's line is busy, due to the fact that a new call has been initiated therefrom or the line has been seized by a connector, then the relay 1022, which is marginal in operation, will not become energized. For this reason, a circuit is closed from sub-battery, through the right-hand armature and front contact of relay 1017', the right-hand armature and back contact of relay 1022, and the winding of relay 1019 to main battery. The relay 1019 becomes energized and closes a circuit from ground, through its right-hand front contact and armature, the right-hand back contact and armature of relay 1004, the operator's telephone set, the left-hand armature and back contact of relay 1004, the left-hand armature and front contact of relay 1019, the left-hand armature and front contact of relay 1018 to a "busy tone" machine, whereby the operator will be informed that the calling line is busy, and she should not attempt to seize it again through the connecting circuit that is being held. If, however, the line is idle, then the relay 1022 becomes energized and locks up through its left-hand armature, front contact and left-hand winding. In view of the energized condition of relay 1022, the relay 1019 does not become energized and thus no busy tone will be connected to the operator's head set. The operator now, by releasing the holding key 912, may permit the deenergization of the relays that were operated upon the actuation of this key, whereupon the line is again made busy.

Attempted connection to a busy line.

If the called line is busy, then, as above stated, the electrical potential applied to its test terminal is reduced, and the relay 1907 does not become energized. In view of the deenergized condition of relay 1907, as soon as the sequence switch 1900 reaches position 12, a circuit is closed from ground, through the upper contacts of cam 1900^K, and the left-hand winding of relay 1908, to grounded battery, and another circuit from ground, through the right-hand armature and back contact of relay 1906, the upper armature and back contact of relay 1907, the right-hand winding of relay 1908, the upper right-hand contact of cam 1900^B, wiper 1916, terminal 1917, and the cutoff relay of the called line to the minus pole of grounded battery. The relay 1908 is electrically polarized, and will become energized if its right-hand winding is connected to the negative pole of grounded battery. For this reason, in position 12, the relay 1902 becomes deenergized, and as soon as the sequence switch reaches position 13, it will be driven into position 15 by the above-traced circuit. The sequence switch will remain in position 15 because the driving circuit, by means of which it may be moved out of this position, is opened in the lower front contact of relay 1907. In position 15 a circuit is closed from main battery, through the winding of magnet 1905, the lower contacts of cam 1900^F, the lower back contact and armature of relay 1907, and the left-hand back contact and armature of relay 1906 to sub-battery. The magnet 1905 becomes energized and causes the restoration of the final selector. When the selector reaches its normal position and the commutator brush engages the Y segment, sub-battery is connected through this segment, the lower left-hand contact of cam 1900^B and the power magnet of sequence switch 1900 to main battery, whereupon the sequence switch 1900 is moved out of position 15, and through position 16 into position 17. In position 17 of the sequence switch, ground is connected through an interrupter 1909, the upper contacts of cam 1900^M, conductor 1815, terminal 1811, wiper 1810, the lower armature and back contact of relay 1807, the winding of supervisory relay 1803, the right-hand contacts of cam 1800^H, conductor 1225, terminal 1221, wiper 1220, the lower right-hand and upper left-hand contacts of cam 1200^K, the left-hand armature and back contact of relay 1214, the winding of relay 1207, the lower make contacts of key springs 1206, and the secondary winding of the repeating coil 1205 to main battery. The supervisory relays 1207 and 1803 are caused to vibrate their armatures, and under the control of the relay 1207, the supervisory lamp 1217 is caused to flash, indicating to the operator

that the line is busy. She then proceeds to sever the connection in the same manner as above described. 65

Overflow.

If the line finder is not stopped in its upward travel by the engagement of its wipers with the terminals of the calling line and moves until its commutator brush engages the overflow segment Z, then a circuit is closed from main battery, through resistance 332, the winding of relay 331, the lower contacts of cam 300^V, commutator brush 312, the right-hand back contact, armature and winding of relay 390 to sub-battery. Relay 331 by attracting its armature, opens in its right-hand back contact the locking circuit of relay 330, which in turn opens the circuit of magnet 328, whereupon the line finder is arrested in its upward movement. A circuit is then closed from main battery, through the power magnet of sequence switch 300, the lower right-hand contact of cam 300^C, the right-hand back contact and armature of relay 330, the upper left-hand and lower right-hand contact of cam 300^Q, segment M 80 and the commutator brush of the connecting circuit selector to sub-battery. The sequence switch 300 is moved out of position 4 and into position 6. The relay 331 becomes deenergized, whereupon a circuit is closed from main battery, through the right-hand winding of relay 330, the upper right-hand and lower left-hand contacts of cam 300^M, conductor 505, the left-hand back contact and armature of relays 510 and 511 to sub-battery. The relay 330 becomes energized, locks up and closes a circuit from sub-battery, through the commutator brush and the segment M of the connecting circuit selector, the lower right-hand and upper left-hand contacts of cam 300^Q, the right-hand armature and front contact of relay 330, the upper right-hand contact of cam 300^C, the left-hand contact of cam 300^A, and the power magnet of sequence switch 300 to main battery, for moving this sequence switch out of position 6 into position 7, from which position it is immediately driven through positions 8, 9, 14 and 15, into position 16, under the control of a circuit extending from sub-battery, through the commutator brush and the segment Z of the line finder, the upper left-hand contact of cam 300^B and the power magnet of sequence switch 300 to main battery. In position 16, the line finder return magnet 329 is energized and causes the release of the line finder to normal, whereupon the circuit through the Y segment of the line finder is closed for driving the sequence switch out of position 16 and into position 17, from which position it is driven into position 1 by the circuit closed through the Y segment of the connecting circuit selector. 100 105 110 115 120 125

- If the line finder is not functioning properly, so as to be stopped at the overflow terminals and be restored to its normal condition as above described, a commutator segment X will be closed when the line finder brushes have passed beyond the overflow terminals, and a signal will be given substantially as described in my Letters Patent No. 1,304,641, granted in May 27, 1919.
- If the connecting circuit selector moves to an overflow position and engages with its commutator brush the segment X, then a circuit is closed from sub-battery, through the commutator brush and the segment X of the connecting circuit selector, the left-hand contacts of cam 300^U and the power magnet of sequence switch 300 to main battery, for driving this sequence switch out of position 9 and into position 15. From this position the sequence switch is moved to position 16, under the control of a circuit extending from main battery, through the power magnet of sequence switch 300, the lower right-hand contact and cam 300^C, the right-hand back contact and armature of relay 330, the upper right-hand contact of cam 300^X, the lower left-hand contact of cam 300^W, and the M segment of the line finder to sub-battery.
- In the district incoming selectors, there is a Z segment provided at the end of each group. If these selectors do not find an idle trunk in a selected group, then they are restored to normal. The district selector is returned to normal in the following manner: The relay 1233 becomes deenergized because of its locking circuit being interrupted at the test wiper 1222. This relay then closes a circuit from sub-battery through the left-hand armature and back contact of relay 1228, the lower contacts of cam 1200^T, the right-hand armature and back contact of relay 1233, the upper left-hand contact of cam 1200^B, the lower contact of cam 1200^A, and the power magnet of sequence switch 1200 to main battery for moving this sequence switch out of position 7 and into position 8. The relay 1232 becomes now energized in the above-described manner, and causes the movement of the sequence switch out of position 8 and into position 9, from which position it is driven into position 10 by a circuit closed through the commutator segment Z and the lower right-hand contact of cam 1200^C. The relay 1232 is now de-energized and closes through its left-hand back contact a circuit for moving the sequence switch out of position 10 and into position 11, from which position the sequence switch is driven into position 17 through the circuit including the commutator segment Z and the lower right-hand contact of cam C. In position 17 a circuit is closed from ground, through interrupter 1236, the lower contact of cam 1200^H, resistance 1216, lamp 1217 to sub-battery, whereupon this lamp is caused to flash, which signal indicates to the operator that the switch, moved to an overflow terminal. By depressing her disconnect key, she causes the energization of relay 1228, which in turn causes the movement of the sequence switch out of position 17 into position 18 through the left-hand contacts of cam 1200^D, whereupon the district selector is restored to normal.
- If the incoming selector moves to an overflow position, then the relay 1835 becomes deenergized because of its locking circuit through the lower contacts of cam 1800^J being opened at test terminal 1813 and closes a circuit from main battery, through the power magnet of sequence switch 1800, the upper left-hand and lower right-hand contacts of cam 1800^C, the left-hand back contact and armature of relay 1835, the right-hand back contact and armature of relay 1802, and the lower contacts of cam 1800^P to sub-battery for moving this sequence switch out of position 6 and into position 7. Relay 1802 is then energized through the upper left-hand contacts of cams 1800-F and G and moves the sequence switch out of position 7 and into position 8, whereupon the relay 1802 becomes deenergized and moves the sequence switch out of position 8 and into position 9. The relay 1802 now again becomes energized under the control of the sender, and moves the sequence switch out of position 9 and into position 10, and upon its deenergization, out of position 10 and into position 11. The relay 1802 is again energized under the control of the sender and moves the sequence switch 1800 out of position 11 into position 12. It then becomes deenergized and moves the sequence switch out of position 12 into position 13, and then, upon the subsequent energization of relay 1802, the sequence switch is driven out of position 13 into position 14. From position 14 the sequence switch is driven through position 16 into position 17 by a circuit closed through the segment Z and the upper right-hand contact of cam 1800^B. In position 17, an interrupter 1823 is connected through the lower left-hand and upper right-hand contacts of cam 1800^H, to the winding of relay 1207, and causes through the agency of this relay, the flashing of lamp 1217, indicating to the operator that a selector reached an overflow segment. The operator will cause then the restoration of the switches in the above-described manner.

Private branch exchange hunting.

If the called line is one of a plurality of lines, such as lines leading to a private branch exchange, then under the control of the relay 1908, the final selector switch is caused to hunt over these lines subsequent to

the sending of the units impulses for the purpose of seizing an idle line. Private branch exchange lines are distinguished from direct lines by this, that except in the 5 case of the last private branch exchange line in the series, positive or sub-battery rather than negative or main battery is connected to the test terminals of such lines. Assuming that the first private branch exchange 10 line encountered by the final selector is busy, the test relay 1907 remains deenergized while the sequence switch 1900 is moved from position 7 to position 13. In positions 12 to 13 of the sequence switch, a circuit is closed 15 from ground, through the upper contacts of cam 1900^K, and the left-hand winding of relay 1908 to sub-battery. At the same time a circuit is closed from sub-battery, through the winding of the cutoff relay of the called 20 line, test terminal 1917, wiper 1916, upper right-hand contact of cam 1900^L, the right-hand winding of relay 1908, the upper back contact and armature of relay 1907, and the right-hand back contact and armature of 25 relay 1906 to ground. Due to the direction of the current flowing through the right-hand winding of relay 1908, this relay does not become energized, and for this reason the circuit, including the windings of relay 1902 30 and contacts of cams F and G, is maintained closed until the sequence switch moves out of position 13. For this reason, when the sequence switch reaches position 13, a circuit 35 is closed from main battery, through the winding of magnet 1903, the upper right- and lower left-hand contacts of cam 1900^E, the right-hand front contact and armature of relay 1902, and the right-hand contacts of cam 1900^J to sub-battery. The magnet 40 1903 becomes again energized, and causes the further travel of the final selector in an upward direction. As soon, however, as the test wiper of the selector engages the terminal of an idle line, the test relay 1907 becomes 45 energized and opens in its upper back contact the circuit including the right-hand winding of relay 1908, whereupon this relay becomes energized under the influence of its left-hand winding, and opens the circuit of relay 1902, which in turn causes the deenergization of magnet 1903. Furthermore, 50 relay 1902 closes a circuit from sub-battery, through its left-hand armature and back contact, the lower contacts of cam 1900^C and the power magnet of sequence switch 1900, for driving this sequence switch out of position 55 13 and into position 15, from which position the sequence switch is driven into position 16 by a circuit including the left-hand contacts of cam 1900° and the lower front contact and armature of relay 1907.

Party line ringing.

Depending whether the sequence switch 60 1800 is in position 15 or in position 16, posi-

tive or negative superimposed ringing current is applied to the called line. In the previously assumed case, the sequence switch 1800 was arrested in position 15 for ringing the line. If however the selection of 70 a party, the bell of which may be rung by negative superimposed current in position 16 of the sequence switch, is desired, then the incoming selector is caused to move with its wipers to the second or fourth groups of 75 contacts in which terminate trunks leading to final selectors through which access may be had to party lines, the bells of which will be actuated by such ringing current. In view of the fact that while the wipers of the 80 incoming selector are hunting within the second and fourth groups, the commutator brush engages the segment P; when the sequence switch 1800 reaches position 14 and until it moves out of position 15₁, sub-battery 85 is connected through the commutator segment P, the upper right-hand and lower left-hand contacts of cam 1800^J and the right-hand winding of relay 1835 to main battery. The relay 1835 is energized and 90 closes a circuit from main battery through the power magnet of sequence switch 1800, the lower right-hand contacts of cams 1800-A and B, the right-hand front contact and armature of relay 1835 and the upper contacts of sequence switch cam 1800^K to sub-battery, whereby the sequence switch is 95 moved into position 16.

As above stated, the party line stations are divided into two groups, one of which is 100 provided with bells responding to positive and the other with bells responding to negative superimposed ringing current. Each of these groups is further divided into two groups, one arranged to be signaled when 105 the ringing current source is connected to the tip and the other when the ringing current source is connected to the ring side of the line. Each party line is represented by four sets of terminals in the final selectors 110 which are connected in such a manner that when a final selector serves a group including a certain two of these sets of terminals, the negative ringing current source is connected to the tip or ring, depending on how 115 the terminals are connected to the line. The other two sets of terminals, (individual to the stations to be signaled by means of positive ringing current, are provided in a similar manner in the terminal bank of another 120 group of final selectors connected to the first or third group of the incoming selectors.

Function of the group circuit.

Each group circuit serving a group of 125 fifty subscriber lines as above described, comprises two relays 104 and 105. These relays located in the group circuits serving the 400 lines which are connected to any one line finder frame, are so interrelated as to pre- 130

vent the simultaneous operation of more than two trip magnets, 106 and 106^a, associated with the multiple bank containing the terminals of the 50 lines of the group. The 5 relay 104 energizes upon the initiation of the call and closes the energizing circuit for relay 105. The back contacts and armatures of relays 104 in the various group circuits are connected in series and obtain sub-battery for 10 energizing the relays 105 of the various group circuits through the right-hand back contact of relay 200 and the above traced circuit to the right-hand back contact of relay 202 of the starting circuit. Therefore, 15 if more than one of the relays 104 in the different group circuits are operated at a time, there is a definite preference as to which one of the associated relays 105 will be operated. The right-hand back contacts 20 and armatures of relays 105 are also connected in series and obtain sub-battery through the right-hand back contact of relay 202 and the winding of relay 200 of the starting circuit. When any relay 105 of the 25 associated group circuits is operated and closes the circuit including its right-hand locking winding, the relay 200 of the starting circuit is energized as above described, and this relay opens in its right-hand back 30 contact the energizing circuit extending to the relays 104. Therefore, when a certain relay 104 causes the operation of its associated relay 105, the relay 200 energizes and removes the energizing circuit for the relay 35 105. The relays 105 of other group circuits cannot then be energized, even though the preference may be indicated by the location of the contacts of its associated relay 104 in the series. It is therefore by the means of 40 the series inter-locking circuits, that but one of the relays 105, and consequently the associated trip magnets 106 and 106^a, can be operated at any one time.

As above described, the start circuit is released from electrical connection with the 45 finder circuit which has been started as soon as the brushes are fully tripped, this circuit being controlled by the commutator segment K of the line finder. It is obvious that 50 if the circuit which originally caused the relay 104 to be energized were maintained, other line finders would be started under action of this same relay 104, and this would continue until the particular line which initiated the call had been seized by the line 55 finder, whereupon the associated cutoff relay 102 operates and causes the deenergization of line relay 101. The purpose of the sequence switch associated with the group 60 circuit and the group circuit relays 104 and 105 is to prevent this unnecessary subsequent starting of line finders after the first line finder has been started. It will be noted that the energizing circuit for the relay 104 65 is led through cams 100^c. This circuit is

broken when the sequence switch 100 has passed beyond position 1 $\frac{1}{2}$ and is not closed until the sequence switch again closes its cam in position 18 $\frac{1}{4}$. The time required for moving the sequence switch 100 from positions 1 $\frac{1}{2}$ to 18 $\frac{1}{4}$ is sufficiently long to permit a line finder having been started to make connection with the topmost line terminals of the multiple bank, to seize that line and to make it busy by causing the operation of the 70 cutoff relay associated therewith. 75

Functions of the two group starting circuit.

In the progress of the call above-described, it was shown how upon the energization of 80 relay 200 the idle line finder of the preferred side was caused to seize the calling line. The relay 200 closes a circuit from sub-battery, through the right-hand back contact of relay 202, the right-hand back contact of 85 relay 201, the right-hand front contact of relay 200 and the left-hand back contact of relay 204, normally closed key contacts 280^e and 240^g, conductor 252 and thus through to the finder circuit as above described. If the 90 relay 204 was energized, this circuit would be led through the left-hand armature of the front contact of relay 204, the key contacts 280^h and 240^f to the conductor 253, and thus 95 to finder circuits similarly described above but on the opposite side of the finder frame. It will now be shown how upon the energization of certain of the relays 263, 264 and 265, or 243, 244 and 245, the relay 204 for connecting the right-hand front contact of relay 200 either to lead 252 for the preferred side of the frame and to lead 253 for the second choice or alternative side of the frame 100 is controlled. With the keys 240, 270, 280 and 290 in the normal positions as shown in Figure 2, the operation of any of the relays 263, 264 and 265 will cause the energization of relay 236. The relay 265, closes the circuit from the ground, through its left-hand armature and front contact, winding of relay 263 to main battery. The energization of either relay 263 or relay 264 results in the closure of a circuit from ground at the right-hand armature at either of the relays, 105 the winding of relay 236 to main battery. The relay 236 closes a circuit from ground, through the normally closed key contact 240^m, the right-hand armature and front contact of relay 236, the normally closed key contact 270ⁿ, and the winding of relay 223 to 110 main battery. The condition is now established for causing the operation of relay 204. 115

In order that the line will not be seized by more than one line finder and in order to prevent other confusion in the operation 120 of the line finders as might result in more than one starting at a time, it is necessary to control the relay 204 so that if the starting circuit is energized in the act of starting 125 a line finder on the preferred side of the 130

frame, such action will continue until the line finder has been fully started and the starting circuit released by the closure of segment K of the line finder which was 5 started as above described. On the other hand, if as will be shown below, the relay 204 has already been energized and the starting circuit is engaged in the act of starting a line finder, that line finder must 10 be fully started, and the starting circuit released under action of segment K of this line finder, before the relay 204 is permitted to deenergize. In other words, it may be said that the relay 204 is, through the action of 15 the circuits about to be described, interlocked with the finder circuit in such a way that it can neither be energized nor deenergized so long as the starting circuit is in the act of starting a line finder. Thus by this locking-in of the relay 204, but one line finder 20 can be started at a time, even if there are two finder sequence switches such as 300, one on each side of the frame, in position 2.

The relay 223 closes a circuit from sub-battery through the left-hand armature and back contact of relay 200, key contact 280^a, the left-hand contact and armature of relay 223, key contact 270^a, the right-hand back contact, armature and winding of relay 224 30 to main battery. Relay 224 is energized and closes a locking circuit for itself, from main battery through its winding, its right-hand armature and front contact, key contact 270^m, the right-hand front contact and armature of relay 223 to sub-battery. The winding of relay 224 is connected in parallel with the winding of relay 204 from main battery, through the winding of relay 204, key contacts 280^k and 270^l to the winding 35 of relay 223 and right-hand armature of relay 224. Thus the relay 224 is in multiple with relay 204 and will be energized when the latter relay is energized. As long as the relay 223 is energized because relay 236 is energized, the 40 latter relay being energized under the action of relays 263, 264 and 265 as above described, calls will be directed to the second choice side of the frame.

Upon the energization of relay 200, a circuit may be traced from sub-battery through the left-hand armature and front contact of relay 200, key contact 280^a, the winding of relay 210 to ground. The relay 210 closes a circuit from sub-battery, through its right-hand armature and first front contact, key contact 270^m, right-hand front contact and armature of relay 224 for maintaining that relay and relay 204 in their energized condition. As above described, relay 200 is 50 maintained in its energized condition until the starting circuit has been released by the finder circuit. If for any reason the condition, to be subsequently described, which produces the change of the start circuit for directing the traffic from the preferred to

the second choice side of the frame, is withdrawn, the starting circuit is maintained in an electrical association with the finder circuit which it starts and which is on the second choice side of the frame. This will happen even if relay 236 and consequently relay 223 is deenergized. When the start circuit is released as above described and relay 200 deenergized, the deenergization of relay 210 permits the release of relays 224 and 204, whereupon subsequent calls will be directed to the preferred side of the frame. As was shown above, it was necessary for the relay 200 to be in a deenergized condition in order that the relays 224 and 204 might be energized even though relay 223 was energized, and it is for this reason that the start circuit cannot be disassociated from the preferred side of the frame if it is engaged in the act of starting the line finder. 75 80 85

The object of the relays 243, 244 and 245, which are connected in a similar manner as 90 263, 264 and 265 to the operator group and line finder group on the second choice side of the frame, is to prevent the operation of relay 204 so as to bar the direction of calls to the second choice side of the frame if there are no paths for receiving such calls. The relay 243 is energized in a circuit from ground, through the left-hand armature 95 and first front contact of relay 245 and the winding of relay 243 to main battery. Relay 235 is energized from ground through the left-hand armature and front contact of relay 243 or the right-hand contact of relay 244, and the winding of relay 235 to main battery. The relay 235 closes a circuit from main battery through the winding of relay 241, winding of relay 233, in parallel, the left-hand armature and front contact of relay 235 and the right-hand front contact of relay 236, if the relay 236 is energized, to sub-battery. The relay 241 becomes energized. The relay 236, therefore, directs traffic from the preferred to the second choice 100 105 110 side of the frame, and the relay 235 prevents the traffic from being directed to the second choice side of the frame.

Upon the energization of relay 241, which 115 cannot occur unless the traffic is to be directed to the second choice side of the frame as above described, a circuit is closed from main battery, through its right-hand armature and first front contact, key contact 280^l, the winding of relay 202, the left-hand back contact and armature of relay 200 to sub-battery. If relay 200 is in a deenergized condition, the relay 202 will be energized and closes a locking circuit from sub-battery, through its right-hand armature 120 and front contact and its winding to the circuit above described. The operation of the relay 202 deprives relay 200 from a circuit which has been previously described, obtaining sub-battery through the right-hand 125 130

armature and back contact of the relay 202. A circuit is also closed from main battery, through the right-hand armature and second front contact of relay 241, the winding of 5 relay 234 to sub-battery. The relay 234 also connects main battery in multiple with the first right-hand front contact of relay 241 to the relay 202. The purpose of relay 234 is to maintain the relay 202 in an energized 10 condition for a longer time than would obtain in the event of relay 241 releasing. The function of relays 241 and 234 is to produce a quick closure and a slow opening of the circuit for energizing the relay 202, so as to 15 permit of the complete deenergization of the relays 224 and 204 when the relays 235 and 236 deenergize at the same time. The relay 224 prevents the control by the front contact 20 of the alarm relay 225 of the lamps 216 and 217.

Referring now to the relays 243 and 263, 244 and 264, and 245 and 265, these relays are arranged in pairs, their functions being to direct the traffic from the preferred to the 25 second choice side of the frame and to prevent traffic from being sent into the second choice side of the frame if there are no paths at that point.

The relays 243 and 263 indicate that the 30 operator selecting circuit on the respective side of the frame has been energized for an undue length of time, or that the series through the M cams of the finder sequence switches is open. The relays 244 and 264 are controlled from the operators' telephone 35 sequence switches 1000 on the respective side of the frame and indicate that all of the operators in the group are busy and therefore no traffic should be directed to the group. The relays 245 and 265 are connected with the series of "J" cams of the finder sequence switches on the respective side of the frame and indicate that all the finders on that side of the frame are busy. Any of these conditions may therefore cause the exchange in 45 the direction of traffic from one side of the frame to another.

Interrelation of finder circuits of one group.

50 As above described, the line finders are arranged on the two sides of a finder frame. Each group of finder circuits whose line finders are thus arranged is complete within itself. The finder circuits on that side of the frame to which the starting circuit is 55 normally attached, that is to say, when the relay 204 is in its deenergized condition and starting lead 252 is used, is termed the preferred side of the frame, and incoming calls will be routed through the finder circuits on 60 this side of the frame, unless there is no available path on that side, and the path is barred as will be hereinafter described. The finder circuits on the other side of the frame

through which the starting circuit becomes 65 attached when relay 204 is energized and starting lead 253 is used, will, therefore, pass the calls to the operator's positions unless there are no available paths. This side of the frame, therefore, becomes the second 70 choice side.

Referring to Fig. 4, three finders A, B and X are indicated for the preferred side, and two finders A' and X' for the second choice side. As has been explained, when sub-battery is connected to the lead 252, the relay 330 of the finder circuit first in order will be operated because that finder sequence switch 300 is in position 2 and the circuit is closed at cam 300^T. When the finder has started 80 and the brush fully tripped, segment K of the line finder closes the circuit through cam 300^L to lead 250 which brings about the de-energization of the starting circuit. During this time sub-battery is connected to lead 85 249 through sequence switch cam 300^G of the sequence switch 300 which is then in position 3, to the next succeeding finder sequence switch which is in position 1. This circuit may be traced through the lower contacts of 90 cam G of the sequence switch associated with line finder A, which is in position 3, the right-hand upper contact of cam G of the next succeeding sequence switch associated with finder B, and if that sequence switch is 95 in position 1 at that time, through the right-hand upper contact of its cam G, the lower right-hand contact of its cam D and thence to the sequence switch power magnet. If, however, the sequence switch associated with 100 finder B was engaged, it would be in some position between 4 and 17 and the circuit would then extend to the right-hand lower contact of its cam G instead of to the right-hand upper contact of its cam G, 105 and thence to the upper right-hand contact of cam G of the next succeeding sequence switch and so on until the sequence switch which is in position 1 is 110 reached. It is by the circuit through cam G that the idle finder sequence switch next in order is always chosen for use, that is to say, by this circuit arrangement the line finders are always allotted in a definite order and there is no so-called starting point. 115

If no finder sequence switch of the group is in position 2 because all of them have been in use, then a series circuit is closed through the H cams of the sequence switches in the group when those sequence 120 switches are in positions 1, or 5 to 18. This circuit is connected directly to the right-hand upper contact of cam G of some sequence switch of the group, usually the first on the frame, in this case designated as A 125 or A'. When any of the sequence switches A, B or X are restored to normal, a circuit may be traced from sub-battery, through the

+ right-hand contacts of the cams H of the sequence switches, the right-hand upper contact of cam G of the sequence switch A, and from there to the above described circuit for moving the sequence switch which has been restored to position 1 into position 2 when the starting lead 252 is closed through its cam T to its relay 330.

When all the finder sequence switches of 10 the group are engaged and are in some position from 4 to 17, a circuit is closed from ground through the J cams of the sequence switches associated with finders A, B, or X and A' or X'. The sequence switches of 15 finders on the preferred side close a circuit over leads 246, the winding of relay 265 to main battery, or the line finders on the second choice side close a circuit over lead 258 to main battery through the winding of 245. 20 Thus either the relay 265 or the relay 245 will be energized when all of the finders on the preferred or second choice sides of the frame, respectively, are engaged. The circuit established upon the energization of 25 the relays 245 and 265 will affect the starting circuit for the finder frame as previously described and bring about the operation of traffic registers and alarms as will be herein-after described.

30 The allotment of a finder circuit to the operator selecting circuit is controlled through a series circuit including the right-hand contacts of the M cams of the finder sequence switches of any one group, when 35 the sequence switch is in any position from 9 to position 4. In position 6, this circuit is interconnected with the particular finder circuit first in order in the series. It will be noted that the series circuit from lead 505 40 (Fig. 4) is in the same general direction through the sequence switches as is the allotting lead through the series of G cams above described. Therefore, the finder sequence switches will obtain connection with 45 the operator selecting circuit in the same preferred order as that in which they are allotted. It may happen that two line finders having been started one after the other, for example, line finder A started for a call 50 in one group, and line finder B started for a call in another group immediately after the starting line finder A, the line finder B will seize its line before line finder A seizes its line. If this should occur, the finder circuit B will immediately obtain connection 55 to the operator selecting circuit and an idle operator will be selected. If, in the meantime, a third line has initiated a call and line finder X is used, but before line finder X 60 has seized its line and arrived in position 6, finder sequence switch A has passed beyond position 4; this finder sequence switch having arrived in position 6 will now obtain connection with the operator selecting circuit 65 in preference to finder sequence switch

X, thus taking its order in the train of events.

Functions of the operator selecting circuit.

As above mentioned, there is one operator selecting circuit which serves one-half of all the finder circuits, which are distributed among the various frames, that is to say, the finder circuits of any one finder frame has access to both operator selecting circuits, the 75 finder circuits on the preferred side having access to the operator selecting circuit serving those operators' positions, the connecting units of which appear in the multiple banks of the connecting unit selectors which are a part of the finder circuits on the preferred side. Similarly the finder circuits on the second choice side have access to the operator selecting circuit serving the other 80 group of operators' positions, the connecting units of which appear in the multiple banks of the connecting unit selectors which are a part of the finder circuits on the second choice side. 85

Each operator selecting circuit consists of 90 sets of three relays each, as relays 601, 602 and 603. One group of these electrically interconnected relays is made available to a given group of finder circuits through the medium of the control circuit shown in Fig. 95 5. Among these sets of operator selecting relays there is one set for each of the operator's positions to be selected. The selecting relays associated with the various groups of finder circuits and which connect to any one operator's position are also interconnected so that but one group of finder circuits can select a particular operator's position at a time. The arrangement of 100 these relays may be likened to a telegraph plug-board wherein the association of a group of relays with one group of finder circuits is the vertical bar, the association of a group of relays with any one operator's position is the horizontal bar, and the function of the relays is to connect a vertical bar 105 with a horizontal bar.

It will be noted that the lead 528 is carried through the back contact of the relay 603 representing each operator's position, 110 returning over lead 531 to main battery through the winding of battery 513. When sub-battery is applied to the lead 528 through the circuit above identified leading 115 to the cam M of the particular finder circuit which has been connected to the operator's selecting circuit, then the relays 601 and 602 will be controlled by the first energized relay 603 in this series. If all of the 120 relays 603 are not energized, then sub-battery is extended to the relay 513. This is the preference series for the selection of the operator, whereby if there is more than one idle operator available at the time a particular finder circuit operates to select an oper- 125 130

ator's position, the relay associated with the idle operator's position which is first in this series will direct the above mentioned circuit to effect the energization of relays 601 and 602 as described above.

Similarly, a series circuit may be traced from the winding of relay 1036 through the normally closed left-hand contacts of the relays 602. If, therefore, there be two finder circuits on different frames which are attempting to make connection with the same idle operator, this series will decide the preference as between the two finder circuits. The energizing circuits for the relay 602 may be traced to the back contact of relay 1036 as above described, and the locking circuit leading through the series contacts above mentioned determines which of the relays associated with that operator's position will be locked up and hence cause the selection of the operator by the finder circuit. Thus by the vertical series circuit through the contacts of the relays 603, the selection by a finder circuit of a particular operator is determined, and by the horizontal series circuit through the contacts of the relays 602 associated with any operator's position, the preference as between two finder circuits on two different frames is determined.

It will be readily seen, therefore, that means are provided for the simultaneous selection of operators' positions by finder circuits located on different finder frames, and means to insure continuous service by arranging the two series circuits (vertical and horizontal) in such a way that when an operator's position of the group is the first choice in the vertical and horizontal series of a group of finder circuits, the next operator's position is the second choice of the same finder group, and the first choice in the vertical and horizontal group for finder circuits of another group. Thus if finders of groups A and B, for example, are selecting operators' positions, then the first and second operators' positions would be simultaneously selected, if these positions are the first choice for both finder frames.

50 *Interrelation of operators' position circuits of one group.*

As above mentioned, there is associated with the common apparatus of an operator's position, a sequence switch 1000 and relays 1036, 1034, 1044 and 1035. The function of the sequence switch is to control the selectability of the position. The selection of the position by some other finder circuit is prevented during the interval which is required for the connecting unit selector of the finder circuit which has selected the operator to find an idle connecting unit. As above described, when the idle connecting unit has been selected by the connecting unit selector, or whenever an operator listens in on a con-

necting unit by causing the sequence switch 900 of that unit to move into position 4, or whenever the operator's position is not occupied and therefore her telephone set is not plugged into jack 1027, the sequence switch 1000 will not be in position 1, this being the sequence switch position in which the operator's position is selectable by the operator selecting circuit.

Referring to Fig. 7, there are shown parts 75 of the operator's position circuits for three operators' positions which show the interrelation of the operators' position circuits of one group. The function of this part of the operators' position circuits is to cause 80 the sequence switch 1000 of each operator's position to be moved to position 1, and thereby render the positions selectable by the operator selecting circuit, after each operator in the group has received a call or has caused 85 her position to be rendered unselectable by listening-in or removing her telephone plugs. A further function of the circuit shown on Fig. 7 is to cause calls to be directed to the second choice side of a certain 90 finder frame, or prevent calls from being directed to the group from a finder frame where this group is on the second choice side.

When all the sequence switches 1000 are 95 in some position between 2 and 18, circuits may be traced from ground through the contacts of keys 1045, the cams G and H, respectively, in a series to the left-hand position circuit. From thence this series 100 circuit is connected through key contacts 1045 to each of the sequence switch cams J of the sequence switches 1000 of all positions. If a sequence switch 1000 is in some position 15 to 18, a circuit is established 105 from the right-hand contact of the cam J, through the right-hand armature and back contact of relay 1035, and the left-hand back contact, armature and winding of relay 1042 to sub-battery. Therefore, any position circuit in which the relay 1035 is de-energized and which is in some position 110 between 15 to 18, will have this relay 1042 energized. A locking circuit is then established 115 from ground, through the contacts of cam 1000^c, the left-hand front contact, armature and winding of relay 1042 to sub-battery (see Fig. 10). Relay 1042 is maintained energized in this circuit independently of its original energizing circuit from 120 ground through the series of G and H cams above described. The sequence switch 1000 will, therefore, be moved out of position 17 and into position 1 by a circuit which may be traced, referring to Fig. 10, from sub-battery through the right-hand armature and front contact of relay 1028, the left-hand contacts of cam 1000^c, the lower armature and back contact of relay 1029, the left-hand armature and front contact of relay 125 130

1042, the lower right-hand contact of cam 1000^b, the left-hand contact of cam 1000^a, and the power magnet of sequence switch 1000 to main battery. The sequence switch 5 is moved out of position 17 and into position 1, which renders the position selectable. This operation is performed in each of the position circuits when relay 1042 is energized, and all of such positions will be rendered selectable by the operator selecting 0 circuit.

Referring to Fig. 10, it will be noted that the contacts of relay 1044 are connected so that the left-hand armature and front contact 15 closes the series circuit through cam H and the right-hand armature and front contact, the series circuit through cam G. The function of this is to close the series circuit through the cams G and H immediately upon the selection of the position or upon the listening-in operation by the operator. These occur in advance of the movement of the sequence switch 1000 into position 1, if the operator's position, in 20 which the relay 1044 is operated, is the last idle position of the group.

When all of the positions are busy, a circuit is closed from ground (Fig. 7), through key contacts 1045^c, the cam I or the right-hand contacts of the relays 1032 of each 30 of the positions to the lead 257. This circuit causes the operation of the relays 264 of the starting circuits of those frames where the group of operators is the preferred group, and of the relays 244 of those frames where the group of operators is the second choice group. The energization of 35 the relays 264 causes the energization of the relays 204 on those frames where the operator group is the preferred group, and therefore, directs the calls to the other group of operators as previously described. The energization of the relays 244 prevents the energization of the relay 204 on those frames 40 where the operator group is the second choice, and thereby prevents the direction of any calls from those frames to the operator group.

When the position is not occupied and 50 the operator's plug is not inserted into the jack 1027, the relay 1028 is deenergized, its circuit being broken at the jack contacts. In its deenergized condition the relay 1028 closes a circuit from sub-battery through 55 its left-hand armature and back contact, the upper left-hand contact of cam 1000^b, the lower right-hand contact of cam 1000^a, and the sequence switch power magnet 1000 to main battery. The sequence switch 1000 is 60 moved out of positions 1 or 17 and will come to rest in position 4, since the circuit for moving the sequence switch out of position 4 is opened at the left-hand front contact of the relay 1028.

Alarm signals and traffic registers.

65

In order to further insure continuous and prompt telephone service, means are provided whereby upon the initiation of a call, if its continued extension to an idle operator is interrupted due to trouble in the apparatus, that is to say, due to failure of the apparatus to perform its required function, such disturbance is indicated to a supervisor who can then take action to insure the extension 70 of the call to an idle operator. The important signals indicating this trouble are assembled on a central board which is termed "control board." Those signals which indicate trouble due to apparatus definitely 75 associated with a group of 400 lines appearing in one line finder frame, are all assembled together in one panel, together with emergency and traffic keys. There will, therefore, be as many of these panels as there 80 are line finder frames serving groups of 400 lines in the system.

Other signals indicating trouble or failures in such apparatus which is in no definite association with any one group of 400 lines, also appear in the control board. These signals are not located in any one 90 panel but are set apart by themselves to indicate trouble of a more general nature.

Each group circuit is provided with a relay 114 having two differentially connected windings. When the call is first initiated, a circuit is closed from sub-battery through the right-hand armature and front contact of the line relay 101, and the upper winding of relay 114 to ground. Relay 114 becomes energized but as soon as the sequence switch 100 closes its cam F in position 2, a circuit is maintained closed until the sequence switch moves out of position 18, through the right-hand front contact of relay 101, the lower contact of cam 100^f, key contact 124^b, key contact 190^c and the lower winding of relay 114 to ground. When this circuit is closed, the relay 114 becomes de- 100 energized due to the differential action of the two windings. When relay 114 is energized, a circuit is closed from ground, through its upper armature and front contact, the lead 161, the left-hand contacts and armatures of relays 210 and 233 to the delay interval relays 230, 231 and 232. These relays function so as to prevent the energization of relay 229 until an interval has 115 passed such as sequence switch 100 will require to close cam 100^f, in position 2. The relays 230 and 231 are slow-release relays and are energized in a circuit through the contacts of relays 210 and 233 above described. Upon the energization of relay 231, the relay 232 becomes energized and is maintained in its energized condition through a 120 circuit including its right-hand front contact 125

and armature and the upper front contact of relay 114. When relay 231 is finally deenergized and if relay 114 is still energized, ground from the armature and upper contact of relay 114 is extended through the left-hand front contact and armature of relay 232 to the left-hand winding of relay 229, and this relay becomes energized. However, the release of relay 231 is delayed sufficiently, both by its own action and the action of relay 230, to permit of the movement of sequence switch 100 in position 2, to effect the release of the relay 114. If the sequence switch 100 does not arrive in position 2 within this time, the relay 229 becomes energized, and closes a circuit from main battery, through a lamp 119 located in the control panel in association with key 190, the lower front contact and armature of relay 114, lead 160, the right-hand armature and front contact of relay 229, key contact 206^c, normally closed contact of key 281, and the winding of relay 221 to ground. Relay 221 becomes energized and closes a circuit from ground through its front contact, lamp 229 which is also located on the control panel, and the winding of relay 219 to main battery. The relay 219 closes a circuit to the alarm bell on the control board. When the relay 229 is maintained in its energized condition by a circuit from main battery through its right-hand winding, right-hand armature and front contact, and then through the above described circuit to ground, including the winding of relay 221, the lamp and the alarm is maintained actuated until the key 206^c is operated. This circuit is maintained closed even though the relay 114 may have become deenergized. The keys 206^c and 281 are located on the control panel so as to enable the supervisor to quickly perform the necessary operations above-described.

Associated with the group circuit there are three slow acting relays 121, 122 and 123. The relay 121 may become energized in a circuit extending through the lower contact of the cam 100^D of the group sequence switch, the relay 122 from ground through the left-hand upper contact of the cam 100^D, and the relay 123 from ground through the lower contact of cam 100^E. Cams D and E close the circuit through the slow acting relays for a time insufficient to permit the relays to become energized, provided the group sequence switch 100 is moving at its normal rate. If, however, the sequence switch is sluggish and does not move at its normal rate, or stops altogether, then one of the relays 121, 122 or 123 will become energized, since the closure of the ground through the contacts D and E is maintained continuous at one contact or the other as shown by the table at the right of

Fig. 11^A. For example, when cams 100^E and 150^E have passed fifteen degrees beyond the center line of position 1 at the start, then these cams are alternately closed for five degrees and opened for ten degrees until the end of rotation when the center line is at position 18 $\frac{1}{2}$. When any one of the relays 121, 122 or 123 becomes energized, a circuit is closed from ground through their contacts, the lamp 120, key contact 190^c, conductor 180, and the winding of relay 222 to main battery. The relay 222 closes a circuit from ground through its armature and front contact, lamp 218, to main battery through the winding of relay 219. The lamp 218 which is located on the control panel, indicates that some group sequence switch is not moving at its normal rate, or has stopped. The lamp 120 and key 124 are associated with the sequence switch on the apparatus frame, and service may be restored by switching the sequence switch 150 in place of sequence switch 100 by actuating key 124. The sequence switches 100 and 150 are driven from different shaftings. Thus, by means of the key 124, either sequence switch may be used should it be desirable to deprive one of the shafts of power. A key 190 is provided on the control panel, whereby upon the lighting of lamps 218 or 299, together with the particular lamp 119 of the group associated with the key 190, an emergency group circuit, similar in character to the one shown in Fig. 1, may be brought into electrical association with this particular group of lines and with the lamps 119, 218 and 299. Service may then be obtained through the operation of this emergency group circuit while the regular group circuit is being repaired.

As above described, the group circuits are electrically interrelated by the series leads 111 and 112, through the normally closed contacts of relays 104 and 105. In order that trouble developing in this series, due to an open circuit through a normally closed contact of these relays, may be indicated, the back contacts of the last set of relays 104 and 105 are connected through the leads 110 and 113, respectively, to the relays 203' and 205, respectively. These relays 203' and 205 are normally in an energized condition, the circuits therefore extending to the right-hand back contact and armature of relay 202. Whenever relay 210 becomes energized in the manner above described, the relay 213 is energized from ground through its winding, the first right-hand front contact and armature of relay 210 to sub-battery. The relay 213 opens the circuit extending from ground through its left-hand back contact, the make contacts of relays 203' and 205 in multiple, and the winding of relay 207 to main battery. Whenever relay 210 is energized the starting circuit is energized in pass-

ing a call to a finder, and relays 203' and 205 will become deenergized upon the operation of relay 201, through the right-hand back contact of which the circuits for relays 203' and 205 pass. The relay 207 cannot, however, become energized because the relays 203' and 205 are slow in deenergizing and relay 213 will become energized before the back contacts of relays 203' and 205 are closed. If, however, the starting circuit is not engaged, and the circuit above-described for maintaining either the relay 203' or the relay 205 in its energized condition becomes open, the relay 207 will become energized and be maintained in its energized condition through a circuit extending through its right-hand front contact and armature and key contact 206^a to ground. Alarm signals will be given under this condition under the control of a circuit from ground, through the left-hand armature and back contact of relay 212, the right-hand armature and front contact of relay 207, the lead 209, and lamp 215 to main battery, through the winding of relay 219. The lamp 215 is located on the control panel and indicates that there is an open circuit in the series leads through the back contacts of relays 104 or 105. Upon the actuation of key 206^a, the relay 207 becomes deenergized, whereby the supervisor is enabled to put out the lamp 215 after the trouble has been cleared.

If the above described series circuit is open in the back contacts of relays 200, 201 or 202, the relay 211 is energized through a circuit from sub-battery, the winding of relay 211 to the lead 111, and from thence through the series contacts of the relays 104 or through the winding of relay 200 and series contacts of relays 105 to main battery through the windings of relays 203' and 205. The relay 211 cannot be energized in the circuit above described, unless the sub-battery is disconnected from the contact of relay 202, and the circuit is completed to main battery through the windings of relays 203 and 205. The relay 211 closes a circuit from ground, through the right-hand armature and back contact of relay 213, the left-hand front contact and armature of relay 211 of the winding of relay 212 to main battery. The relay 212 becomes energized and is maintained in this condition through a circuit from ground, through key contact 206^b, right-hand armature and front contact of relay 212. A circuit is closed from ground through the left-hand armature and front contact of relay 212, the lamp 214, and the winding of relay 219 to main battery. The lighting of lamp 214 indicates that the circuit arranged to cause the functioning of the group and starting circuits is open, the break being in the starting circuit itself. The relay 212 will be maintained in its energized condition through key contact

206^b, which is actuated by the supervisor after trouble has been cleared, by the actuation of key 280.

The actuation of key 280 switches a group of relays in the starting circuit which are of a similar character and similarly connected and which replace the relays 200, 201, 202, 203 and 204, thereby restoring service to the group of 400 lines and permitting the repair of the trouble which caused the display of signal lamp 214, the key 280 being located on the control panel in association with the lamp 214.

When the relay 200 was energized, a circuit was closed from sub-battery through its left-hand armature and front contact, key contact 280^c to the relays 226, 227 and 228. These relays perform the same function as relays 230, 231 and 232, delaying the connection of sub-battery from the contacts of relay 200 through the left-hand armature and front contact of the relay 226, the winding of relay 225, to ground. The time required to bring about the closure of this circuit to energize the relay 225 is such that, if there is no delay due to trouble in the apparatus in the starting of a line finder by the starting circuit and the release of the starting circuit by the closure of the commutator segment K of the line finder in the manner previously described, the relay 225 will not become energized. If, however, the starting circuit is not released before this interval, the relay 225 will become energized and a circuit will be closed from sub-battery through its right-hand armature and front contact, the left-hand armature and back contact of the relay 224, the lamp 217 and the winding of relay 220 to ground.

The lamp 217 will glow and relay 220 will give the signal to the supervisor that the above described action is taking place, and also that the finder circuit, which is delaying the release of the starting circuit, is on the preferred side of the frame because the relay 224 is in its deenergized condition. If the relay 224 was in its energized condition when this action took place, the lamp 216 would be lighted instead of the 217 lamp, indicating that the trouble was on the second choice side of the frame, the relay 224 having become energized in the manner previously described. The relay 225 closes a circuit from sub-battery through its left-hand armature and front contact, the normally closed key contact 240^b to the leads 249 and 266, and thus to the series of G cams of the finder sequence switch to the power magnet thereof through cam D as previously described. The sequence switch is now moved out of position 3 so as to insure that the next sequence switch to be allotted has moved into position 2. The function of this circuit is to further insure the proper allotment of the line finders in case of trou-

ble. The sequence switch is now moved out of position 3 so as to insure that the next sequence switch to be allotted has moved into position 2. The function of this circuit is to further insure the proper allotment of the line finders in case of trou-

ble. The sequence switch is now moved out of position 3 so as to insure that the next sequence switch to be allotted has moved into position 2. The function of this circuit is to further insure the proper allotment of the line finders in case of trou-

ble caused in the operation of the left-hand armature and front contact of the relay 203.

When the condition exists for directing calls from the preferred side of the frame to the second choice side of the frame, and also when the condition exists for barring calls from the second choice side, there are no paths open over which calls may be extended. It is, therefore, necessary to prevent the 10 operation of the alarm signals above described. Under these conditions the relay 202 becomes energized in the manner previously described and closes a circuit from sub-battery, through its left-hand armature 15 and front contact, and the key contact 280^m to ground through the winding of relay 213. The relay 213 prevents the alarm lamps 214 and 215 from becoming lighted. When the relay 241 is energized under the control of 20 relays 235 and 236, a circuit is closed in parallel to main battery through the winding of relay 241. This circuit extends from main battery, winding of relay 233, the left-hand armatures and front contacts of relays 25 235 and 236 to sub-battery. Relay 233 being energized, prevents the lighting of lamps 119 and 299, even though some relays 114 may be energized. Thus, if the calls are 30 completely blocked no alarm indication will be given.

A circuit may be traced from ground, through the upper armature and front contact of relay 114, lead 161, the left-hand armature and back contact of relay 229, and 35 the windings of relays 259 and 260 to main battery. The relay 260 closes a circuit from main battery through the winding of register magnet 261, the left-hand armature and front contact of relay 260, the left-hand 40 front contact and armature of relay 241, and the left-hand second front contact and armature of relay 245 to ground. As previously described, the relay 245 is 45 energized only when all of the finders on the second choice side of the frame are engaged. Therefore, a count will be made on the register 261 when all of the finders on the second choice side of the frame are engaged and a call is initiated 50 which has no path to the preferred side of the frame.

A circuit is also closed from the main battery, through the winding of register magnet 262, the right-hand armature and front 55 contact of relay 260, the right-hand armature and front contact of relay 245, the right-hand front contact and armature of relay 265 to ground. If the relays 265 and 245 are both energized, indicating that all 60 of the finders on both the sides of the frame are busy, the register 261 will become energized and a count will be made, indicating that a call is being initiated and all of the 65 paths which might be used to extend the call to an idle operator are engaged.

The relay 259 closes circuits for lighting the call-waiting pilot lamps shown on Fig. 7 at 1037, 705 and 707, located at the operators' positions, lamp 708 located at the chief operator's desk, and lamp 709 located 70 on the control board. The circuits for these lamps may be traced from sub-battery, through the back contacts of relay 225, the front contacts of relay 259, one path then leading through the upper front contact of 75 the relay 242, the left-hand back contact and armature of relay 263, the contacts of key 242, the conductor 256, and the right-hand winding of relay 701 to ground and the other path through the lower armature 80 and front contact of relay 242, the right-hand back contact and armature of relay 243, contacts of keys 240^r and 270^r to the conductor 256', and thence to the right-hand 85 winding of relay 701'. Relay 701 is associated with the operators' positions of the second choice side. The relay 701 becomes energized and closes circuits from ground, through the right-hand armature and back 90 contact of relay 700, the armatures and front contacts of the relay 701 to the lamps 705, 707, 708, 709 and 1037 to main battery. As previously shown, the relays 243 and 263 are energized when all of the finders in 95 the group are busy, that is to say, when there are no available paths over which the calls might be directed to the group of operators. Therefore, when there are no available paths to the operators then under the control of 100 relays 243 or 263, the call-waiting pilot lamp in that group will not be lighted.

As above mentioned, means are provided on the control panel whereby by the actuation of the key 240, the preference as to the 105 finder group on one side of the frame may be switched to the finder group on the other side of the frame. The actuation of the key 240 changes the effect of the contacts of the relay 204. In the previously assumed case, when this relay is deenergized, it controls connection with lead 252, whereas in the present case, it controls connection with conductor 253. The other leads are correspondingly reversed upon the actuation 110 of key 240.

If desirable, it is possible to prevent the direction of calls to the second choice side of the frame with any of the previously mentioned barring conditions being present. This may be done by the actuation of key 120 270 mounted in the control panel. By means of the keys 240 and 270, it is therefore possible to direct the calls to either the normally preferred or normally second choice side of the frame and confine all calls 125 to those paths. For example, if the key 270 be actuated, calls will be confined to the normally preferred side of the frame. If both the keys 270 and 240 are actuated, 130 the calls would be confined to the normally

second choice side of the frame. Therefore, by means of these two keys it is possible to divert the traffic from one group of operators to another or to change the direction of traffic from one group of operators to another.

It was shown how, under certain conditions, the line finder or the connecting unit selector was moved to its topmost position 10 and the commutator segment X closed. If this occurs, a circuit is closed from sub-battery through the commutator segment X of the connecting unit selector, the lower contact of cam 300^U and to a relay 401, 402, 15 403, 405 or 406. These relays are connected to the lower left-hand contacts of cam U of every third finder sequence switch on the two sides of the frame, that is to say, relays 401 are connected to the first, fourth, 20 eighth, etc., finder circuits; relay 403 to the second, fifth, ninth, etc., finder circuits; relay 405 to the third, seventh, tenth, etc., finder circuits on the preferred side of the frame. Similarly relays 402 and 406 are connected to the second choice side of the frame. The left-hand contacts of these relays close 25 a circuit from sub-battery, through their armatures and front contacts to a tell-tale signal which is located on the control board. The right-hand contacts of the relays on one 30 side of the frame are connected in a series circuit from ground through their armatures and front contacts to a lamp 408 and winding of relay 409 to main battery. The lamp 35 408 which is located on the control board indicates that all of the finders on one side of the frame have gone to the topmost position. The purpose of this signal alarm lamp 408 is to indicate when a line relay 101 40 of a calling line does not become deenergized for any reason after the line has been seized by the line finder and the make busy resistance 338 is connected through contacts of cam 300^K, the sleeve brush and 45 the terminals to the cutoff relay 102.

Referring to Figs. 3 and 5, it will be noted that when the operator selecting circuit is seized and the finder sequence switch 300 moves into position 6₄, a circuit is closed 50 from main battery, through the right-hand winding of relay 508, lead 502, the upper left and lower right-hand contacts of cam 300^E, commutator segment 312, wiper 308, terminal 304, and conductor 115 to the left-hand armature of relay 101. If at this time the relay 101 is energized, the circuit will be completed to the contacts and winding of relay 107 and sub-battery, and the relay 508 will be energized. The relay 508 will not 55 be energized if the relay 101 is in its deenergized condition, this being the same test condition as is applied when the line finder seizes the line. If the relay 508 is energized, a locking circuit is closed from main battery, through its left-hand winding, left-

hand front contact and armature, conductor 500, cams 300^X and 300^W, segment M of the line finder to sub-battery. The relay 508 is maintained energized until the sequence switch 300 moves out of position 8. The 70 relay 508 closes a circuit from sub-battery through commutator M of the line finder, lower contacts of cam 300^W, conductor 507, right-hand armatures and back contacts of relays 511 and 509, right-hand armature and 75 front contact of relay 510, right-hand armature and front contact of relay 508, and conductor 503 for moving the sequence switch 300 out of position 7 as previously described. The connecting unit selector will now be 80 started but no brush will be tripped because no selection of an operator's position has been permitted since the selecting lead 528 has been opened at the right-hand back contact of relay 508. The connecting unit selector will, therefore, move to its topmost position whereupon the X segment of the connecting unit selector commutator will be closed and the sequence switch will be moved to position 16. One of the relays 401, 402, 403, 405 or 406 becomes energized. Although the 85 first line finder has seized the line and attempted to make it busy by the closure of the make busy resistance 338, the relay 101 not having become deenergized will start another line finder as soon as the sequence switch 100 arrives in position 1. The relay 508 will again be energized when the second line finder circuit attempts to select an operator; and the connecting unit selector of 90 that finder circuit will be sent to its topmost or tell-tale position. This action will continue until the relays 401, 403, 405, etc., of the preferred side of the frame or the equivalent relays of the second choice side of the frame have all been energized, whereupon the lamp 408 is lighted, indicating to the supervisor that trouble of this nature has occurred. The number of the particular line 95 causing the trouble will be indicated by the position of all the line finders on the frame. The supervisor can remove the line from service and restore the finder circuits to their normal condition, thereby restoring service 100 to the group of 400 lines. 105

Referring to Figs. 3, 4 and 5, a series circuit may be traced from ground, through the winding of relay 515, the lead 501, the left-hand contacts of the cams M in series 110 of the sequence switches 300 on one side of a frame which is associated with one operator selecting circuit, conductor 505 of the last sequence switch, left-hand contacts and armatures of relays 510 and 511 to sub-battery. The relay 515 is normally energized, but whenever the series circuit through the M cam is broken, the relay will become deenergized unless the relays 512 and 577 become energized upon the seizure of the operator selecting circuit by the finder circuit. 115 120 125 130

The relay 515 is slow to deenergize, and will not deenergize during the interval required for a finder sequence switch to move from position 4 to position 7, and for the relays 5 512 and 577 to become energized. The circuit for relay 515 is opened at cam M in position 4, the circuit for the relay 512 is closed in position 7, and the circuit for relay 577 is closed in position 6 $\frac{1}{2}$ of the cam 300 $\times$ of the 10 finder sequence switch which seizes the operator selecting circuit. If the series circuit is open when all of the finder sequence switches are in some position from 9 to 4, the relay 515 will become deenergized, and 15 a circuit closed from ground through the lamp 516 and the right-hand winding of relay 574 in multiple to main battery. The lamp 516 is located on the finder frame in association with the relays shown in Fig. 5, 20 and indicates that the series circuits through the M cam of the finder sequence switch are open. The relay 574 closes a circuit from sub-battery through its right-hand armature and front contact to a lamp 524 or 525 located on the control panel and a relay 523 to 25 ground. The relay 523 closes the alarm circuit. The lamp 524 or 525 will be lighted depending upon whether the trouble is on the preferred or second choice side of the 30 frame. The relay 574 also closes a circuit from ground, through its left-hand armature and front contact, and conductor 260 to energize the relay 263 if the trouble is on the preferred side of the frame, or through 35 conductor 261 to energize the relay 243 if the trouble is on the second choice side of the frame. The relays 243 or 263 prevent the calls from being directed to the finder 40 circuits, or that side of the frame on which the trouble is located, and will also, as above described, prevent the call-waiting pilot lamps being lighted because this trouble condition is the same as if the finders are busy. 45 Since there is trouble on one side of the frame, no calls should be directed thereto, just as if there were no paths available.

The relay 512 closes a circuit from ground through the right-hand armature and back contact of relay 513, the right-hand armature and front contact of relay 512, the right-hand armature and back contact of relay 520, and relay 519 to main battery. The relay 519 closes a circuit for energizing the relay 521 and the latter closes a circuit for energizing the relay 518, which in turn causes the energization of relay 520. The relay 520 opens the first mentioned circuit to the relay 519, whereupon the relays 519, 521 and 518 become deenergized. These relays, however, due to their mechanical construction, are slow in becoming deenergized, but if the circuit above described through the right-hand contacts of relay 512 is still closed when relay 518 becomes deenergized, 60 the circuit is extended from the back contact of the relay 518, the left-hand front contact and armature of relay 520, which is maintained energized through its right-hand contacts, the lamp 522, and the left-hand winding of the relay 514, in multiple, to main battery. The lamp 522 is located on the finder frames like lamp 516. The relay 514 causes the lighting of the lamp 524 or 525 and the blocking of calls on that side of the frame. The lamp 524 or the lamp 525 is 70 a master lamp located on the control board, and corresponds to either of the lamps 516 or 522 located on the finder frame, the latter lamp serving to identify the particular nature of the trouble, and the former to 80 identify the particular side of the frame which is causing the trouble.

When all of the operators are busy, the conductor 528 closed to sub-battery in the finder circuit as previously described, is extended through the back contacts of all of the relays 603, conductor 531, and the winding of relay 513 to main battery. The relay 513 becomes energized, and opens at its right-hand back contact and armature the 90 circuit for the alarm relays 518, 519, 520 and 521. A circuit is now closed from ground, through the right-hand armature and front contact of the relay 513 to conductor 533, and from thence through the 95 back contact of the relay 702 (see Fig. 7), and the winding of relay 700 to main battery. The relay 700 becomes energized if the relay 702 is deenergized. Assuming this is to be the case, the relay 700 prevents the 100 lighting of the call-waiting pilot lamps 705, 707, 708, 709 and 1037. At its right-hand front contact, the relay 700 closes a circuit from ground, through its armature and front contact, the lamp 712 and the 105 winding of the relay 704, in multiple, and the winding of relay 703 to main battery. The lamp 712 and the relay 703 are located on the control board. The relay 703 closes the alarm circuit to the control board. The 110 lighting of the lamp 712 indicates that trouble exists in the operator's allotting circuit, because the relay 702 has not become energized. The failure of the relay 702 to become energized indicates, furthermore, 115 that the series circuit which should be closed by the cams G and H of the operator's sequence switch 1000 in that group when all operators are busy, is open. The relay 704 closes circuits from ground through its front 120 contacts to the lower left-hand contacts of the cams P of the operators' sequence switch. Referring to Fig. 10, it will be noted that this circuit is further extended through the lower right-hand contacts of the cam 1000 $\times$ 125 and lamp 1031 to main battery. If the operator's sequence switch is in position 1, the lamp 1031 will burn brightly. If, however, the operator's sequence switch is in some position from 5 to 3 other than position 1, 130

the lead to the cam P is extended through a resistance 1030 and the contacts of the cams 1000^p to the lamp 1031, and the lamp will burn dimly. This indicates that the operator's sequence switch is in its selectable position. The supervisor may thus identify one of two things: If all of the lamps are burning dimly at the time 712 is lighted on the control board, the circuit of cams G and H must be open and prevent the resetting of the sequence switches 1000 of the idle operators' positions into position 1; if, on the other hand, one or the other of the lamps are burning brightly and the lamp 712 on the control board is lighted, the supervisor is notified that there are one or more idle operators available in the group but that selection is prevented on account of some trouble in the operator selecting circuit, or possibly due to trouble in some operator's position circuit itself. The supervisor is further provided with a key 710 on the control board for connecting ground directly to the cams J of the operators' sequence switches. By actuating this key, operators' sequence switches of those positions which are idle can be restored to position 1, even though the circuit through the cams G and H of sequence switches may be open. By this means the supervisor is enabled to restore service in the event of the above mentioned trouble.

Another circuit is closed by relay 513 from sub-battery, through the right-hand armature and back contact of the relay 574, the left-hand armature and front contact of the relay 513, conductor 532, and the left-hand winding of the relay 701 to ground for causing the lighting of the call-waiting pilot lamps.

- 40 An alarm is provided for the horizontal series circuit through the relays 602 representing an operator's position in the operator selecting circuit. This circuit may be traced from main battery, through the resistance 1033, the winding of relay 1036, the lead 605, the left-hand back contacts of the relays 602 in series, and the winding of relay 612 to ground. The relay 612 is normally energized and is very slow in deenergizing.
- 45 If the relay 612 should become deenergized, a circuit will be closed from ground through the back contacts of relay 612 to the relay 613. The relay 613 closes a circuit through its front contact, the lamp 625, and the relay 608 to main battery. The relay 608 closes a circuit from ground through its armature and front contact, lamp 623, and the winding of relay 604 to main battery, the lamp and the relay being located on the control board. The relay closes the alarm circuit on the control board. The lighting of the lamp 623 indicates that one or more of these horizontal series circuits are open. A lamp 625, one for each operator, is located on the frame on which the selecting

relays 601, 602 and 603 are located. Upon the lighting of the lamps 622, 623 or other signal lamps on the control board each individual to an operator's position the supervisor may ascertain at the frame on 70 which the selecting relays are mounted, which of the lamps similar to 625 is lighted. The supervisor may actuate the key 711 individual to a particular operator's position at which a lamp is lighted, and close 75 the series circuit of the G and H cams, and by actuating the keys 690 for the particular sets of relays 601, 602 and 603 representing the operator's position indicated by the lamp similar to 625 in the operator selecting circuit, find out which of the sets of selecting relays is causing the trouble. The key 690 closes the horizontal lead 605 through its contact 690^a. When this lead is closed by the actuation of the particular key 80 690 representing the set of relays causing the trouble, the relay 612 will again be energized and extinguish the lamp 625. Similarly, the lamp 623 on the control board 85 will be extinguished.

It is noted that there are relays 612, 613 and a lamp 625 for each operator's position. The lamps 625, 627 and 629 of one group of positions are connected in series with a relay 608, and there are on the control board 90 lamps 622 and 623 each individual to an operator group. Therefore, the supervisor is able to tell from the control board which particular group of operators' positions is causing the trouble, and by actuating the 100 keys 690, may determine the particular group of selecting relays causing the trouble. The actuation of the key 690 prevents any trouble in the selecting relays from reacting upon the other selecting relays of the 105 operator's selecting circuit, whereby proper service is continuously maintained.

Special connecting equipment.

In tracing the circuits in this portion of 110 the description, the drawings should be placed together in the manner indicated in Fig. 27.

If, for any of the mentioned reasons, the operator decides to use the special equipment, she depresses a listening key 2104 associated with that unit. A circuit is then closed from main battery through the winding and left-hand back contact of relay 2105, the right-hand contacts of cam 2100^d, 115 the upper contact of key 2104, conductor 2110, the contacts of cam 1000^e, the right-hand armature and back contact of relay 1040, the right-hand back contact and armature of relay 1036, and the right-hand front contact and armature of relay 1028 to sub-battery. The relay 2105 becomes energized and is maintained in its energized condition by main battery through its winding, 120 left-hand front contacts and armature, up- 130

per contacts of key 2102, normally closed contacts of key 2101, upper right-hand contact of cam 2100^P, and cam 2100^C to sub-battery, a circuit from main battery, 5 through the power magnet of sequence switch 2100, the right-hand contacts of cam 2100^M, the right-hand front contact and armature of relay 2105, the normal contact of key contacts 2101, the upper right-hand contact of cam 2100^P, and cam 2100^C to sub-battery, causing the movement of the sequence switch 2100 out of position 1, 10 through position 2 and into position 4. As soon as the sequence switch 2100 reaches position 1₄, and when the incoming sequence switch 2200 moves into position 2, a call signal 2107 is caused to flash under the control of a circuit extending from ground, 15 through an interrupter 2060, conductor 2038, the lower contacts of cam 2200^N, conductor 2119, resistance 2108, lamp 2107, the upper left-hand contact of cam 2100^P, and the cam 2100^C to sub-battery. When the sequence switch 2200 reaches position 3 and 20 until it moves out of position 13, ground is connected to conductor 2119 through the upper right-hand contact of cam 2200^N, causing the lamp 2107 to light steadily. The relays shown in Fig. 10 perform the 25 same functions as previously described.

As soon as the sequence switch 2100 reaches position 2, a circuit is closed from main battery, through the winding of relay 2210, the left-hand contacts of cam 2200^M, conductor 2121 and the right-hand contact of cam 2100^C to sub-battery. Relay 2210 becomes energized, and locks up through its right-hand front contact and armature, conductor 2120 and the left-hand armature and back contact of relay 2122 to sub-battery. It closes a circuit from sub-battery, through its left-hand armature and front contact, the upper left-hand contact of cam 2200^B and the left-hand contact of cam 2200^A for moving the sequence switch 2200 out of position 1 and into position 2. With the sequence switch 2100 in position 4, and the sequence switch 2200 in position 2, a circuit is closed from main battery, through the winding of relay 1314, the lower right-hand and upper left-hand contacts of cam 1300^F, conductor 980, the lower contacts of cam 2100^Q, conductor 2114, the lower contacts of cam 2200^R, conductor 2049, and the left-hand back contact and armature of relay 2019 to sub-battery. The relay 1314 becomes energized, and causes the association of an idle sender by means of the cord finder with the double ended unit, in the same manner as above described. A circuit is now closed from ground, through interrupter 2060, conductor 2038, the right-hand contacts of cam 2200^M, conductor 2043, resistance 2090, lamps 2022, the lower contacts of cam 2000^V and the 55 left-hand front contact and armature of relay

2019 to sub-battery. The relay 2019 corresponds in function to relay 1235.

When the cord finder sequence switch 1300 moves from position 2 to position 3, a circuit is closed from main battery through the 70 winding of relay 1317, the left-hand contacts of cam 1300^W and from main battery through the winding of relay 1319 in parallel, the upper right-hand and lower left-hand contacts of sequence switch cam 1300^X, 75 wiper 1309 and terminal 1303, the conductor 1241, the left-hand contacts of cam 2200^Q, conductor 2042 and the lower contacts of cam 2000^P to sub-battery. The relays 1319 and 1317 become energized, and the former 80 closes a locking circuit for these relays through its left-hand front contact and armature, and the upper right-hand contacts of cams 1300^S and 1300^R to sub-battery. The relay 1319 remains energized through this locking circuit until the sequence switch 1300 moves beyond position 17, and opens the upper right-hand contact of cam S, and the relay 1317 until the sequence switch 1300 moves beyond position 8, and opens the left- 85 hand contacts of cam W. The relay 1319 opens in its left-hand back contact the locking circuit of relay 1382, so that when the incoming end of the unit is used, the relay 1382 releases after the allotter moves out of 90 an allotting position and opens the lower left-hand contacts of its cam 1350^W, thus cancelling the reverting busy test feature. The relay 1317 opens the circuit which is effective in the previously assumed case, for 100 moving the sender sequence switch 1400 out of position 1, through a circuit including the lower right-hand contact of cam 1400^C and the right-hand back contact and armature of relay 1317. The relay 1317 closes a circuit 105 to cancel the automatic listening-out feature by actuating relay 1316. When the sequence switch 1300 is passing through positions 4 to 6, the circuit extending from main battery through the lower contacts of cam 1300^J, the winding of relay 1316, the right-hand front contact and armature of relay 1317, the upper left-hand contact of cam 1300^Q and the right-hand contacts of cam 1300^R to sub-battery is maintained. 110

Upon the depression of the office and number keys, the cord finder sequence switch 1300 moves out of position 3 into position 8, due to the setting of the registers in the above described manner, and out of position 8 into position 15, due to the fact that the sender sequence switch 1400 is in position 1. The control circuit for moving this sequence switch out of position 8 into position 15, 120 extends from main battery, through the power magnet of sequence switch 1300, conductor 1335, right-hand contacts of cam 1400^H, conductor 1341, the lower left-hand contacts of cam 1300^Q, and the right-hand contacts of cam 1300^R to sub-battery. The 125 130

relay 1317 becomes now deenergized, and closes a circuit (as soon as the sequence switch 1300 reaches position 9) from main battery, through the power magnet of sequence switch 1400, the lower right-hand contacts of cam 1400^c, conductor 1340, the right-hand armature and back contact of relay 1317, the upper left-hand contact of cam 1300^q and the right-hand contacts of cam 1300^r to sub-battery. Sequence switch 1400 moves out of position 1 into position 2. A circuit is now closed from main battery, through the winding of relay 2213, the left-hand contacts of cam 2200^e, resistance 2214, conductor 2050, the upper right-hand and lower left-hand contacts of cam 2000^l, the right-hand front contact and armature of relay 2019, conductor 1238, terminal 1304, and wiper 1310 of the cord finder, the lower left-hand and upper right-hand contacts of cam 1300^e, conductor 1324, the lower contact of cam 1400°, the left-hand armature and back contact of relay 1405, the winding of stepping relay 1401, the lower contacts of cam 1400^g, conductor 1328, the lower contacts of cam 1300^h, wiper 1312, terminal 1306 of the cord finder, conductor 1237, conductor 2036, the lower right-hand and upper left-hand contacts of cam 2200^f, and resistance 2208 to sub-battery. The relay 2213 becomes energized and locks up through its left-hand front contact and armature, the lower left-hand contact of cam 2200^p, and the lower left-hand contact of cam 2200^e, and then through the above-traced circuit. The relay 1401 also becomes energized and controls the operation of the counting relays in the above described manner. The relay 2213, upon energization, closes a circuit from main battery, through the power magnet of sequence switch 2200, the lower right-hand and upper left-hand contacts of cam 2200^j, the right-hand front contact and armature of relay 2213 and the left-hand front contact and armature of relay 2210 to sub-battery for moving this sequence switch out of position 2 into position 3. The up drive magnet 2209 is now energized and causes the upward movement of the incoming selector which operates in the same manner to select a final selector, as the incoming selector illustrated in Fig. 18 operates. Relay 2213 corresponds in function to relay 1802, relay 2212 to relay 1835, relay 2210 to relay 1801, magnet 2209 to magnet 1818, magnet 2211 to magnet 1819, and magnet 2216 to magnet 1820. The operation of a final selector like the one illustrated in Fig. 19 is controlled through the incoming selector illustrated in Fig. 22, in the same manner as above described. When the units selection is completed, then, under the control of relay 2213, the incoming selector sequence switch 2200 is moved from position 13 to position 14, and the sender sequence switch 1400 from position 10 into position 16, whereupon a circuit is closed from sub-battery, through the right-hand contact of cam 1300^r, the lower right-hand contact of cam 1300^s, the left-hand armature and back contact of relay 1382, the right hand front contact and armature of relay 1319, conductor 1338, the left-hand contacts of cam 1400^r, conductor 1328, the lower contacts of cam 1300^h, wiper 1312, terminal 1306, conductor 1237, conductor 2036, the upper right-hand contacts of cam 2200^c, the left-hand contact of cam 2200^a and the power magnet of sequence switch 2200 to main battery. Under the control of this circuit the sequence switch 2200 moves out of position 14 into position 16. When this occurs, the circuit including the lower contacts of cam 2200^k, conductor 2052, winding of relays 2019 and 1399, is opened, whereupon the sender is disconnected from the connecting unit in the above-described manner.

A circuit is now closed from ground through the upper left-hand winding of the repeating coil 2007, the upper normally closed contacts of the key 2024, conductor 2026, the left-hand contacts of cam 2100^g, conductor 924, the right-hand normally closed contacts of keys 1013, 1012, 1011, 1010 and 1009, the right-hand back contact and armature of relay 1001, conductor 920, the lower contacts of cam 2100^e, the back contact and upper armature of relay 2103, conductor 2111, the upper contacts of cam 2200^p, wiper 2201, terminal 2202, conductor 1814, the upper left-hand and lower right-hand contacts of cam 1900ⁱ, the right-hand winding of relay 1902, and the right-hand contacts of cam 1900° to main battery. The relay 1902 closes a circuit to move the sequence switch 1900 of the final selector out of position 7 whereupon the line is tested in the manner previously described. If the line is busy, the sequence switch 1900 is moved to position 17 and the busy back signal is given. Assuming that the line is idle, a connection is made thereto. The operator may now ring the calling subscriber's station by actuating the proper ring-back key 1010, 1011, 1012 or 1013. It will be noted that the two relays 1016 and 1017 are operated in a circuit from main battery through the windings of the two relays connected in multiple, conductor 2109 and the upper contacts of cam 2100^r to sub-battery. Upon the operation of these two relays the connections to the ring-back keys 1012 and 1013 is reversed, whereby the sending of the proper ringing current to the line is insured. The reason for the reversal of the contacts of the keys 1012 and 1013 is to reverse the application of the positive and negative ringing current to the line so as to compensate for the reversal of the line terminals in the final selector as explained in

connection with party line ringing. These ring-back keys may be used by the operator when she is listening-in on a regular connecting unit such as above described and 5 illustrated in Figs. 9 and 12. In this event, it is obvious that the transposition of the ringing current in order to properly actuate the bell at the subscriber's station must be done at the ring-back keys because the 10 line appears but in one of the terminals in the line finders.

When the no-test key 1560 is used, then it is unnecessary to depress the start key as the relay 1693 will be energized under 15 the control of the key 1560. The final no-test relay 1906 operates while the incoming sequence switch 2200 is in position 14, and the sender sequence switch is passing through positions 11 to 15, the circuit of this 20 relay being closed from main battery, through the cutoff relay of the calling line, terminal 1917, wiper 1916, the lower right-hand contact of cam 1900^L, the winding of relay 1906, the lower contacts of cam 1900^K, 25 the right-hand armature and back contact of relay 1902, the lower left-hand contact of cam 1900^G, the lower left-hand contact of cam 1900^H, conductor 1815, terminal 2204 and the wiper 2203 of the incoming selector, 30 the upper left-hand and lower right-hand contacts of cam 2200^P, conductor 2050, the upper right-hand and lower left-hand contacts of cam 2000^L, the right-hand front contact and armature of relay 2019, conductor 35 1238, terminal 1304 and wiper 1310 of the cord finder, the lower left-hand and upper right-hand contacts of cam 1300^E, conductor 1324, the left-hand contact of cam 1400° and the left-hand front contact and armature of relay 1415 to ground.

While the incoming sequence switch 2200 is in positions 14 to 18, the call signal circuit is closed through to the district circuit, the call signal flashing until the district sequence switch 2000 moves out of position 2, 45 when it lights steadily until the call is disconnected. The circuit may be traced from sub-battery, at cam 2100^C, the upper left-hand contact of cam 2100^D, lamp 2107, resistance 2108, conductor 2119, the lower right-hand and upper left-hand contacts of cam 2200^N, conductor 2037, the upper left-hand and lower right-hand contacts of cam 2000^H, and interrupter 2060 to ground. 50 When the sequence switch 2000 reaches position 3, and until it moves out of position 18, the circuit is closed, as above traced, but from conductor 2037, it passes through the upper right-hand and lower left-hand contacts of cam 2000^T to ground. When the incoming sequence switch 2200 reaches position 16, a circuit is closed from main battery through the power magnet of sequence switch 2000, the lower left-hand contact of 55 cam 2000^P, conductor 2051, the lower right-

hand and upper left-hand contacts of cam 2100°, conductor 2118, the right-hand contacts of cam 2200°, and the left-hand front contact and armature of relay 2210 to sub-battery. The district sequence switch 2000 70 moves out of position 1 and into position 2. A circuit is then closed from sub-battery, through the lower right-hand contact of cam 2000^P, the upper right-hand contact of cam 2000^Q, the right-hand armature and back 75 contact of relay 2001, the lower contacts of cam 2000^F, the left-hand armature and back contact of relay 2015, the upper right-hand and lower left-hand contacts of cam 2000^W, conductor 2045, the upper left-hand and lower right-hand contacts of cam 2100^Q, conductor 980, the upper left-hand and lower right-hand contacts of cam 1300^F and the winding of relay 1314 to main battery. The 80 relay 1314 becomes energized and causes in 85 the above-described manner the connection of an idle sender with the double ended connecting unit. The relay 2019 is energized upon the seizure of this connecting unit by a cord finder, the circuit extending from 90 sub-battery through the left-hand armature and back contact of relay 2001, the left-hand contacts of cam 2000°, winding of relay 2019, conductor 1239, terminal 1301, wiper 1307, left-hand contacts of cam 1300^V, the 95 left-hand armature and front contact of relay 1399, the lower contacts of cam 1300^G and the winding of relay 1399 to main battery. Upon the energization of relay 1314, the sender sequence 100 switch 1300 moves out of position 2 and into position 3, in the above-described manner, to await the setting of the class and district brush registers. Lamp 2020 is caused to flash now under the control of the interrupter 2060, the circuit being closed through the right-hand contacts of cam 2000^U, the lamp 2020, resistance 2021, the right-hand contacts of cam 2000^V, and the left-hand 105 front contact and armature of relay 2019 to 110 sub-battery.

The operations to take place after the depression of the numerical keys are the same as in the first assumed case, except for the action of the relay 1411 in the sender. 115 When a local call is made, this relay operates regardless of what line the final selector may seize, because main battery is connected through resistance 2023, the upper contacts of cam 2000^U, the right-hand back contact and armature of relay 2019, conductor 1238, terminal 1304, wiper 1310, the lower left-hand and upper right-hand contacts of cam 1300^E, conductor 1324, the upper right-hand contacts of cam 1400°, the right-hand armature and front contact of relay 1410, and the right-hand winding of relay 1411 to ground.

The subscribers may now converse by means of the double-ended connecting unit through the conductors indicated in heavy lines.

It sometimes happens that the operator having established a connection over a regular connecting unit may desire to re-establish such connection by means of one of the 5 special units. When she does this, the calling line is held busy by its connection to the regular connecting unit over a finder circuit. The operator will then listen in on a double ended unit by actuating key 2104 10 as above described, and write down on the keyboard the number of the calling line. When she does this at this time, she will actuate the no-test key 1560. Upon the actuation of this key, a circuit is closed from 15 main battery through the winding of relay 1415, conductor 1337, the left-hand front contact and armature of the relay 1317, the lower contact of cam 1350^U, conductor 1352, and the left-hand back contact of the no-test 20 key 1516 to sub-battery, causing the relay 1415 to become energized. The relay 1415 is maintained in its energized condition from main battery, through its winding, right-hand front contact and armature, and conductor 1336 to the locking circuit above 25 described. When the call has progressed to the extent that the sequence switch 2200 is in position 14, the sequence switch 1900 in position 7 and the sequence switch 1400 is 30 moving through positions 11 to 15, a circuit is closed from ground, the left-hand armature and front contact of the relay 1415, the left-hand contact of the cam 1400°, conductor 1324, the upper right-hand and lower 35 left-hand contacts of cam 1300^E, wiper 1310, terminal 1304, conductor 1238, the right-hand armature and front contact of the relay 2019, the lower left and upper right contacts of cam 2000^L, conductor 2050, the lower 40 right-hand and upper left-hand contacts of cam 2200^P, wiper 2203, terminal 2204, conductor 1815, the lower left-hand contact of cam 1900^H, the lower left-hand contact of cam 1900^G, the right-hand back contact and 45 armature of relay 1902, the lower contacts of cam 1900^K, the winding of relay 1906, the lower contact of cam 1900^L and terminal 1917 to sub-battery or main battery through the cutoff relay of the line. The relay 1906 50 becomes energized and is maintained in this condition by ground through its right-hand armature, front contact and winding, to the sleeve of the line. The sequence switch 1900 is moved to position 13, under the control 55 of a circuit from sub-battery through the left-hand armature and front contact of relay 1906, the lower right-hand contact of cam 1900^B, the lower contact of cam A, and the power magnet 1900 to main battery, and 60 hence to the talking position as previously described. The sequence switch 2000 is moved out of position 14 in the manner above described, and the connection is therefore established to the calling line, regardless 65 of the busy condition of such line. It

should be noted that when the operator is setting up a connection at the distant end (Fig. 20) of the special unit, the relays 1314 and 1317 will not be energized and therefore the relay 1415 cannot become energized even though the no-test key should be actuated. In other words, the no-test key is effective only on the special incoming end, (Fig. 22) of the special unit and not under any other condition. 70

Single group starting circuit.

In those finder frames wherein the operators are all arranged in one large group, the circuits should be arranged as shown in the figures indicated in brackets in Fig. 26. This arrangement of circuits is substantially the same as that for the two group starting circuit arrangement previously described, except that the starting circuit and 80 finder allotter circuit shown in Figs. 2 and 4 are replaced by Figs. 23 and 24, respectively. In Figs. 23 and 24, the relays, lamps and keys perform the same functions as the relays, etc., shown in Figs. 2 and 4 and designated by reference numerals having the same last two digits. For example, the relays 2300, 2301, and 2303 correspond to relays 200, 201 and 203. Relay 224 corresponds to the relays 2324 and 2324^a. It will 85 be noted that certain relays shown in Fig. 24 corresponds with relays shown in Fig. 2. For example, relays 2443, 2463 and 2420 correspond to relays 243, 263 and 220 of Fig. 2; similarly lamps 2416 and 2417 correspond to lamps 216 and 217. The key 290 of the two group arrangement appears in the single group arrangement as two keys 90 2490 and 2490^a. The overflow relays 2401, 2402, 2403 and 2404 are equivalent to the 95 relays 401, 402, and 403, and the lamps 407 and 408 are represented by the lamps 2407 and 2408 in the single group arrangement. The general operation of the single group 100 starting circuit as regards the starting of a line finder, and the general arrangement of the finder allotting circuit, is exactly the same in the single group arrangement as in the two group arrangement, and the circuits, as previously described for starting line 105 finders and for giving the various alarm signals, may be traced in Figs. 23 and 24 in the same manner as previously described. The finder allotting circuit shown in Fig. 24 indicates two finder circuits, A and X of a 110 group of finders on the front of the frame, and two finder circuits, A' and X' of a group of finders on the rear of the frame. The allotting circuits of the finders on the two sides of the frame are connected together through the cams of sequence switches 2400 and 2450. Normally, the allotting circuits of the two sides of the frame are so connected as to provide one large 115 group of circuits allotted in the same man- 120

ner as one group of finder circuits of the two group arrangement. If, however, it is desired to shut down the back of the frame and to confine calls to the finder circuits on the front of the frame, the sequence switch 5 2450 is caused to move to position 3, in which position the allotting circuit for the finders on the front of the frame is closed up and includes only the finders on the front 10 side of the frame. The allotting circuit on the back of the frame is disconnected from the front of the frame. Hence it is possible to make any tests necessary on the finder circuits on the back of the frame without interfering with the service given by the 15 finders on the front of the frame. When it is desired to restore the service to the finders on the back of the frame, the sequence switch 2450 is caused to move to position 8, in which position it is arrested until no calls 20 are passing through the starting circuit, and the finder circuits are in such condition that when the sequence switch 2450 moves into position 1, there will be but one finder circuit on both the front and back of the 25 frame which is in position 2. Similarly, the sequence switch 2400 may be moved so as to confine the calls to the back of the frame and sever the finder circuits on the front of the frame from those on the back of the 30 frame. The sequence switch 2400 may be operated in a manner similar to the sequence switch 2450.

The detailed operation of the sequence 35 switches 2400 and 2450 and their control by relays 2443 and 2453, corresponds to the operation of the structure described in patent to Samuel B. Williams, jr., and Ralph L. Quass, No. 1,324,365, granted December 9, 40 1919; the sequence switches 500 and 600 of the mentioned patent corresponding to the sequence switches 2450 and 2400, respectively, of Fig. 24; the relays 133, 135, 134 and 136 of the patent corresponding to the 45 relays 2453, 2443, 2473 and 2463, respectively, of Fig. 24. To further enable the comparison of the circuits of the mentioned patent with the herein disclosed circuits, it is noted that relays 137 and 138 of the 50 patent correspond to relays 2345 and 2365, respectively, of Fig. 23. The function of the key 2380 is similar to the key 280 of Fig. 2, and merely serves to replace the relays 2300, 2301, 2303, 2345 and 2365 with similar relays in the event that the regular relays are 55 in trouble. The equivalent of this key is not indicated in the patent. The keys 143 and 144 of patent correspond to keys 2490^A and 2490 respectively of Fig. 24. In the patent, 60 no indication is made of the alarms involved in the single group starting circuit, as indicated on Figs. 23 and 24 and as previously identified and described. For this reason, certain relay contacts and certain sequence 65 switch cam contacts are not present in the

structure disclosed in the patent, that are shown in Figs. 23 and 24, but the operation of the sequence switches 500 and 600 of the patent is identical with that of sequence switches 2450 and 2400 of Fig. 24. 70

Fig. 25 shows the general arrangement of the horizontal and vertical series leads through the back contacts of the relays 603 for the vertical leads, and a left-hand normally closed contact of the relay 602 for the horizontal leads. The contacts of keys 2500, 2501 and 2502 shown singly, are in reality contacts sufficient in number to provide for the three leads 604, 605 and 606 for each operator's position. As shown in Fig. 80 25, the operator's group is divided into two parts, those for the odd positions indicated as 2550, and those for even positions indicated as 2560. There are two vertical lines for each finder frame, one for the front and one for the back of the frame. For example, the frame 2530 is the front of the same frame as 2540, and 2531, similarly is the front of the same frame as 2541, which is the back. This holds good also for 2532 90 and 2542, and 2533 and 2543. The operator group 2550 is normally connected in the vertical series on the fronts of the frames through the selecting relays, shown as circles at 2510, 2511, 2512 and 2513, and is the preferred one over the even group of operators 2560 in this part of the operator selecting circuit. However, on the back of the frames 2540, 2541, 2542, 2543, the horizontal lead is led through the contacts of the keys 100 2500 to the selecting relays 2514, 2515, 2516 and 2517, but in this part of the operator selecting circuit, odd operators 2550 are no longer the preferred, the even operator group 2560 having the preference. The selecting leads for the even group of operators 2560 are connected so as to be preferred in that part of the selecting circuit serving 2540, 2541, 2542 and 2543, and are chosen after the odd group of operators in 105 that part of the selecting circuits serves the frames 2530, 2531, 2532 and 2533. By means of the keys 2500, 2501 and 2503, it is possible to test the selecting relays of the operator selecting circuit of the odd group 110 of operators and give telephone service by means of switches and circuits on the backs of the frames, represented by finder groups 2540, 2541, 2542 and 2543. In this event, the keys 2500, 2501 and 2503 will be actuated. With this arrangement, all of the selecting relays on the front of the frame can 115 be tested. Similarly, if it is desired to test the relays associated with the finder circuits on the backs of the frames, the keys 2500, 2502 and 2504 are actuated and service is given through the fronts of the frames. In the making of these tests the calls must be 120 confined to one side of the frame or the other. For example, in testing each select- 125 130

ing relay on the fronts of the frames, the calls are confined to the back of the frame and key 2490^A should be operated. Similarly, when the relays associated with the 5 finder circuits on the back of the frame are to be tested, the calls are confined to the front of the frame and key 2490 operated.

What is claimed is:

1. In combination, a plurality of switching 10 devices, a variably operable mechanism for selectively operating said devices, a switch for associating said mechanism with any one of said devices, automatic means for actuating said switch to associate said mechanism with certain ones of said devices, and means operable at will for actuating said switch to associate said mechanism with a certain other one of said devices.
2. In combination, a plurality of switching 20 devices having movable and stationary contacts, a controlling mechanism, means for adjusting said mechanism for variably operating the movable contacts of said switching devices, a telephone line terminating at its incoming end in stationary contacts of one of said devices and at its outgoing end in movable contacts of another one of said devices, another telephone line terminating at its incoming end in movable 25 contacts of a switching device, and means for operatively associating said mechanism with either telephone line.
3. In combination, a plurality of switching 30 devices having movable and stationary contacts, a controlling mechanism, means for adjusting said mechanism for variably operating said movable contacts, a telephone line terminating at one end in stationary contacts of one of said devices and at the 35 other end in movable contacts of another one of said devices, another telephone line terminating at both ends in movable contacts of switching devices, and means for operatively associating said mechanism with either telephone line.
4. In a telephone exchange system, two 40 groups of lines, a trunk line, a switching device for connecting said trunk line with a line of one of said groups, another switching device for connecting said trunk line with a line of the other group, and a single means 45 controllable at will for selectively operating said switching devices to connect through said trunk line a line in one group with a line in the other group.
5. In a telephone exchange system, two 50 groups of lines, a trunk line, a switching device for connecting said trunk line with a line of one of said groups, another switching device for connecting said trunk line with a line of the other group, a controlling 55 mechanism for said devices, means for associating said controlling mechanism with said trunk line, and means operable thereupon for selectively operating said switch-

ing devices under the control of said mechanism to connect through said trunk line a line in one group with a line in the other group.

6. In a telephone exchange system, calling 70 lines and called lines, a trunk line, a switching device for connecting said trunk line with a calling line, another switching device for connecting said trunk line with a called line, a controlling mechanism, means for adjusting said mechanism in accordance with the designation of the calling line, another controlling mechanism, means for adjusting said other controlling mechanism in accordance with the designation of 75 the called line, means for associating said first-mentioned controlling mechanism with said first-mentioned switching device for controlling its operation, and means operable upon the completion of the operation of said first-mentioned switching device for associating said second-mentioned mechanism with said second-mentioned switching device for controlling its operation. 80

7. In a telephone exchange system, two groups of lines, a trunk line, a switching device for connecting said trunk with a line of one of said groups, another switching device for connecting said trunk line with a line of the other group, a plurality of switch controlling mechanisms, and means for operating any one of said mechanisms for selectively operating said switching devices to connect through said trunk 90 line a line in one group with a line in the other group. 95

8. In a telephone exchange system, two groups of lines, a trunk line, a plurality 100 of switching devices for connecting one end of said trunk line with a line of one of said groups, another plurality of switching devices for connecting the other end of said trunk line with a line of the other group, and a controlling mechanism for successively operating said switching devices to connect through said trunk line a line in one group with a line in the other group. 110

9. In a telephone exchange system, two groups of lines, a trunk line, a plurality 115 of switching devices for connecting one end of said trunk line with a line of one of said groups, another plurality of switching devices for connecting the other end of said trunk line with a line of the other group, a controlling mechanism, means for associating said mechanism with said trunk line, means operable thereupon for causing said mechanism to successively control through said trunk line the first-mentioned 120 plurality of switching devices, and means operative thereupon for causing said mechanism to control through said trunk line the operation of said other plurality of 125 switching devices. 130

10. In a telephone exchange system, two groups of lines, a trunk line, a switching device for connecting one end of said trunk line with a line of one of said groups, 5 another switching device for connecting the other end of said trunk line with a line of the other group, a controlling mechanism, means for adjusting said mechanism for selectively operating said switching devices 10 to connect through said trunk line a line in one group with a line in the other group, means for operatively associating said mechanism with one of said devices, and means operable upon the completion of the 15 operation of said one of said devices for operatively associating said mechanism with the other device. 11. In a telephone exchange system, two groups of lines, a trunk line, a series of 20 switching devices for connecting one end of said trunk line with a line of one of said groups, another series of switching devices for connecting the other end of said trunk line with a line of the other group, and a 25 controlling mechanism for operating first one of said series of switching devices and then the other of said series of switching devices to connect through said trunk line a line in one group with a line in the other 30 group. 12. In a telephone exchange system, two groups of lines, a trunk line, a series of switching devices for connecting one end of said trunk line with a line of one of said 35 groups, another series of switching devices for connecting the other end of said trunk line with a line of the other group, a controlling mechanism, means for adjusting said mechanism for successively operating 40 the switching devices of a series, and means for operatively associating said mechanism with the devices of either series independently of the other series. 13. In a telephone exchange system, two 45 groups of lines, a trunk line, a series of switching devices for connecting one end of said trunk line with a line of one of said groups, another series of switching devices for connecting the other end of said trunk 50 line with a line of the other group, a controlling mechanism, means for adjusting said mechanism for successively operating the switching devices of a series, means for operatively associating said mechanism with 55 the devices of one of said series, and means operative upon the operation of all of said devices in said one of said series for operatively associating said mechanism with the devices of the other series. 14. In a telephone exchange system, two 60 groups of lines, a trunk line, a switching device for connecting one end of said trunk line with a line of one of said groups, another switching device for connecting the 65 other end of said trunk line with a line of the other group, a controlling mechanism, means for adjusting said mechanism for selectively operating said switching devices to connect through said trunk line a line in one group with a line in the other group, means for operatively associating said mechanism with one of said devices, and means operable upon the completion of the operation of said one of said devices for operatively associating said mechanism with the other device. 15. In a telephone exchange system, two groups of lines, a trunk line, a series of switching devices for connecting one end of said trunk line with a line of one of said groups, another series of switching devices for connecting the other end of said trunk line with a line of the other group, a plurality of controlling mechanisms, means associated with each mechanism for adjusting it to successively control the operation of the switching devices of either series, an automatic hunting switch for each of said mechanisms, contacts for each of said hunting switches representing said trunk line, means for operating an idle one of said hunting switches to connect its associated mechanism with the contacts representing said trunk line, means operative thereupon for operatively associating the mechanism with said one of said series of devices, means operative upon the operation of all the devices in said one of said series for restoring said last-mentioned hunting switch, means operable thereupon for actuating an idle hunting switch to connect its associated mechanism with the contacts representing said trunk line, means operative thereupon for operatively associating said last-mentioned mechanism with the other series of devices, and means actuated upon the operation of all of said devices in said other series for restoring said hunting switch. 16. In a telephone exchange system, two lines, a switching device operable to select one of said lines, another switching device operable to select the other one of said lines, a switch controlling mechanism adjusted in accordance with the designation of one of said lines, another switch controlling mechanism adjusted in accordance with the designation of the other one of said lines, a switch having a plurality of operating positions, means actuated in one of said operating positions for associating said first-mentioned switching device with said first-mentioned controlling mechanism, and means actuated in another operating position of said switch for associating said second-mentioned switching device with said second-mentioned controlling mechanism. 17. In a telephone exchange system, a group of lines, a switching device operable to select one of said lines, another switching device operable to select another one of said lines, a switch controlling mechanism adjusted in accordance with the designation of one of said lines, another switch controlling mechanism adjusted in accordance with the designation of the other one of said lines, a switch having a plurality of operating positions, means actuated in one of said operating positions for associating said first-mentioned switching device with said first-mentioned controlling mechanism, and means actuated in another operating position of said switch for associating said second-mentioned switching device with said second-mentioned controlling mechanism.

trolling mechanism adjusted in accordance with the designation of the other one of said lines, a switch having a plurality of operating positions, means actuated in one of said operating positions for associating said first-mentioned switching device with said first-mentioned controlling mechanism, and means actuated in another operating position of said switch for associating said second-mentioned switching device with said second-mentioned controlling mechanism.

18. In a telephone exchange system, a group of lines, a series of switching devices successively operable to select one of said lines, another series of selectively operable switching devices successively operable to select another one of said lines, a switch controlling mechanism adjusted in accordance with the designation of said one of said lines, another switch controlling mechanism adjusted in accordance with the designation of said other of said lines, a switch having a plurality of operating positions, means operable in certain operating positions of said switch for operatively associating said first-mentioned controlling mechanism with said first-mentioned series of switching devices, and means actuated in certain other operating positions of said switch for operatively associating said second-mentioned controlling mechanism with said other series of switching devices.

19. In a telephone exchange system, two groups of lines, means for connecting a line of one of said groups with a line of the other group, other means for connecting said last-mentioned line with a line of said groups, and separate means for connecting a line of said one of said groups with a line of the other group.

20. In a telephone exchange system, two groups of lines, means for connecting a line of one of said groups with a line of the other group, other means for connecting said last-mentioned line with a line of said one of said groups, and automatic means for connecting a line of said one of said groups with a line of the other group.

21. In a telephone exchange system, two groups of lines, automatic means for connecting a line of one of said groups with a line of the other group, automatic means for connecting said last-mentioned line with a line of said one of said groups, and separate selectively operable means for connecting a line of said one of said groups with a line of the other group.

22. In a telephone exchange system, two groups of lines, means responsive to the initiation of a call for connecting a line of one of said groups with a line of the other group, selectively operable means for connecting said last-mentioned line with a line of said one of said groups, and separate selectively operable means for connecting a

line of said one of said groups with a line of the other group.

23. In a telephone exchange system, calling and called lines, trunk lines, means responsive to the initiation of a call for connecting the calling line with one of a plurality of trunk lines, switching devices associated with said trunk lines, a variably adjustable mechanism for selectively operating said devices, means including said mechanism for operating the device associated with the last-mentioned trunk line for extending said trunk line towards a called line, another switching device associated with a certain one of said trunk lines, and means including said mechanism for operating said last-mentioned device to extend said certain one of said trunk lines with a calling line.

24. In a telephone exchange system, an operator's position, a group of subscribers' lines, another group of lines, subscriber controlled means for connecting a line of said group with a line of said other group, operator controlled means for connecting said last-mentioned line with a subscriber's line and separate operator controlled means for connecting a subscriber's line with a line of the said other group.

25. In a telephone exchange system, an operator's position, two trunk lines at said position, subscribers' lines, means controlled by a subscriber for connecting his line with one of said trunk lines, operator controlled means for connecting said one of said trunk lines with a subscriber's line, and separate operator controlled means for connecting a subscriber's line with the other one of said trunk lines.

26. In a telephone exchange system, an operator's position, two trunk lines at said position, each trunk line having an incoming and an outgoing end, subscribers' lines, means controlled by a subscriber for connecting his line with the incoming end of one of said trunk lines, operator controlled means for connecting the outgoing end of said one of said trunk lines with a subscriber's line, and other operator controlled means for connecting the incoming end of the trunk line with a subscriber's line.

27. In a telephone exchange system, an operator's position, a group of trunk lines, another trunk line, each trunk line having an incoming and an outgoing end, subscribers' lines, means controlled by a subscriber for connecting his line with the incoming end of any one of said group of trunk lines, a selectively operable switching device associated with the outgoing end of each trunk line of said group, a selectively operable switching device associated with the incoming end of said other trunk line, variably operable mechanism at said operator's position arranged to control the opera-

tion of said switching devices, means for connecting said mechanism with the trunk line of said group to which a subscriber's line has been extended, and means for connecting said mechanism with said other trunk line.

28. In a telephone exchange system, subscribers' lines, an operator's position, means controlled by a subscriber for connecting his line with said position, an operator controlled selectively operable switching device for connecting the position with a called line, and a separate operator controlled selectively operable switching device for connecting the position with a calling line.

29. In a telephone exchange system, a calling and a called line, an automatic switching device operable upon the initiation of a call, a selectively operable switching device, a connection established between said lines through both said devices, and a connection established between said lines only through said selectively operable switching device.

30. In a telephone exchange system, a calling and a called line, a switch, two selectively operable switching devices, trunk lines, means for operating said switch to connect a trunk line with the calling line, means operative thereupon for actuating one of said devices to connect said last-mentioned trunk line with the called line, means for operating any one of said devices to connect a trunk line with the calling line, and means operative thereupon for actuating one of said devices to connect said last-mentioned trunk line with the called line.

31. In a telephone exchange system, a calling and a called line, a switch, a plurality of switching mechanisms, trunk lines, means for operating said switch to connect the calling line with a trunk line, means operative thereupon for actuating one of said mechanisms for connecting said last-mentioned trunk line with the called line, means for operating one of said mechanisms to connect a trunk line with the calling line, and means operative thereupon for actuating a mechanism to connect said last-mentioned trunk line with said called line.

32. In a telephone exchange system, a calling and a called line, an automatic hunting switch, a plurality of selectively operable switching devices, trunk lines, means for operating said hunting switch to connect a trunk line with the calling line, means operative thereupon for actuating one of said devices to connect said last-mentioned trunk line with the called line, means for actuating one of said devices to connect a trunk line with the calling line, and means operative thereupon for actuating one of said devices to connect said last-mentioned trunk line with the called line.

33. In a telephone exchange system, a calling and a called line, a line finder and a

trunk hunting switch responsive to the initiation of a call on the calling line for extending the same, a selectively operable switch, a connection between said lines established through said finder and trunk hunting switch and selectively operable switch, and a connection established between said lines only through said selectively operable switch.

34. In a telephone exchange system, a calling and a called line, a line finder and a trunk-hunting switch, selectively operable switching means, a connection between said lines established through said finder, trunk-hunting switch and switching means, and a connection established between said lines only through said switching means.

35. In a telephone exchange system, a calling and a called line, a hunting switch, a plurality of selectively operable switching devices, a connection between said lines established through said switch and devices, and a connection established between said lines only through said devices.

36. In a telephone exchange system, a calling and a called line, an automatic switching device operable upon the initiation of a call, selectively operable switching devices, a talking circuit established between said lines through said automatic and selectively operable switching devices, means operable through said circuit for controlling said devices, another talking circuit established between said lines only through said selectively operable switching devices, and means operable through said other circuit for controlling the operation of said selectively operable switching devices.

37. In a telephone exchange system, a calling and a called line, a plurality of selectively operable switching devices, a variably adjustable mechanism for controlling the operation of said devices, a connection established between said lines by operating a certain number of said selectively operable switching devices, and a connection established between said lines by operating a different number of the same selectively operable switching devices used in the first mentioned connection.

38. In a telephone exchange system, a calling and called line, a plurality of selectively operable switching devices, a variably adjustable controlling mechanism for controlling the operation of said devices, means for operatively associating said controlling mechanism with a certain number of said selectively operable switching devices for controlling the operation of said devices to establish a connection between said lines, and means for operatively associating the said controlling mechanism with a larger number of said switching devices for controlling the establishment of a connection between said lines.

39. In a telephone exchange system, a calling and a called line, a plurality of selectively operable switching devices, a variable adjustable controlling mechanism for controlling the operation of said devices, and an automatic hunting switch for operatively associating said controlling mechanism with a certain number of said selectively operable switching devices for controlling the operation of said devices to establish a connection between said lines, said automatic hunting switch serving also to operatively associate said controlling mechanism with a larger number of switching devices for controlling the establishment of a connection between said lines.

40. In a telephone exchange system, a calling and a called line, groups of district, incoming and final selectors, means for establishing a connection between said lines through a district, an incoming and a final selector, a special incoming and a special district selector, and means for establishing a connection between said lines through said special incoming, special district selector, an incoming and two final selectors.

41. In a telephone exchange system, a calling and a called line, switching devices including an incoming and a final selector, means for connecting said calling line with said incoming selector, means operable thereupon for causing said incoming selector to connect said calling line with said final selector, other means for connecting said line with said final selector, and means operable thereupon for connecting the final selector to said incoming selector.

42. In a telephone exchange system, a calling and a called line, a district, an incoming and a final selector, means for operating said three selectors to interconnect said lines, and means including said incoming and final selectors only for interconnecting said lines.

43. In a telephone exchange system, a calling and a called line, a trunk line, means for rendering busy said calling and called lines, a selectively operable switching device associated with each end of said trunk line, means for operating one of said switching devices to select and seize said calling line, means associated with the other switching device for operating it to select and seize the called line, means associated with each switching device for preventing the associated device from seizing a busy line, and means for operating one of said switching devices irrespective of the busy or idle condition of the called line.

44. In a telephone exchange system, calling and called lines, a group of selectively operable switching devices, means including any two of said devices for interconnecting said calling and called lines, means for rendering said lines busy, testing means

associated with each one of said switching devices, and means for rendering ineffective the operation of the testing means associated with one of said switching devices used in the establishment of said connection. 70

45. In a telephone exchange system, a calling and a called line, means including two selectively operable switching devices for establishing a connection between said lines, means for rendering said lines busy, testing means associated with each of said selectively operable switching devices, means common to said switching devices operable to render the operation of said testing means ineffective, and means for operatively associating said last-mentioned means only with one of said devices in the establishment of a connection. 75

46. In a telephone exchange system, a calling and a called line, a plurality of selectively operable switching devices, means for operating said devices for interconnecting said lines, means for restoring certain ones of said devices and maintaining the other devices in their actuated position, and means for restoring said other devices and maintaining said certain devices in their actuated position. 80

47. In a telephone exchange system, a calling and a called line, a trunk line, a plurality of switching devices for connecting said calling line with one end of said trunk line, a plurality of switching devices for connecting the other end of said trunk line with said called line, means for restoring said other plurality of switching devices and maintaining said plurality of switching devices actuated, and means for restoring said plurality of switching devices and maintaining said other plurality of switching devices actuated. 100

48. In combination a connecting circuit, a telephone line, an automatic switching means and a selectively operable switching device, each arranged for interconnecting said line and said circuit, testing means associated with said switching device and said automatic switching means, means actuated in connecting said telephone line to said connecting circuit for producing a busy test condition on said line to prevent the establishment of other connections therewith, a switch associated with said connecting circuit, means controlled by said switch for withdrawing said busy test condition and holding operated said automatic switching means, a test magnet brought into operative relation with said connecting circuit by the operation of said switch, said test magnet being responsive to the establishment of any other connection with said extended line, and circuit controlling apparatus controlled by said test magnet. 110

49. In combination, a connecting circuit, a telephone line, a selectively operable

- switching device for establishing connection with said line, testing means associated with said switching device, means for extending said telephone line to said connecting circuit, operative thereupon for producing a busy test condition on said line, means for actuating said last-mentioned means upon the operation of said switching device, a test magnet responsive to said busy test condition, a switch associated with said connecting circuit for removing said busy test condition, and connecting said test magnet with said extended line without disconnecting said line from said connecting circuit, and circuit extending apparatus controlled by said test magnet. 5
50. In combination, a telephone line, a connecting circuit, an automatic switch for extending said line to said connecting circuit, a selectively operable switching device for completing other connections with said line, busy test means for preventing the successful operation of said selectively operable switching device when said line is extended 20 to said connecting circuit, a holding key associated with said connecting circuit, means actuated by the operation of said holding key for rendering said busy test means inoperative when disconnecting said line from said connecting circuit, a busy signal device associated with said connecting circuit, said busy signal device being responsive to the existence or non-existence of another connection with said extended line, and means 25 for bringing said busy signal device into operative relation with said connecting circuit to which said telephone line is extended. 30
51. In combination, a telephone line, a connecting circuit, an automatic switch for connecting said line with said connecting circuit, automatic selectors for establishing connection with said line, means made operative by the connection of said line with said connecting circuit for preventing the establishment of other connections with said line, means associated with said connecting circuit for rendering said preventing means inoperative without operating said automatic switch to disconnect said line from 40 said connecting circuit, an operator's position apparatus, a switch controlling the connection of the same with said connecting circuit, and means responsive to the existence or non-existence of another connection 45 with said telephone line for controlling the operation of said switch. 55
52. In combination, a connecting circuit, a telephone line extended thereto, a selectively operable switching device for establishing connection with said telephone line, means operable upon the extension of said line to said connecting circuit and upon the connection with said line by said switching device for producing a busy test condition 60 on said line, operator's telephone apparatus, 65
- a listening switch actuated on the extension of said line to said connecting circuit for connecting said operator's telephone apparatus with said circuit, an operator's controlling switch associated with said connecting circuit, means actuated by the actuation of said listening switch for operating said operator's controlling switch, a holding key associated with said connecting circuit, means actuated on the operation of said holding key for removing said busy test condition produced in the extension of said line to a connecting circuit while holding the connection of said line with said connecting circuit, means actuated on the operation of said holding key for moving said listening switch to disconnect said operator's telephone apparatus from the connecting circuit, means actuated on the operation of said holding key for restoring said operator's 70 controlling switch to normal, a test magnet responsive to the non-existence of another connection with said telephone line, means under the joint control of said holding key and said listening switch for connecting said test magnet to said extended line, means under the joint control of said magnet and said listening switch for reconnecting said operator's telephone apparatus with said connecting circuit, and means actuated during 75 the operation of said holding key for preventing said subsequent movement of said listening switch from actuating said apparatus controlling switch. 80
53. In combination, a connecting circuit, a telephone line extended thereto, a selectively operable switching device for establishing connection with said line, means operable on the extension of said line to a connecting circuit or upon the connection with 85 said line by said switching device for producing a busy-test condition upon said line, class-of-service operating means associated with said line, a class-of-service indicating device associated with said connecting circuit, operator's telephone apparatus, a listening switch for connecting said telephone apparatus and said class-of-service indicating device with said connecting circuit, a holding key for removing said busy test condition from said extended line while holding the connection of said line with said connecting circuit, and means associated in the operation of said holding key for preventing 90 the operation of said listening key from connecting said class-of-service indicating device with said connecting circuit. 95
54. In a telephone exchange system, a calling and a called station, lines leading to said stations, means for interconnecting said stations, a controlling mechanism common to said interconnecting means for controlling the operation thereof, testing means associated with said controlling mechanism 100 for determining the busy or idle condition 105
- 110
- 115
- 120
- 125
- 130

of the line leading to the called station, and other testing means for determining the location of the called station with regard to the calling station.

- 5 55. In a telephone exchange system, a calling and a called station, lines leading to said stations, means including a plurality of selectively operable switching devices for interconnecting said lines, a controlling mechanism for controlling the operation of said devices, means for rendering said called line busy, testing means associated with said selectively operable switching device responsive to the condition of the called line, other testing means associated with said controlling mechanism for determining the relative location of said calling and called stations, and a signal controlled by said other testing means.
- 10 56. In combination, a plurality of groups of selectively operable switching devices, a finder switch having switch terminals arranged in groups, connecting circuits terminating at one end on said devices and at the other end in a corresponding group of switch terminals, and means independent of said switch for selecting an idle group of switching devices and causing said finder switch to select a terminal in the corresponding group.
- 15 57. The combination with a plurality of finder switches having terminals arranged in groups, said switches being adapted for group and individual terminal selection, of a selecting magnet for each group common to all of the switches, means controlled by each of said magnets for causing an operated switch to select the corresponding group, a plurality of groups of selectively operable switching devices, groups of circuits extending from corresponding groups of terminals on all of said switches and leading to corresponding groups of switching-devices, and means independent of said finder switches for selecting a particular idle group of switching devices and operating the corresponding common selecting magnet.
- 20 58. The combination with a plurality of groups of selectively operable switching devices, of test means associated with each group and responsive to the busy or idle condition of the corresponding group, a switch for extending a connection to any of said groups, a selecting magnet associated with said switch for each of said groups, means controlled by each of said magnets for causing said switch to select the corresponding group, and common selecting apparatus responsive to the test means of the various groups and controlling said selecting magnets, said apparatus being adapted when operated to select an idle group and cause the operation of the corresponding test magnet.
- 25 59. The combination with a plurality of

groups of selectively operable switching devices, a selector switch cooperating therewith and provided with a selecting magnet for each of said groups, selecting means independent of said switch for selecting an idle group of devices and actuating the corresponding selecting magnet on said switch, means for operating said selecting means, and means for causing said switch to select a switching device of the selected group.

60. The combination with a plurality of selectively operable switching devices, a plurality of selector switches having groups of terminals with which the various groups of switching devices are connected and brushes for engaging the terminals of said groups, a magnet common to all of the switches for each group of terminals, means controlled by each magnet for causing the switch to select the corresponding group, and means for selecting a particular group of switching devices and actuating the common selecting magnet of the group corresponding to said group of switching devices.

61. The combination with a united pair of multiple brush finder switches, each having a plurality of groups of terminals and a set of normally inactive brushes for each group, of groups of lines extending to groups of terminals of one of said switches, groups of selectively operable switching devices connected to groups of terminals of the other switch, a device associated with each group of terminals on each switch for rendering the corresponding set of brushes active, all of said devices on each switch being adapted to be rendered operable simultaneously in the movement of the corresponding switch, selecting apparatus common to said groups of lines and under the control thereof for actuating one of said devices of the corresponding switch and preventing the actuation of the other devices of that switch, and selecting apparatus common to the groups of switching devices and under the control thereof for actuating a single one of the brush controlling devices of the corresponding switch and preventing the actuation of the other devices of that switch.

62. The combination with a plurality of groups of selectively operable switching devices, of a magnet for each group adapted to control the selection of said group by an incoming call, a series of relays one for each of said groups, an energizing circuit for said magnets controlled in contacts of the corresponding relays, said energizing circuit being adapted by the actuation of any of said relays to have its path completed to the associated magnet and cut off from the succeeding relays and magnets of the series, means at each group of switching devices responsive to the busy or idle condition of the group for controlling the actuation of the corresponding relay, and means made opera-

tive in the initiation of a call for closing said energizing circuit.

63. The combination with a plurality of groups of selectively operable switching devices, a group relay for each group, means for operating the same when the corresponding group is unengaged to render the corresponding group selectable, group selecting means under the joint control of said 10 group relays, and means adapted to prevent the selection of more than one group when a plurality of said group relays are operated.

64. The combination with a plurality of selectively operable switching devices arranged in groups, of a finder switch having groups of terminals to which said groups of switching devices are connected, said finder switch being adapted for group and individual device selection, a group relay 15 for each group adapted to control the group selecting operation of said finder switch, an energizing circuit for each group relay extending serially through resting contacts of all the other group relays below it in the 20 series, an operator's position corresponding with each of said groups, and means at each operator's position adapted to control the closure of said energizing circuit, through the corresponding group relay.

65. The combination with a plurality of operators' positions, of a plurality of selector switches at each position, a finder switch adapted for group and individual terminal selection, a plurality of groups of connecting circuits extending from groups of stationary terminals on said switch to the selector switches at corresponding operators' positions, a magnet associated with each group of terminals on said switch adapted 35 to control the selection of the corresponding group, a relay for each of said magnets controlling the operation thereof, an initial energizing path having a branch for each of said relays, means at each operator's position 40 responsive to the busy or idle condition of said position for controlling the branch of said energizing path to the corresponding relay, a permanent energizing path closed by any of said relays in its operation, 45 means operated by the actuation of any of said magnets for opening the initial energizing path for all of said relays, and means for opening said permanent energizing paths at the end of the group selecting operation of said switch.

66. The combination with a plurality of operators' positions each having a group of selectively operable switching devices, of a multiple brush finder switch having groups of stationary terminals to which said groups of switching devices are connected, electromagnetic tripping devices, one for each brush, an energizing circuit for each of said tripping devices, means under 60 the control of the corresponding operator's

position for closing said energizing circuit, and means actuated in the closure of any of said energizing circuits for rendering the other energizing circuits inoperative.

67. The combination with an operator's 70 position, of automatic selectors associated therewith, a plurality of switches having terminals to which said selectors are connected in multiple, normally inactive brushes for each switch, a magnet for each switch adapted when operated to render the associated brushes active, and means actuated in the operation of the magnet of one switch for rendering the magnet of another 75 switch inoperative.

68. The combination with an operator's 80 position, of automatic selectors associated therewith, a plurality of switches having terminals to which said selectors are connected in multiple, a normally inactive 85 brush for each switch, a tripping magnet for each switch adapted when operated to render the associated brush active, calling lines, means for extending the same to the said switches, means made active in extending a 90 line for operating the tripping magnet of the switch to which the line is extended, and means made operative in the actuation of one of said tripping magnets for rendering another of said magnets inoperative.

69. The combination with a plurality of 95 operators' positions, of a plurality of groups of finder switches, each finder switch of each group being adapted for group and individual terminal selection, a group of automatic selectors for each operator's position multiplied to corresponding groups of terminals upon each finder switch of the corresponding group of switches, apparatus associated with the finder switches of each group 100 for controlling the selection by any finder switch of the associated groups of stationary terminals, and means made operative in the actuation of said group selection apparatus for temporarily preventing the selection of 105 a corresponding group of terminals by the finder switches of the same or another finder switch group.

70. The combination with a plurality of 110 operators' positions, of a group of automatic selectors for each position, a plurality of finder switches having groups of terminals and adapted for group and individual terminal selection, each of said groups of 115 selectors being connected in multiple to corresponding groups of terminals on each of said finder switches, selecting apparatus common to said operators' positions and controlling the group selection of said finder switches, means for bringing one of said 120 finder switches under the control of said selecting apparatus, and means for preventing the establishment of such control over another finder switch until the group selection of the first finder switch is completed.

71. The combination with a plurality of selectively operable switching devices, of a plurality of switches for extending connections thereto, selecting apparatus common to said switches and controlled by said switching devices, and means for causing said selecting apparatus to exercise control over a single one of said switches at a time. 70
72. The combination with a plurality of 10 groups of automatic selectors, of a plurality of switches for extending connections thereto, mechanism associated with said switches for controlling the selection by a switch of a particular group of selectors, selecting apparatus common to said groups of selectors and under the control thereof for controlling the aforesaid mechanism, means active in the operation of the selecting apparatus for bringing the mechanism of one of said 20 switches under its control, and means made active in the operation of said switch for enabling the mechanism of another switch to be brought under the control of said selecting apparatus. 90
73. The combination with a plurality of automatic selectors, of means for extending calls thereto, selecting apparatus common to said selectors for predetermining the particular selector to which a call shall be extended, means actuated in the initiation of a call for operating said selecting apparatus, and a switch at each selector responsive to the busy or idle condition thereof for controlling the selective operation of said apparatus. 100
74. The combination with a group of selectors, of means for selecting the same and subsequently extending a call thereto, and a device associated with the group actuated at the completion of the selecting operation for temporarily preventing the extending of another call to the group. 105
75. The combination with a group of automatic selectors, of means for selecting the same to extend a call thereto, and a timing switch associated with said group of selectors for making said group inaccessible to calls, said timing switch being made operative when said group has been selected. 110
76. The combination with a group of automatic selectors, means for selecting said group of selectors and subsequently extending a call thereto, a circuit controlling said selecting means, a switch associated with said selectors for controlling said circuit to render said selecting means inoperative, and means for operating said switch upon the selection of said group of selectors. 115
77. The combination with a plurality of 60 automatic selectors, of means for selecting the same, a sequence switch adapted when operated to render said selectors unselectable, and means for causing the operation of said switch after said selectors have been selected. 125
78. The combination with a group of automatic selectors, of means for selecting the same and subsequently extending a call thereto, a device for rendering said group unselectable, means for operating said device when said group has been selected, and means for restoring said device to its normal condition to render said group again selectable. 70
79. The combination with a group of automatic selectors, of call-extending means adapted to select the same, a switch operated upon the completion of the selecting operation to render said group unselectable for a predetermined interval and then restore the selectability of the group, and apparatus operable at will for preventing said restoration by the switch. 80
80. The combination with an operator's position, of means for selecting said position to extend calls thereto, a plurality of automatic selector switches at said position, and a switch automatically operated to render said selecting means inoperative when all of said selector switches are in use. 90
81. The combination with an operator's position, of a plurality of automatic selector switches therefor, means for extending calls to said operator's position, said means being adapted to select said position and then select one of the associated selector switches, a device for preventing the selection of said position, and means made operative when all of said selector switches are in use for actuating said device. 100
82. The combination with a group of automatic selector switches, of means including connecting links for extending calls thereto, a device associated with said group adapted to render the same inaccessible to incoming calls, operator's telephone apparatus associated with said group, and means automatically operated to disconnecting said operator's telephone apparatus from said group for actuating said device. 105
83. The combination with a plurality of groups of automatic selector switches, of means for extending calls thereto, a device associated with each group operated in the selection of the associated group by a call for diverting other calls to other groups, and means actuated to restore each of said devices to its normal position and again render the associated group accessible when all of said devices have been operated. 110
84. The combination with a plurality of groups of automatic selectors, of a switch for extending calls to said selectors, said switch being adapted first to select a group and then one of the selectors included in said group, a common calling signal associated with each group of selectors, an individual calling signal for each of said selectors, means made operative upon the selection of a group for operating the common signal 120
85. The combination with a group of automatic selector switches, of means for extending calls thereto, a device associated with said group adapted to render the same inaccessible to incoming calls, operator's telephone apparatus associated with said group, and means automatically operated to disconnecting said operator's telephone apparatus from said group for actuating said device. 125
86. The combination with a plurality of groups of automatic selector switches, of a switch for extending calls to said selectors, said switch being adapted first to select a group and then one of the selectors included in said group, a common calling signal associated with each group of selectors, an individual calling signal for each of said selectors, means made operative upon the selection of a group for operating the common signal 130

- associated therewith, and means actuated upon the selection of a selector for operating the individual calling signal of the selector.
- 5 85. The combination with an automatic selector switch, of a connecting circuit terminating therein, operator's telephone apparatus, means for extending a call to said circuit, two switches each of which acts 70 when operated to connect said telephone apparatus with said connecting circuit, one of said switches being relatively slow-acting and the other relatively quick-acting, and energizing circuits for both of said switches 10 completed in the act of extending a connection to said circuit.
86. The combination with a connecting circuit, of a switch adapted to extend a call thereto, an electromagnetic switch associated 20 with said circuit, means for moving said electromagnetic switch out of its normal position by the extension of a call to said circuit, an automatic selector for connecting said circuit with a called line, a magnet for 25 causing the selecting operation of said call-extending switch, and an energizing circuit for the same closed when said electromagnetic switch is in its normal position and said selector is inactive.
- 30 87. The combination with a plurality of automatic selectors, of connecting circuits terminating therein, means for extending calls to said connecting circuits, an automatic listening-in device for each circuit, 35 means responsive to the extending of a call to one of said circuits for operating the associated listening-in device, and means for preventing the extension of a call to any other of said connecting circuits while the 40 listening-in device of one of said circuits is operated.
88. The combination with a plurality of groups of automatic selector switches, of means for extending calls thereto, a signal 45 associated with each group, means responsive to the unavailable condition of all of the groups for preventing the operation of said call-extending means and rendering said signals operable, and means actuated in 50 the initiation of a call for operating said signals.
89. The combination with a group of selectively operable switching devices, of means for extending calls thereto, a signal 55 associated with said group, means responsive to the unavailable condition of said group of switching devices for preventing the operation of said call-extending means and rendering said signal operable, and 60 means actuated in the initiation of a call for operating said signal.
90. A plurality of lines, a plurality of 65 automatic switching devices divided into groups and selectively operable to interconnect calling and called lines, means for ex- tending calling lines to said switching devices, an automatic switch for normally directing calls towards one of said groups of devices, and means responsive to the condition of said one of said groups of devices 70 for operating said automatic switch to direct calls to another of said groups of devices.
91. In combination, a plurality of telephone lines, two groups of finder switches 75 for making connection therewith, means for moving said finder switches, a starting conductor for each group for controlling the switch-moving means of the group, a device for bringing said telephone lines into operative relation alternatively with one or the other of said starting conductors, and a series of selectively operable automatic switching devices for connecting a line finder with a called telephone line.
92. In combination, a plurality of telephone lines, a plurality of selectively operable automatic switching devices divided into groups, a corresponding plurality of groups of finder switches for extending calling lines towards one of said groups of selectively operable switching devices, one of said groups of finder switches being normally 80 in operative relation with said lines, and means responsive to the busy condition of all the finder switches of said group for bringing another group of finder switches into operative relation with said lines.
93. In combination, a plurality of groups of selectively operable automatic switching devices, each group being divided into sub-groups, means for extending calls thereto, a device associated with each sub-group of switching devices responsive to the condition of the devices of the sub-group, apparatus for each group of devices controlled by said devices of the sub-groups included in said group and operated when all of said devices are actuated, and means made operative in the operation of said apparatus for diverting calls from the associated sub-groups 95 of devices.
94. In combination, a plurality of groups of selectively operable automatic switching devices, means for extending calls thereto, said means normally acting to extend calls 100 to one of said groups, and means made active when all of the devices of said group are unavailable for causing said call-extending means to direct calls to the devices of another group.
95. In combination, a plurality of groups of selectively operable automatic switching devices, each group being divided into sub-groups, means for extending calls thereto, said means normally acting to extend calls 105 to one of said groups, and means made active when all of the sub-groups of said last-mentioned group of devices are unavailable for causing said call-extending means to direct calls to the sub-groups of another group.

96. In combination, a plurality of telephone lines, a plurality of finder switches to the terminals of which said lines are multiplied, said finder switches being divided 5 into groups, corresponding groups of selectively operable switching devices, circuits connecting said finder switches of each group with the switching devices of the corresponding group, and means for making 10 the finder switches of one or another of said groups active to extend said lines to one or another of said groups of selectively operable switching devices.

97. In combination, a plurality of groups 15 of selectively operable automatic switching devices, each group being divided into sub-groups, means for extending calls thereto, a selecting circuit common to the sub-groups of each group of switching devices, and 20 means responsive to an abnormal condition of said selecting circuit of any group for causing said call-extending means to divert calls from said group of devices.

98. In combination, a plurality of operators' positions divided into groups, a plurality of switching devices for each group, means controllable by the operator for selectively operating any one of the switching devices associated with her position, a plurality 30 of groups of circuits, each group serving to extend calls to an associated group of switching devices, a switch at each operator's position operated when the corresponding position is vacant, and means responsive 35 to the coincident operation of all of said switches in a particular group of operators' positions for diverting calls from the group of circuits leading to the switching devices associated with such positions.

99. In combination, a plurality of groups 40 of selectively operable automatic switching devices, each group being divided into sub-groups, a corresponding plurality of groups of circuits, each of said groups of circuits serving to extend calls to the corresponding 45 group of switching devices, a switching mechanism associated with each sub-group of devices operated when all of the devices of the corresponding sub-group are in use, and means responsive to the coincident operation 50 of all of said switching mechanisms of a particular group for diverting calls from the aforesaid circuits leading to the associated group.

100. In combination, a group of selectively operable automatic switching devices, a group of circuits for extending calls thereto, and means made operative when the 60 group of devices to which said circuits extend becomes unavailable for handling calls to bar calls from the circuits of said group.

101. In combination, a plurality of telephone lines, two groups of selectively operable automatic switching devices, a switch 65 for making either of said groups of devices

the preferred group with respect to the extension thereto of calls from said telephone lines, and a switch under the control of the preferred group and adapted when operated to divert calls from said preferred group and direct them to the other or alternate group.

102. In combination, a plurality of telephone lines, a plurality of groups of operators' positions, automatic switching devices, connecting circuits at each position of each group, one end of said circuits terminating in contacts of one of said devices and the other end in contacts of another one of said devices, means for initiating calls from said telephone lines, automatic switching mechanism for directing an initiated call to a group of positions that is at that time available, means active in the extension of a call in a particular group for directing the call to an unengaged position of that group, and means made active in the extension of a call to an unengaged position for actuating said one of said devices to select an idle connecting circuit of that position, and operator-controlled means for actuating said other one of said devices to complete the connection with a called line.

103. In combination, a group of telephone lines, a group of selectively operable automatic switching devices, two sub-groups of circuits normally acting as a single group to extend calls from said group of lines to said group of switching devices, a switching mechanism for controlling the access of calls to said group of circuits, and means controlled by the unavailability of either sub-group of circuits for operating said switching mechanism to divert calls from that sub-group and confine them to the other sub-group.

104. In combination, a plurality of selectively operable automatic switching devices, a group of circuits for extending calls thereto, and an electro-magnetic switching mechanism for dividing said group of call-extending circuits into sub-groups and confining the calls to one of said sub-groups.

105. In combination, a plurality of selecting devices, incoming lines and groups of 115 outgoing lines, means for operating said devices in rotation, means responsive to the operation of a device for causing the connection of an incoming line with an outgoing line belonging to a certain group, means 120 for preventing the operation of a plurality of said devices, and means for causing the remainder of the devices to perform the selecting operations in rotation.

106. In a telephone exchange system, a 125 plurality of lines, operators' positions, a plurality of sets of relays each arranged to cause the connection of a calling line with a certain operator's position, means for controlling the operation of said sets of relays 130

in a certain order, means for preventing the operation of certain sets of relays, and means for causing the remainder of said sets of relays to operate in said certain order.

107. In a telephone exchange system, a calling and a called line, means including groups of switching devices for interconnecting said lines, a plurality of mechanisms for variably operating said switching devices, one mechanism being provided in common for each group of devices, means for extending calling lines to said switching devices, and means for preventing the extension of a calling line to a group of switching devices the mechanism associated with which is busy.

108. In a telephone system, a plurality of lines divided into groups, an operator's position, means including a conductor for extending any one of said lines to said operator's position, a device for producing different characteristic groups of impulses through said conductor, means for applying said groups to the different groups of lines to distinguish the lines of one group from the lines of another, an indicating device connected to said conductor at said position and variably operable under the control of said characteristic groups of impulses, a signal individual to each line, and means controllable over said conductor for actuating the signal of the calling line.

109. In a telephone system, a plurality of lines adapted for different classes of service, class-of-service identifying means associated with each of said lines, a line-identifying means permanently associated with each line, means for bringing said class-of-

service responsive device temporarily into association with each of said lines, and means operable at will for actuating the line-identifying signal of the line with which the class-of-service responsive device has been associated.

110. In a telephone exchange system, a plurality of lines, means including selectively operable switching devices and a trunk line for interconnecting two of said lines, a normally inactive controlling mechanism, means for adjusting said mechanism to control the operation of said switching devices, starting means for said mechanism, an operator's telephone set, a switch for connecting said operator's telephone set with said trunk line, and means responsive to the actuation of said starting means for disconnecting said operator's telephone set from said trunk line.

111. In a telephone exchange system, a plurality of lines, means including selectively operable switching devices and a trunk line for interconnecting two of said lines, a normally inactive controlling mechanism, means for adjusting said mechanism to control the operation of said switching devices, starting means for said mechanism, an operator's telephone set, a switch, means for actuating said switch upon the connection of a calling line with a trunk line for connecting said operator's telephone set with said trunk line, and means responsive to the operation of said starting means for actuating said switch to disconnect said operator's telephone set from said trunk line.

In witness whereof, I hereunto subscribe my name this 8th day of March A. D., 1919.

SAMUEL B. WILLIAMS, JR.
